2,244,901

ABSOLUTE PERMISSIVE BLOCK SYSTEM OF
RAILWAY SIGNALINGCrawford E. Staples, Wilkinsburg, Pa., assignor
to The Union Switch & Signal Company,
Swissvale, Pa., a corporation of Pennsylvania

Application January 26, 1940, Serial No. 315,801

39 Claims. (Cl. 246—33)

My invention relates to absolute permissive block (A. P. B.) systems of railway signaling and it has special reference to systems of this character wherein all major functions of signal control are performed without the aid of line wires and by means of coded energy that is transmitted through the track rails.

Generally stated, the object of my invention is to improve certain features of non-line-wire A. P. B. systems that utilize track circuits which operate on the "coded feed back" principle of Frank H. Nicholson Patent No. 2,021,944.

A more specific object is to improve the design and broaden the utility of track and other circuits of the "coded feed back" type.

Another object is to extend the number of signal control functions which such track circuits are capable of performing in systems of two-direction signaling.

An added object is to utilize these extended functions in such manner that each train coming into and passing through the two-direction running stretch automatically sets up its own directional protection and provides its own following protection wholly by means of the coded energy which the track circuits transmit.

An additional object is to provide for the approach energization of each and every signal in the non-line-wire A. P. B. system and in other respects to lower the power consumption of the system apparatus.

A further object is to reduce the quantity of the decoding and signal control apparatus which A. P. B. systems of the above referred to non-line-wire type require.

Still further objects are to provide for the non-line-wire A. P. B. control of either or both wayside signals and train-carried cab signals; to readily extend the number of indications which the controlled signals display; to adapt the improved A. P. B. system to automatic signal blocks which both do and do not contain cut sections; to make improved provision for controlling highway crossing signals which the named blocks may embrace; and to retain all of the advantages of continuously coded track circuits.

In practicing my invention I attain the above and other objects and advantages by equipping each of the track sections in the two-direction running stretch with track circuit facilities of the "coded feed back" type previously referred to; providing means that are responsive to the direction of train movement through the stretch and that at all times cause the recurring pulses of "master" code energy to be supplied to the

train exit ends of the stretch sections; imparting "normal" polarity to the "off" period pulses of "feed back" energy under vacant conditions of the stretch and using those normal polarity pulses to hold at "proceed" the headblock signals which guard the extreme ends of the stretch; reversing the polarity of the feed back pulses when a train comes into the stretch and using those "reverse" polarity pulses to put the opposing headblock signal at "stop" and thereby establish directional protection for the train; using the feed back pulses of both "normal" and "reverse" polarity to keep the system signals de-energized at all times except when indications must be displayed to an approaching train; and using the recurring pulses of "master" code energy to control the signals behind each train in customary automatic block manner whereby to provide following protection for the train.

I shall describe one representative form of A. P. B. signaling apparatus embodying my invention and shall then point out the novel features thereof in claims. This illustrative embodiment, together with supplemental showings of certain modified portions thereof, is disclosed in the accompanying drawings in which:

Figs. 1a to 1e, inclusive, are diagrammatic views which when placed end to end in the order named represent a stretch of two-direction running track that is equipped with A. P. B. signaling apparatus which embodies the improvements of my invention;

Fig. 2 is a diagrammatic showing of "master" and "feed back" codes which are suitable for controlling the apparatus of Figs. 1a—e;

Figs. 3 and 4 represent facilities which may be used to supply energy to certain portions of that apparatus;

Figs. 5 to 8, inclusive, are simplified showings of the "coded feed back" track circuits which are identified with the several track sections of Figs. 1a—e;

Figs. 9 and 10 are single line representations of the track stretch of Figs. 1a—e showing the trackway codes and the wayside signal indications that are effective under various traffic conditions of the stretch;

Figs. 11 to 14 show alternative forms which certain of the relay control circuits of Fig. 1 may take;

Fig. 15 is a representation of cab signaling apparatus which may be controlled by the trackway equipment of the preceding figures;

Fig. 16 shows an adaptation of the A. P. B.

system apparatus of Fig. 1 to the control of wayside signals of the searchlight type; and

Fig. 17 shows an alternative arrangement for controlling certain of the signals in the A. P. B. system.

In the several views of the drawings, like reference characters designate corresponding parts. To facilitate the description of the various circuit diagrams of these views, it will be assumed that the left end thereof is west and the right end is east. Hence train movements in the direction of from left to right will be spoken of as "eastbound" and movements in the direction of from right to left will be spoken of as "westbound."

Referring first to the composite diagram of Figs. 1a-e, the improvements of my invention are there disclosed as being incorporated in a system of absolute permissive block (A. P. B.) signaling for a stretch of single track 1-2 which extends from a first passing siding WPS (Fig. 1a) to a second passing siding EPS (Fig. 1e) and over which traffic may move in either direction. The usual insulated joints 3 divide the rails 1 and 2 of this stretch into the customary plurality of successive track sections I-II, II-III, III-IIIa and IIIa-IV and the rails of each of these sections form a part of a "coded feed back" track circuit combination which will be described presently.

Positioned at the locations I, II, III and IV of track section division are wayside signals SE which are arranged to govern eastbound traffic through the track stretch and other wayside signals SW which similarly are arranged to govern the passage of westbound trains over the track. These signals may, of course, be of any suitable form such as of the color light type of Fig. 1, the searchlight type of Fig. 16, or any other equivalent type not shown. When of the color light type of Fig. 1, each of the named signals includes three lamps G, Y and R which when selectively lighted respectively display the indications of green or "clear," yellow or "approach," and red or "stop."

The signal SEI at the west end I of the represented stretch of A. P. B. track governs the entry of eastbound traffic into that stretch while the signal SWIV at the opposite or east end IV similarly controls the entry of westbound traffic into the stretch. To distinguish the two just named "headblock" signals from the remaining signals of the system, they are provided with a fourth lamp which is constantly illuminated in the manner represented at M.

The location IIIa of the composite diagram of Fig. 1 marks a cut in the main signal block III-IV and hence it has no wayside signal associated with it. Such a cut may, of course, be occasioned by excessive block length, by an intersecting highway such as is indicated at 4, or for any other reason. At the intersection which is represented in Fig. 1d, a highway crossing signal XS is installed in the usual way.

The particular stretch of two-direction running track that is represented in Figs. 1a-e thus includes (between the end or headblock signal locations I and IV) two "intermediate" locations II and III at which wayside signals SE and SW are provided and one cut section location IIIa with which a highway crossing signal XS is associated. Alternatively, of course, the stretch may include either a greater or lesser number of these intermediate and cut section locations. Moreover, all of the intermediate lo-

cations need not necessarily have the represented double signals (eastbound SE and westbound SW) associated therewith as some may instead be provided with only one of these signals or with no wayside signal at all.

When applied to the multi-section stretch of single track 1-2 of the composite diagram of Fig. 1, the improved organization of apparatus and circuits of my invention enables the trains themselves automatically to control the traffic governing signals SE and SW in the typical A. P. B. manner which is indicated in Figs. 9 and 10. This form of control permits two more trains to follow each other through portions of

15 the single track that extend between passing sidings and at the same time prevents a train from entering the single track stretch when that stretch is occupied by another train moving in the opposite direction. In the represented 20 scheme of my invention, moreover, this A. P. B. control of the system signals is effected without the aid of line wires and wholly by means of coded energy which is transmitted through the track rails.

25 *Coded feed back track circuits and reversing means therefor*

This novel and advantageous form of A. P. B. control is made possible by operating two coded

30 track circuits simultaneously on each of the sections I-II, II-III, III-IIIa and IIIa-IV into which the track 1-2 of Fig. 1 is divided. One of these track circuits transmits recurring pulses of "master code" energy over the section rails in one direction and it will be referred to as the first or "master" track circuit; the other transmits "off" period pulses of "feed back" energy over the section rails in the opposite direction and it will be referred to as the second or "feed 35 back" track circuit. To designate both of these simultaneously operating track circuits, use will be made of the expression "coded feed back" track circuit combination.

One elementary form of such a combination 40 is disclosed and claimed in the before referred to Nicholson Patent No. 2,021,944. In the "coded feed back" track circuit combination of that patent the direction of transmission of the "master code" pulses is always the same; the direction of transmission of the "feed back" pulses likewise never changes; and the character of these feed back pulses is never altered in a selectively distinctive way.

As utilized by the non-line-wire A. P. B. system of my invention the "coded feed back" track circuits now about to be described possess a number of added refinements and they are; moreover, novelly arranged to have all three of the just named factors variously change in response to the passage of trains through the circuited sections of the two-direction running track. In the case of the first two named factors (directions of "master" and "feed back" energy transmission) these changes are effected by traffic directional relays TD that, in the manner shown, are installed at all of the intermediate locations (II, III and IIIa) in the system.

At times these traffic directional relays TD hold their contacts in the right-biased position and they then set up the several "coded feed back" track circuit combinations of the stretch in the manner which is shown in Figs. 1a-e, 5a, 6a and 7a; at other times, however, all of the relays TD shift their contacts to the left and they then transfer the track circuit set-ups to the re-

versed relation which is represented in Figs. 5b, 6b and 7b. The set-up first named is in effect when the stretch is conditioned for the passage of "eastbound" trains while the reversed set-up is in effect when the stretch is conditioned for the passage of "westbound" trains.

During the first or "eastbound set-up" of the track circuits the "master code" energy is transmitted in the direction of from east to west (or towards the approaching eastbound traffic) while the "feed back" energy is transmitted in the opposite or west-to-east direction. This relation is most clearly represented in Figs. 9a-c and 10d. It, of course, requires that the "master" energy supply facilities be located at the east end of each section and that the "feed back" energy supply facilities be located at the opposite or west end. Such a positioning is shown in Figs. 5a, 6a, 7a and 8.

During the reversed or "westbound set-up" of the track circuits the "master code" energy is transmitted in the direction of from west to east (or towards the approaching westbound traffic) while the "feed back" energy is transmitted in the opposite or east-to-west direction. This relation is most clearly represented in Figs. 10a-c and 9d. It requires that the "master" energy supply facilities be located at the west end of the section and that the "feed back" energy supply facilities be located at the opposite or east end. Such a positioning is shown in Figs. 5b, 6b and 7b.

As each of the "coded feed back" track circuit combinations which the simplified diagrams of Figs. 5, 6, 7 and 8 represent is distinctive in certain of its details, these drawing views will be considered individually. As has already become evident, Figs. 5a-b show the track circuits which are identified with track section I-II of the complete stretch of Fig. 1; Figs. 6a-b show the track circuits for section II-III; Figs. 7a-b show the circuits for section III-IV; and Fig. 8 shows the track circuits for an end section which spans one of the passing sidings PS.

Looking first at the track circuits for section I-II, the "eastbound set-up" thereof is represented in Fig. 5a and the "westbound set-up" in Fig. 5b. These two set-ups may be distinguished from each other by the traffic direction arrows (left-to-right for "eastbound" and right-to-left for "westbound") and also by the interchanged relation of the "master" and "feed back" ends.

In each of the two set-ups both of the before referred to "master" and "feed back" track circuits include the section rails 1 and 2. In the eastbound set-up of Fig. 5a the "master" circuit further includes an energy source TB and a code repeating relay CR installed at the section east end II and a code following track relay NKE (together with a companion relay RKE) installed at the section west end I; in this same eastbound set-up, likewise, the "feed back" circuit further includes an energy source KB and a rail connection transfer device CRW located at the section west end and a pair of polarized track relays RK and NK installed at the section east end.

The just mentioned energy sources TB and KB preferably are direct current track batteries and may be of any suitable type, such as primary, storage or the like. Alternatively, of course, these direct current sources also may take the form of rectifier units (not shown) which convert alternating current energy from a commercial supply source into the required direct current.

The code repeating relay CR for the "master" track circuit of Fig. 5a functions through a con-

tact 6 thereof; (1) periodically to connect the "master" track battery TB in energy supplying relation with the section rails for the purpose of producing one or the other of the two "master" codes of Fig. 2; and (2) to connect the "feed back" circuit track relays RK and NK in energy receiving relation with those rails during each "off" period of the thus supplied master code. Current for operating this relay CR is supplied to the winding thereof by way of a circuit that includes one or the other of a pair of coding contacts 180 and 75 selected over a contact 7 of a relay H (later to be described).

In the particular arrangement shown, these coding contacts 180 and 75 form parts of two separate code transmitters CT180 and CT75 each of which actuates the contact at its distinctive preselected speed. For purposes of explanation it will be assumed that the speed of up and down movement effected by contact 180 is such as to produce the 180 pulse per minute "master clear" code of Fig. 2 and that the speed of actuation of contact 75 is such as to produce the 75 pulse per minute "master approach" code of Fig. 2. Instead of forming parts of the represented separate coder units the two contacts 180 and 75 may, of course, be included in a single transmitting device having the usual common driving mechanism which actuates the two contacts at the required different distinctive speeds.

The master circuit track relay NKE (at the section west end) is a code following device which responds only to positive or "normal" polarity energy and which has a control winding 8 that is connected in energy receiving relation with the section rails over the back point of a contact 9 of the before named device CRW. This relay NKE is provided with contacts 11 and 12 which pick up during each "on" period of master code energy that the control winding receives and which release during each master code "off" period. Serially included in the control winding connection of device NKE is a companion code following relay RKE which responds only to negative or "reverse" polarity energy and which performs a function later to be described in connection with Fig. 5b.

Coding of the energy which the "feed back" track battery KB (at the section west end) supplies to the section rails is performed by back contact 11 of the master circuit track relay NKE aided by contact 9 of the just mentioned device CRW. That device receives pick-up current over front contact 12 of relay NKE and has a period of release delay which is slightly less than the "off" period length of the fastest "master" code to which relay NKE is called upon to respond. In a manner which will presently become apparent, the just named contacts 9 and 11 transmit "feed back" energy to the section rails during the "off" periods of the master trackway code that is received by relay NKE.

Each pulse of this "feed back" energy constitutes an "on" period in one of the "feed back" codes of Fig. 2. From an inspection of that figure it will be seen that the "on" periods of each of the there shown "feed back" codes coincide with the "off" periods of the master" code which is represented immediately thereabove, and vice versa. This relation allows the "master" and the "feed back" track circuits simultaneously to operate over the same section rails without interfering with each other.

The feed back circuit track relay NK (at the section east end) also is a code following device

which responds only to positive or "normal" polarity energy and which has a control winding 8 that during the "off" periods of the before described "master" trackway code is connected in energy receiving relation with the section rails over the back point of contact 6 of the before described code repeating relay CR. Serially included in the represented connections is a companion code following relay RK which responds only to negative or "reverse" polarity energy and which performs a function later to be described in connection with Fig. 5b.

As already indicated, the "feed back" circuit track relays NK and RK (at the section east end) are both disconnected from the section rails (under the action of contact 6 of device CR) during the "on" periods of the there supplied "master" code. This disconnection prevents the "master" track circuit energy from reaching those relays and thus renders them responsive only to energy that is supplied to the rails from the feed back track battery KB at the section west end.

As will become more evident presently, the master circuit track relay NKE (and device RKE also) at the section west end is similarly disconnected from the section rails (under the action of contact 9 of device CRW) during the "on" periods of the there supplied "feed back" code and in that manner those relays are rendered responsive only to energy that is supplied to the rails from the master track battery TB at the section east end.

In operation of those basic portions of the "master" and "feed back" track circuits for section I-II which are shown in Fig. 5a (for the eastbound set-up of the section), the code repeating relay CR at the east end of the section acts as a "master" device in that it sets the rate at which the pulses of both the "master" and the "feed back" trackway codes recur. This rate, in turn, is determined by which of the coding contacts 75 and 180 is included (under the selecting action of relay H) in the driving circuit for the code repeating relay CR.

As already indicated, both of these coding contacts move (each at a distinctive rate) between an upper position and a lower position. When in the upper position the selected or active contact completes for the code repeating relay CR a pick-up circuit which may be traced from the positive terminal of a suitable supply source (such as a local control battery of the type shown at CB in Fig. 3), through one or the other of coding contacts 180 and 75, contact 7 of relay H, conductor 13 and the winding of relay CR, back to the negative terminal of the control source.

By picking up contact 6 of relay CR, each of these completions constitutes an "on" period of one of the "master" codes of Fig. 2 and causes the track battery TB to energize the master circuit track relay NKE (at the section west end) over a circuit which extends from the positive terminal of that battery through conductor 14, the secondary of a transformer 15, conductors 16 and 17, a contact 18 of the traffic directional relay TD, conductor 19, track rail 2, conductors 21 and 22, the control winding 8 of relay NKE, relay RKE, conductor 23, back contact 9 of relay CRW, conductor 25, track rail 1, conductor 26, contact 27 of relay TD, conductor 28, front contact 6 of device CR and a current limiting impedance 29 back to the negative terminal of battery TB.

In responding to each of the thus supplied en-

ergizing pulses, relay NKE picks up and causes contact 11 to disconnect the feed back battery KB from the section rails and thereby produce a feed back code "off" period. At the same time 5 contact 12 of relay NKE energizes device CRW over a circuit extending from the positive terminal of a local supply source (which again may take the form of a control battery such as is shown at CB in Fig. 3), through front contact 12, conductor 31 and the winding of device CRW back to the negative terminal of the control source.

Device CRW now picks up contact 9 and thereby transfers the connection of track circuit conductor 25 from conductor 23 to a conductor 32. Even under this new condition, however, relay NKE continues its energy receiving connection with the track rails but by way of a by-pass which includes a conductor 33, front contact 11 15 of relay NKE, conductor 32 and front contact 9 of device CRW. This by-pass path is established early in the master code "on" period (contact 9 included therein picks up with sufficient rapidity to insure that relay NKE will not falsely release during the transfer of its supply connection from the back point of contact 9 to conductors 33 and 32) and once set up the by-pass path continues uninterruptedly until the end of the master code "on" period during which it 20 occurred.

In going to the lower position at the end of the master code "on" period, the active coding contact (180 or 75 code) at the east end of the section interrupts the energizing circuit for code 25 repeating relay CR, that action releases contact 6 of the repeating relay, and that release marks the beginning of a master code "off" period. During each of those "off" periods, the just 30 named contact 6 connects the feed back circuit 30 track relays NK and RK in energizing receiving relation with the track rails.

At the same time (that is, during each master code "off" period) the master circuit track relay NKE at the section west end becomes deenergized 45 and it releases in the usual manner. That release, in turn, marks the beginning of an "on" period of one of the "feed back" codes of Fig. 2.

Incident thereto there is completed (at contact 11) a circuit over which battery KB at the 50 feed back end of the section energizes the track relays NK and RK at the east section end. This circuit may be traced from the positive terminal of track battery KB through conductor 34, the current limiting impedance 35, conductor 21, track rail 2, conductor 19, contact 18 of relay TD, conductor 17, control winding 8 of relay NK, relay RK, conductor 36, back contact 6 of device CR, conductor 28, contact 27 of relay TD, conductor 26, track rail 1, conductor 25, front contact 9 of device CRW, conductor 32, back contact 11 of relay NKE, conductor 31, the secondary of a transformer 15 and conductor 38 back to the negative terminal of battery KB.

Each of the above transmitted pulses of feed 65 back energy is effective for picking up relay NK but does not produce any response on the part of the companion device RK (due to the before explained polarized characteristics of these feed back circuit devices). At the opposite or west end of the section, the rail disconnecting action 70 of the now released contact 11 of the relay NKE prevents that relay from responding to the feed back code energy with which the section rails are supplied.

During the entire length of this pulse, of

course, contact 9 of device CRW remains picked up. Prior to the end of each master code "off" period, however, this contact 9 of device CRW releases and interrupts the above traced energy supply circuit. As already stated, the device just named has a period of release delay which is slightly less than the shortest "off" period of any of the master codes which the system employs.

As has been seen, moreover, the energizing circuit for this device CRW is interrupted at contact 12 of relay NKE at the beginning of the master code "off" period. This interruption starts the release timing and thus causes each pulse of "feed back" code energy to have a length which is the same as that of all other pulses of that energy and the magnitude of which is indicated at f in Fig. 2. This action, of course, explains why the feed back energy pulses which recur at the slow rate of 75 times per minute are no longer than the feed back energy pulses which recur at the higher rate of 180 pulses per minute.

In releasing as just described, device CRW terminates the feed back code "on" period and conditions the master circuit track relay NKE for a reception of and a response to a succeeding pulse of master code energy. That pulse is supplied to the section rails when the code repeating relay CR at the section east end again moves its contact 6 to the picked up position.

When that happens the just described cycle of two-direction coded track circuit operation starts to repeat itself. In the manner just outlined, therefore, the "master" and the "feed back" track circuits operate over the same section rails simultaneously and without interfering with each other. This lack of interference, as has been stated, results from the fact that each "on" period of the "feed back" code is supplied during an "off" period of the "master" code and vice versa.

The coded feed back track circuits which have just been described for track section I-II operate under conditions of the A. P. B. system of Fig. 1 wherein traffic movement through the section in the eastbound direction is authorized. As has been seen, master code energy then is supplied to the east end II of the section and feed back energy then is supplied to the west end I thereof.

For system conditions wherein traffic movements in the opposite or westbound direction are authorized the set-up of the track circuit for section I-II is modified to the extent indicated in Fig. 5b. As previously pointed out, this modification is effected by the traffic directional relay TD through a shift of its contacts 18 and 27 from the right-hand position represented in Fig. 5a to the left-hand position represented in Fig. 5b. A later portion of the specification describes the manner in which this shift of traffic directional relay contacts is produced.

When made, the effect is to transfer the master end of the coded feed back track circuits for section I-II from the east end II to the west end I of the section and to substitute at the east end II the feed back end equipment of Fig. 5b for the master end equipment which is shown in Fig. 5a.

In the westbound traffic set-up of Fig. 5b, the battery KB at the west location I constitutes the source of master code energy; device CRW at the same location serves to code this energy by periodically connecting battery KB in energy sup-

plying relation with the section rails under the control of one or the other of a pair of code transmitters CT180 and CT75 selected over a contact 39 of a relay NP; and the thus coded master energy is transmitted eastwardly over the section rails to a code following track relay TR at the section east end II.

This track relay TR may be of conventional code following design and in the particular arrangement shown it receives the recurring pulses of master code energy over the back point of a contact 41 of an impulse relay KR. That impulse relay, in turn, likewise forms a part of the substituted feed back end facilities at the east location II. Also comprised by the same facilities are a source of feed back energy represented as a track battery KB and a relay KS which selects the polarity of the energy which this battery supplies to the track rails during the master code "off" periods under the control of relays KR and TR.

The function of the impulse relay KR is to transfer the connection of the track rails 1 and 2 from the track relay TR to battery KB during each "off" period of the master code energy which is received by relay TR. Pick-up current is supplied to relay KR over the front point of a contact 42 of relay TR during each "on" period of the received master code. During the "off" periods of that code the impulse relay is deenergized and contact 41 thereof then occupies the lowermost position (shown in full lines) in which it connects the operating winding of the track relay TR directly across the section rails. As in the case of device CRW which was described in connection with Fig. 5a, this relay KR has a release delay period which is slightly less than the shortest "off" period length of any of the master codes which the system employs.

In picking up in response to each received pulse of master code the track relay TR completes (at contact 42) for relay KR an energizing circuit which may be traced from the positive terminal of battery KB through conductor 43, the winding of relay KR, conductor 44, front contact 42 and conductor 45 back to the negative terminal of battery KB. This energization causes relay KR to move contact 41 upwardly into the picked up position (shown dotted) wherein it disconnects the track rails from relay TR. This disconnection, however, is now bridged by a contact 46 of relay TR over the front point of which the winding of that relay continues to be connected with the rails during the full continuance of the energy pulse.

At the end of that pulse relay TR releases and contact 46 now breaks the connection of its winding with the track rails. At the same time contact 42 connects those rails in energy receiving relation with the battery KB at location II by way of a circuit which includes front contact 41 of relay KR. That relay having the before-described releasing characteristics, contact 41 is released before the beginning of the succeeding "on" period of the received master code.

If the polarity selector relay KS is picked up as shown, contacts 47 and 48 thereof establish a circuit over which the battery KB at location II supplies positive or "normal" polarity energy to the section rails during each "off" period of the received master code. If, however, the contacts 47 and 48 of relay KS are released, the polarity connections of battery KB are reversed and in that event the battery supplies the section rails with feed back energy of negative or "re-

verse" polarity during each master code "off" period.

At the west location I of the section this feed back energy is received from the rails and impressed upon the control windings 8 of relays NKE and RKE over a circuit which includes the back point of contact 9 of master code repeating device CRW and which is completed during each master code "off" period. If this feed back energy is of normal polarity (as determined by the picked up condition of relay KS at location II) relay NKE responds to each of the recurring pulses thereof while if the received feed back energy is of "reverse" polarity (as determined by the released position of relay KS at location II), then relay RKE is picked up by each of the recurring pulses thereof.

Comparing the diagram of Fig. 5b with that of Fig. 5a, it will be seen that in both the westbound and the eastbound traffic set-ups for the section I-II, use is made of the same devices KB, CRW, NKE and RKE at the west location I. In the westbound set-up of Fig. 5b, however, device CRW acts as a code repeating relay for the master code transmitters CT180 and CT175 at location I; battery KB acts as a source of master code energy rather than of feed back code energy as in Fig. 5a; and code following relays NKE and RKE are included in the feed back track circuit rather than in the master track circuit.

The manner in which the master and the feed back track circuits of Fig. 5b operate over the rails of section I-II during the westbound set-up thereof will have become more or less apparent from the foregoing description. Depending upon whether contact 39 of relay NP at the west end of the section is picked up or released, the there locate ddevice CRW moves its contact 9 up and down at the rate of 180 times per minute or at the rate of 75 times per minute. This movement results from device CRW receiving recurring pulses of pick-up current over a circuit which may be traced from the positive terminal of a local control source through either contact 180 of device CT180 or contact 75 of device CT175, contact 39 of relay NP, conductor 31 and the winding of device CRW back to the negative terminal of the control source.

Each time that contact 9 is picked up, battery KB at location I energizes relay TR at location II over a circuit which may be traced from the positive terminal of the battery through conductor 34, impedance 35, conductor 21, track rail 2, conductor 19, contact 18 of relay TD, conductors 49 and 51, the winding of relay TR, conductor 52, back contact 41 of relay KR, conductor 53, contact 27 of relay TD, conductor 26, track rail 1, conductor 25, front contact 9 of device CRW, conductor 32, back contact 11 of relay NKE, conductor 37, the secondary of transformer 15, and conductor 38 back to the negative terminal of battery KB.

Relay TR at location II, picks up in response to each of these pulses of master code energy and in so doing completes for impulse relay KR an energizing circuit which extends from the positive terminal of battery KB (at the same location) through conductor 43, the winding of relay KT, conductor 44, front contact 42 of relay TR and conductor 45 back to the negative terminal of battery KB. At the same time contact 46 of relay TR puts around the back point of contact 41 of relay KR a by-pass connection which may be traced from conductor 52 through conductor 54, front contact 46 and conductor 55

back to conductor 53 of the track relay energizing circuit.

Impulse relay KR now picks up contact 41 setting up over the front point thereof a circuit 5 over which battery KB at location II supplies the section rails with feed back energy during the succeeding "off" period of the received master code. At the beginning of that succeeding "off" period, relay TR releases, and that release disconnects the relay operating winding from the track rails at contact 46 and completes over the back point of contact 42 the before referred to feed back energizing circuit.

With the polarity selector relay KS in the 15 represented picked up position, the now supplied feed back energy is of positive or "normal" polarity and when transmitted over the track rails to location I, it flows over the now released contact 9 of device CRW through the control windings of relays NKE and RKE and causes normal 20 polarity relay NKE to pick up. The circuit over which it is transmitted may be traced from the terminal of battery KB at location I, through conductors 43 and 56, front contact 47 of relay 25 KS, conductors 57, 58 and 49, contact 18 of relay TD, conductor 19, track rail 2, conductors 21 and 22, control winding 8 of relay NKE at location I, relay RKE, conductors 23 and 24, back contact 9 of relay CRW, conductor 25, track rail 30 1, conductor 26, contact 27 of relay TD, conductor 53, front contact 41 of relay KR, a current limiting impedance 59, conductor 61, contact 48 of relay KS, conductor 62, back contact 42 of relay TR, and the conductor 45 back to the 35 negative terminal of battery KB at location II.

If the polarity selector relay KS is released 40 the feed back energy which is supplied during each "off" period of the master code that is received at location II has the negative or "reverse" polarity, and it then picks up relay RKE at location I instead of relay NKE. The circuit over which it is transmitted to relay RKE may be traced from the positive terminal of battery KB at location II, through conductors 43 and 56, back contact 47 of relay KS, conductor 61, impedance 59, front contact 41 of relay KR, conductor 53, contact 27 of relay TD, conductor 26, track rail 1, conductor 25, back contact 9 of device CRW, conductors 24 and 23, the control winding 8 of relay RKE at location I, relay NKE, conductors 22 and 21, track rail 2, conductor 19, contact 18 of relay TD, conductors 49 and 58, back contact 48 of relay KS, conductor 62, back contact 42 of relay TR and conductor 55 45 back to the negative terminal of battery KB.

Each thus supplied pulse of feed back energy is interrupted at location II by the release of contact 41 of relay KR prior to the beginning of the succeeding "on" period of master code 60 energy with which the section rails are supplied at location I. This release of contact 41 restores the connection of the master circuit track relay TR with the section rails and thus conditions that relay for reception of and response to the next pulse of master energy.

That pulse is supplied when contact 9 of device CRW at location I is again moved to its uppermost position. When that happens the just described cycle of two-direction coded track 70 circuit operation starts to repeat itself. In the manner just outlined, therefore, the "master" and the "feed back" track circuits for the westbound set-up (Fig. 5b) of section I-II operate over the section rails simultaneously and without interfering with each other.

Looking next at the "coded feed back" track circuits of section II-III, the eastbound set-up therefor is represented in Fig. 6a and the westbound set-up in Fig. 6b. As the view of Fig. 6a indicates, both the "master" and "feed back" track circuits of the eastbound set-up include the section rails 1 and 2; the "master" circuit further includes an energy source TB and a code repeater relay CR installed at the section east end III and a code following track relay TR installed at the section west end II; and the "feed back" circuit further includes an energy source KB together with impulse and polarity selecting relays KR and KS located at the section west end and a pair of code following track relays RK and NK installed at the section east end.

Comparing the diagram of Fig. 6a with that of Fig. 5b, it will be seen the eastbound set-up for section II-III utilizes the same feed back apparatus at the west location II as is used at the east end II of section I-II under westbound set-up conditions thereof. Comparing the diagram of Fig. 6a with that of Fig. 5a it will further be seen that the eastbound set-up of section II-III makes use at the east end III thereof of master end apparatus which is a duplicate of that used at the east location II of section I-II under eastbound set-up conditions of that previously described section.

In the latter case, the duplication of the master end equipment extends even to the right biased contacts 18 and 27 of the traffic directional relay TD and the conductors 19 and 26 with which these contacts are joined with the section rails. In the former case, moreover, it will be seen that the feed back end apparatus at location II in the eastbound set-up of section II-III is not only a duplicate of but actually consists of the same devices TR, KR, KS and KB as are connected over left biased contacts 18 and 27 of relay TD at location II with the rails of section I-II in the westbound set-up of that section.

In the eastbound set-up of section II-III, however, the connection of this feed back apparatus is with the rails of section II-III by way of conductors 63 and 64 and a second pair of contacts 65 and 66 of traffic directional relay TD at location II. As shown in Fig. 6a, these contacts are biased to the right.

In operation of the master and feed back track circuits of Fig. 6a, code repeating relay CR at the east location III recurrently picks up and releases contact 6 thereof either at the rate of 180 times per minute or at the rate of 75 times per minute, depending upon whether contact 1 of code selector relay H is picked up or released. Each pick-up of contact 6 connects the battery TB in energy supplying relation with the section rails and causes those rails to transmit a pulse of master code energy to the master circuit track relay TR at the west location II.

In response to each of the above pulses which are received at location II, relay TR picks up, completing at contact 42 an energizing circuit for relay KR and establishing at contact 46 a by-pass around the back point of contact 41 of relay KR. Relay KR now picks up this contact 41 and thereby sets up a circuit over which battery KB will supply feed back energy to the section rails during the succeeding master code "off" period.

At the beginning of that "off" period, relay TR releases, disconnecting its operating winding from the section rails at contact 46 and completing at contact 42 the feed back energy sup-

ply circuit. This circuit includes front contact 41 of relay KR and is maintained completed until that relay releases, which it does after time f of Fig. 2. If polarity selector relay KS is picked up the section rails now receive from battery KB at location II a pulse of positive or "normal" polarity feed back energy while if relay KS is released the polarity of this feed back energy will be negative or "reverse."

At the master end location III this pulse of feed back energy is transmitted over the back point of contact 6 of relay CR to the feed back circuit track relays RK and NK. If the energy is of "normal" polarity relay NK responds thereto while if of "reverse" polarity relay RK is picked up thereby.

At the end of the master code "off" period contact 6 of repeating relay CR again returns to the uppermost position and thus marks the beginning of another master code "on" period. Prior to that beginning, however, the release of relay KR at location II has reconnected the master relay TR with the section rails and thus conditions that relay for reception of and response to a succeeding master energy pulse.

With that pulse the just described cycle of two-direction coded track circuit operation repeats itself and in the manner just outlined the "master" and the "feed back" track circuits for the eastbound set-up of section II-III operate over the same section rails simultaneously and without interfering with each other.

When the direction of authorized traffic through section II-III is westbound, the master and the feed back track circuits for this section are modified to the extent indicated in Fig. 6b. As is there shown, the master end is now at the west location II while the feed back end is at the east location III. This change is due to a shift from the right to the left positions of contacts 65 and 66 of the traffic directional relay TD at location II and of contacts 18 and 27 of the corresponding relay TD at location III.

In this westbound set-up for section II-III the section rails 1 and 2 are included in both the master and the feed back track circuits for the section. Further included in the master circuit is the previously described energy source TB and the code repeating relay TR at the west location II and a code following track relay TR at the east location III. Further included in the feed back circuit for the section are an energy source KB and impulse and polarity selecting relays KR and KS at the east location III and the previously described code following track relays RK and NK at the west location II.

Comparing the diagram of Fig. 6b with that of Fig. 5a, it will be seen that the master end equipment at location II which the westbound set-up of section II-III utilizes is constituted of the same elements TB, CR, RK, NK, TD, H, CT15 and CT180 as are used by the eastbound set-up for section I-II at the master location II of that set-up. In Fig. 6b, it will be seen that this master end equipment is connected with the rails of section II-III by way of conductors 63 and 64 and the second pair of contacts 65 and 66 of relay TD. This traffic directional device TD is the same relay as is represented in Fig. 5a.

Comparing the diagram of Fig. 6b with that of Fig. 5b, it will be seen that the westbound set-up of section II-III makes use at the east location III of feed back apparatus which in all respects is a duplicate of that utilized at the east location II in the westbound set-up for section I-II.

This identity extends even to the section rail connection wherein conductors 19 and 26 and left biased contacts 18 and 27 of relay TD are included.

In operation of the coded feed back track circuits of the westbound set-up for section II-III, the code repeating relay CR at location II recurrently picks up and releases its contact 6 either at the rate of 180 times per minute or at the rate of 75 times per minute, depending upon whether contact 1 of code selector relay H is picked up or released. Each pick-up of this contact 6 causes the source TB to impress upon the section rails a pulse of master code energy which is transmitted over those rails to the master circuit track relay TR at the east location III.

Each pick-up of relay TR by-passes at contact 46 the back point of contact 41 of relay KR and completes at contact 42 the energizing circuit for relay KR. That relay now picks up and sets up at contact 41 a circuit over which the feed back source KB supplies during the succeeding master code "off" period the section rails with a pulse of feed back energy having either "normal" or "reverse" polarity, depending upon whether relay KS is picked up or released.

This feed back pulse is impressed upon the rails when contact 6 of relay CR at location II goes to its lowermost position and thus deenergizes relay TR at location III. When that happens contact 46 of relay TR disconnects the relay winding from the rails while contact 42 deenergizes the impulse relay KR and completes the feed back supply circuit over the back point thereof.

If relay KS is picked up the thus supplied feed back energy is of "normal" polarity and in being transmitted over the rails and the back point of contact 6 of relay CR to the feed back circuit track relays NK and RK at location II it causes relay NK to respond. If, however, this feed back energy is of "reverse" polarity, as determined by a released condition of relay KS, it then is effective to pick up relay RK at location II.

At the end of the release period of relay KR contact 41 thereof drops and thus terminates the feed back pulse and conditions the relay TR for reception of and response to the succeeding pulse of master code energy. This pulse is supplied when contact 6 of relay CR at location II returns to its uppermost position.

When that happens the just described cycle of coded feed back track circuit operation for the westbound set-up of section II-III starts to repeat itself and in the manner just outlined the "master" and the "feed back" track circuits operate over the rails of this section simultaneously and without interfering with each other.

Looking next at the "coded feed back" track circuits for section III-IV, the eastbound set-up thereof is represented in Fig. 7a and the westbound set-up in Fig. 7b. As shown in Fig. 1, this signal block III-IV includes a cut location IIIa. In Figs. 7a-b, however, none of the details of the apparatus which is installed at this cut have been represented.

Instead the rails 1 and 2 of the two sections of the block which adjoin at the cut are shown as there being joined in the staggered manner indicated in dotted lines. As is described in a later portion of this specification, the cut section facilities at location IIIa of Fig. 1 serve to repeat the coded energy in a manner causing the equipments at the two ends of the block III-IV to act on each other in the same manner as

were the broken line rail connections of Figs. 7a-b to be made. Hence, in order to simplify explanation of the coded feed back track circuits of Fig. 7 it will be assumed that such staggered connections actually do exist at the cut location IIIa.

As the view of Fig. 7a indicates, the section rails 1 and 2 are included in both of the referred to "master" and "feed back" track circuits for the eastbound set-up of section III-IV. Further included in the "master" circuit is an energy source TB and a code repeating relay CRE installed at the section east end IV and a code following track relay TR installed at the section west end III. Similarly, the represented "feed back" circuit further includes an energy source KB and impulse and polarity selecting relays KR and KS located at the section west end III and a pair of polarized track relays RK and NK installed at the section east end IV.

Comparing the diagram of Fig. 7a with that of Fig. 5b, it will be seen that the eastbound set-up for section III-IV makes use at the west location III of feed back equipment which is a substantial duplicate of the corresponding equipment shown at location II for the westbound set-up of section I-II. From this comparison it will likewise be seen that the master end equipment at the east location IV in the eastbound set-up of section III-IV also corresponds very closely to the master end equipment which section I-II utilizes at the west location I.

In the latter connection relays RK and NK correspond to and have the same characteristics as the devices RKE and NKE of Fig. 5b. Code repeating relay CRE corresponds to and has the same characteristics as device CRW of Fig. 5b and the battery TB of Fig. 7a performs the same function as does battery KB of Fig. 5b. Still further, device CRE of Fig. 7a is selectively energized over contacts 180 and 75 of code transmitters CT180 and CT75 over a selector contact 67 of a relay HW which corresponds to device NP of Fig. 5b.

Comparing the diagram of Fig. 7a with that of Fig. 6b, it will also be seen that the feed back end equipment at location III in the eastbound set-up for section III-IV makes use of the same elements KB, KS, KR, TR and TD as are utilized at location III in the westbound set-up for section II-III. Instead of being connected with the section rails over left biased contacts 18 and 27 of relay TD, these devices are connected with the rails of section III-IV at the west end thereof over right biased contacts 65 and 66 of the traffic directional relay TD.

In operation of the coded feed back track circuits for the eastbound set-up of section III-IV, code repeating relay CRE at location IV recurrently picks up and releases its contact 9 either at the rate of 180 times per minute or at the rate of 75 times per minute, depending upon whether contact 67 of relay HW is picked up or released. Each pick-up of contact 9 causes the track battery TB at location IV to impress upon the section rails a pulse of "master code" energy which is transmitted westwardly to the master circuit track relay TR at location III.

In receiving that master code pulse at location III, relay TR picks up, completing at contact 46 a by-pass path around the back point of contact 41 of relay KR and completing at contact 42 an energizing circuit for the impulse relay KR. Thus energized, that device picks

up contact 41 and sets up a circuit over which battery KB supplies during the next master code "off" period the section rails with a pulse of feed back energy which is either of "normal" or "reverse" polarity, depending upon whether relay KS is picked up or released.

When contact 9 of device CRE at location IV moves to its lowermost position, the pulse of master code energy is interrupted and the relay TR at location III then becomes deenergized and releases. In so doing contact 43 disconnects the relay winding from the section rails while contact 42 deenergizes the relay KR and completes the before referred to feed back supply circuit over which battery KB transmits feed back energy to the section rails.

That energy is transmitted eastwardly to location IV where it is impressed over the back point of contact 9 of device CRE upon the feed back circuit track relays RK and NK. If this feed back energy is of "normal" polarity, relay NK responds thereto, while if it is of "reverse" polarity, relay RK is picked up thereby.

Prior to the end of the master code "off" period, impulse relay KR at location III releases contact 41 and thus terminates the pulse of feed back energy and at the same time reconnects the master circuit track relay TR with the section rails, thereby conditioning it for reception of and response to the succeeding pulse of master code energy. That pulse is supplied when contact 9 of relay CRE at location IV is returned to its uppermost position.

When that happens the just described cycle of two-direction coded track circuit operation starts to repeat itself and in the manner just outlined the "master" and the "feed back" track circuits of the eastbound set-up for section III-IV operate over the rails of that section simultaneously and without interfering with each other.

When the direction of authorized traffic movement through the section III-IV is shifted to the westbound direction as shown in Fig. 7b, the two-direction track circuits are modified in the manner there represented. This modification results from a shift of the contacts of the traffic directional delay TD at location III from the right to the left positions.

As a result of this shift contacts 65 and 66 of the named relay transfer the connection of the section rails at location III to the master end equipment which is there represented in Fig. 7b. Meanwhile, at location IV the section rails continue their connection with devices CRE, RK, NK and TD as before. Now, however, these devices function as feed back end apparatus rather than as master end equipment.

Comparing the diagram of Fig. 7b with that of Fig. 5a, it will be seen that the westbound set-up for section III-IV utilizes at the east end IV feed back apparatus which is a substantial duplicate of that utilized at the west headblock location I in the eastbound set-up of section I-II. Thus, in the represented equipment at the east headblock location IV devices CRE, RK, NK and TD correspond to, have the same characteristics, and perform in the same manner as devices CRW, RKE, NKE and KB of Fig. 5a.

From a comparison of the two named diagrams, it will further be seen that the master end equipment which the westbound set-up of track section III-IV utilizes at the intermediate location III is a duplicate of that utilized by the eastbound set-up of section I-II at intermediate location II. That is, elements TB, CR, RK

and NK have an exact correspondence both as to characteristics and function. The identity further extends to the master code transmitters CT188 and CT75 which are selectively assigned by contact 7 of relay H to the control of the code repeating device CR.

In operation of the coded feed back track circuits of the westbound set-up of track section III-IV, device CR at location III periodically moves its contact 6 up and down at the rate of either 130 times per minute or 75 times per minute depending upon whether contact 7 of relay H is picked up or released. Each pick-up of this contact 6 causes the master battery TB to supply the section rails with a pulse of master code energy which is transmitted eastwardly over the rails to the east headblock location IV.

There the master code pulse is fed over the back point of contact 9 of device CRE to the control windings of relays NK and RK. In this case relay NK only responds and thereby it acts as the code following track relay for the master circuit.

In picking up, contact 12 of relay NK completes an energizing circuit for the feed back circuit device CRE and causes contact 9 thereof to pick up. This action does not, however, disconnect relay NK from the track rails since contact 11 in its present picked up position establishes a connection from conductor 25 over front contact 9, conductor 32, front contact 11 and conductor 33 to conductor 23.

When contact 6 of device TR at location III goes to the lowermost position, the pulse of master code energy is terminated and the now deenergized relay NK at location IV releases. This action causes contact 11 to complete a circuit which includes front contact 9 of device CRE and over which battery TB at location IV supplies the section rails with a pulse of feed back energy. This pulse has a duration determined by the release delay of device CRE and which is indicated in Fig. 2 by the symbol f . At the end of that period device CRE releases (the energizing circuit thereof previously having been broken when contact 12 of relay NK released) and thereby terminates the feed back pulse and reconnects the control winding 8 of relay NK with the section rails.

Prior to that action and during the continuance of the feed back pulse, the energy thereof flows westwardly over the section rails to location III where it is transmitted over the back point of contact 6 of relay CR to devices NK and RK. The polarity of this energy being "normal," relay NK responds thereto and thus it acts as the code following track relay for the feed back circuit.

Following the release of device CRE at location IV, master device CR at location III moves contact 6 to the uppermost position and thus marks the beginning of a succeeding master code "on" period. When that happens the just described cycle of coded feed back track circuit operation starts to repeat and in the manner just outlined the "master" and the "feed back" track circuits for the westbound set-up for section III-IV operate over the rails of that section simultaneously and without interfering with each other.

Looking finally at Fig. 8, I have there represented the coded feed back track circuits which are used between the ends of each of the passing sidings PS in the A. P. B. system of Fig. 1. For the purpose of more clearly tying these circuits

in with the equipment which is represented at the two headblock locations I and IV of the Fig. 1 system, I have given the west and the east ends of the track section of Fig. 8 the respective designations of IV and I. The illustrated section IV—I, therefore, is such as would result were the passing siding EPS which begins with the west headblock location IV of Fig. 1e to continue eastwardly as siding PS of Fig. 8 and terminate at a succeeding headblock location which will be a duplicate of location I of Fig. 1a and which accordingly has been designated by the reference character I.

The coded feed back track circuits of section IV—I which span the passing siding PS of Fig. 8 are in one sense non-reversible in that the master end of the coded feed back combination always remains at the east location I as there marked, while the feed back end of the combination always remains at the west location IV as there marked. As will be explained presently, however, these track circuits possess certain features in addition to those of the usual coded feed back combination and because of these features the entry of a train into the section IV—I causes 15 distinctively coded energy simultaneously to be supplied from both ends thereof.

In this arrangement of Fig. 8, both the "master" and the "feed back" track circuits utilize the section rails 1 and 2 as common conductors; the "master" circuit further includes an energy source TB and a code repeating relay CR installed as shown at the section east end I and a code following track relay TR installed at the section west end IV; and the "feed back" circuit further includes an energy source KB and a rail connection transfer device CRW located at the section west end IV and a pair of polarized track relays RKW and NKW installed at the section east end I.

In operation of the "master" track circuit of Fig. 8, the code repeating device CRE at location I recurrently picks up and releases its contact 6 at the rate of either 180 times per minute or 20 75 times per minute depending upon whether the control current supplied to the relay winding over conductor 69 is derived from contact 180 of a coding device CT180 over front contact 70 of a code selector relay H or from contact 75 of a second coding device CT75 over back contact 70 of the selector relay.

Each pick-up of the contact 6 causes battery TB at location I to energize relay TR at location IV over a circuit which extends from the positive terminal of battery TB through current limiting impedance 29, conductor 26, track rail 2, conductor 21, the winding of relay TR, conductor 52, back contact 9 of device CRW, conductor 25, track rail 1, conductor 19, front contact 6 of device CR, conductor 71, the secondary of a transformer 15 and conductor 72 back to the negative terminal of battery TB.

In moving to the lowermost position contact 6 of device TR breaks the just traced circuit and allows relay TR at location IV to release, and in this manner the code following operation of contact 6 of device TR at location I is repeated by relay TR at location IV.

In operation of the "feed back" track circuit of Fig. 8 each pick-up of relay TR at location IV causes contact 12 thereof to complete for device CRW at the same location an energizing circuit which may be traced from the positive terminal of a local control source through front contact 12, front contact 73 of a relay HE, con-

ductor 14 and the winding of device CRW back to the negative terminal of the control source. As a result, device CRW picks up contact 9 at the beginning of each master code "on" period 5 and holds the contact in that position for the full continuance of that "on" period and thereafter for the release delay time which is represented at f in Fig. 2.

This pick-up of device CRW does not, however, discontinue the transmission of the master code pulse to relay TR for the reason that when that relay picked up at the beginning of the master code pulse contact 11 thereof set up a bypass path around the back point of contact 9 of device CRW. As soon, therefore, as contact 9 reached the uppermost position, the connection of conductor 52 with conductor 25 was restored over conductor 33, front contact 11, conductor 32 and front contact 9.

As contact 6 of device CR at location I moves downwardly to terminate the master code "on" period that contact breaks the energizing circuit for relay TR at location IV and also connects relays RKW and NKW at location I across the section rails. As relay TR releases, contact 11 sets up a circuit over which the battery KB at location IV supplies the section rails with a pulse of feed back energy.

Depending upon whether the contacts 71 and 78 of a relay HW are picked up or released, this feed back energy is of either the "normal" or the "reverse" polarity. In the former case it picks up relay NKW at location I over a circuit which may be traced from the positive terminal of battery KB to front contact 71, impedance 35, conductor 21, track rail 2, conductor 26, the control winding 8 of relay NKW, the relay RKW, conductor 36, back contact 6 of device CR, conductor 19, track rail 1, conductor 25, front contact 9 of device CRW, conductor 32, back contact 11 of relay CR, conductor 37, the secondary of a transformer 15, conductor 19, and front contact 78 of relay HW, back to the negative terminal of battery KB.

In the latter instance, in which the feed back energy is of "reverse" polarity, relay RKW at location I is picked up over a circuit which extends from the positive terminal of battery KB through the back contact 71 of relay HW, conductor 79, the secondary of transformer 15, conductor 37, back contact 11 of relay TR, conductor 32, front contact 9 of relay CRW, conductor 25, track rail 1, conductor 19, back contact 6 of device CR, conductor 36, the control winding 8 of relay RKW, the relay NKW, conductor 26, track rail 2, conductor 21, impedance 35, conductor 80, and back contact 78 of relay HW back to the negative terminal of battery KB.

Each of these pulses of feed back energy is terminated by the release of contact 9 of device CRW, which release takes place after time f of Fig. 2. When that happens the picked up relay NKW or RKW at location I releases.

Following that action relay CR at location I picks up its contact 6 and thereby marks the beginning of another master code "on" period. With that action the just described cycle of coded feed back track circuit operation starts to repeat itself and in the manner just outlined the "master" and the "feed back" track circuits of the siding spanning section IV—I of Fig. 8 operate over the rails of that section simultaneously and without interfering with each other.

In the event that a train enters the section IV—I of Fig. 8, the following special action takes

place. Not only does the supply of master code energy to the east end I thereof continue, but the section occupancy causes relay HE at location IV to release (in a manner later to be explained). This, in turn, causes contact 73 to transfer the control circuit of device CRW at location IV to one or the other of coding contacts 180a and 75a of the before described code transmitters CT180 and CT75 at the same location.

Selection between the just named coding contacts is made by a contact 81 of relay HW. When this contact is picked up device CRW receives 180 energizing pulses per minute over the contact 180a of transmitter CT180, a conductor 82 and back contact 73 of relay HE. When relay HW releases contact 81, device CRW receives 75 energizing pulses per minute over the contact 75a of transmitter CT75, conductor 82 and back contact 73.

Each time that contact 9 of device CRW is in this manner picked up, it completes for the section rails a circuit over which battery KB at location IV supplies energy thereto and which may be traced (under picked-up conditions of relay HW) from the positive terminal of battery KB through front contact 77 of relay HW, impedance 35, conductor 21, the track rail 2, track rail 1, conductor 25, front contact 9 of device CRW, conductor 32, back contact 11 of relay CR, conductor 37, the secondary of transformer 15, conductor 79 and front contact 78 of relay HW back to the negative terminal of battery KB.

In releasing or going to the lowermost position, contact 9 of device CRW interrupts the just traced circuit. In again returning to the uppermost position, however, it recompletes that circuit, and in this manner the west end of track section IV—I is supplied with coded energy of either the 180 pulse per minute or the 75 pulse per minute rate as selected by contact 81 of relay HW.

The utility of this special action will be made evident in a later portion of the specification. For the present it will suffice to say that this occupied-section performance of the apparatus at the west end IV of the track section is duplicated or performed in an equivalent or comparable manner by the equipment at the section east end I. There device CRE recurrently makes and breaks the circuit over which battery TB energizes the section rails while relay H selects the rate of operation of relay CRE between the 180 pulse per minute and the 75 pulse per minute speed.

Before considering the remaining portions of the herein disclosed system of non-line-wire A. P. B. signaling, it is desired to comment further on: (1) the impulse relays KR which form a part of the "feed back" apparatus at each of the intermediate locations II, III and IIIa; and (2) the associated polarity selector relays KS at the same locations.

Each of these impulse relays KR: (1) completely disconnects the "master code" responsive track relay TR from the section rails during each of the master code "off" periods that those rails receive "feed back" energy from battery KB; and (2) eliminates wastage of power during the feed back supply operations in a manner similar to that disclosed and claimed in a related Patent No. 2,174,255 which issued September 26, 1939, to Herman G. Blosser on "Approach control apparatus for railway signaling systems."

Without interfering with the intended function of transferring the connection of the section rails

from the track relay TR to the track battery KB during each "off" period of the "master" code to which relay TR is responding, each of these impulse devices KR may, of course, be controlled in manners other than the particular one which I have shown in Figs. 1, 5b, 6a-b and 7a. One such alternative energizing scheme is shown in Fig. 11. There the means for supplying the relay KR with a pulse of pick-up energy at the beginning of each of the master code "off" periods takes the form of an added secondary winding 68 of the decoding transformer DT that is supplied with pole changed primary current in customary manner over the contact 85 of the track relay TR.

Each time that the track relay releases the pole changing action of this contact 85 causes to be induced in the secondary winding 68 a pulse of transformer voltage having the polarity designated by the small arrow and which for convenience will be referred to as "positive". Each time, however, that the track relay picks up the reverse action of contact 85 causes to be induced in this winding 68 a pulse of transformer voltage of the opposite or "negative" polarity. Both half waves of the just described voltage are impressed upon the operating winding of the impulse relay KR.

In the arrangement of Fig. 11 this relay KR is of the polarity selective type and contact 41 thereof occupies the released position (shown in full lines) as long as the relay remains deenergized or receives current of the negative polarity just described. In that position the contact connects the operating winding of the track relay TR directly across the section rails. When, however, relay KR receives from winding 68 the before mentioned pulse of positive polarity energy, it picks up contact 41 and thereby disconnects relay TR from the rails and connects the track battery KB (see the diagrams of the earlier figures) thereacross.

In this manner the modified control circuit of Fig. 11 causes the impulse relay KR to respond to each release of the associated track relay TR and momentarily transfer the section rail connection from the winding of the track relay to the output circuit of the track battery KB at the same location. At the same time each pick-up of the track relay TR is prevented from interfering with the normal connection of the rails with the winding of that relay.

Further regarding the before named relays KS at the intermediate locations II, III and IIIa, I am aware that in their broad function of selectively changing the polarity of the "feed back" trackway energy they have something in common with the disclosures of each of the following co-pending applications: (1) Serial No. 294,897 filed September 14, 1939, by Ralph R. Kemmerer on "Absolute permissive block system of railway signaling", and (2) Serial No. 329,316 filed April 11, 1940, by me on "Apparatus for detecting the approach of railway trains."

In all three instances, however, the functions that are performed by this selectively polarized "feed back" energy widely differ one from another. In particular, those now about to be disclosed in connection with the non-line-wire A. P. B. system of the present invention are so novel and original as clearly to distinguish from all corresponding functions with which I am now familiar.

Control of system signals

The "coded feed back" track circuits which

have just been described (for the several sections into which the single track stretch of Figs. 1a-e is divided) control the wayside signals SE and SW of the A. P. B. system in a manner which will now be explained.

To introduce this explanation it may first be stated that under the conditions of eastbound traffic authorization which are shown in Figs. 1a-e, 5a, 6a, 7a, 9a-c and 10d, the "master" track circuits (of the several "coded feed back" combinations) control the eastbound traffic governing signals SE and the "feed back" track circuits govern the westbound headblock signal SWIV. However, for the conditions of westbound traffic authorization which are represented in Figs. 5b, 6b, 7b, 9d and 10a-c the "master" track circuits control the westbound traffic governing signals SW and the "feed back" track circuits govern the eastbound headblock signal SEI.

Inasmuch as the facilities for effecting the just set forth forms of signal governing differ somewhat at different locations, the control means for each of the signals in the system will be described individually.

Referring first to the eastbound headblock signal SEI at location I of Fig. 1a, the indication which this signal displays is selected by the previously described code following track relay NKE through the medium of a pair of decoding relays H and J. These two relays carry contacts 83 and 84 which are included in the lamp energizing circuits for the signal. Those circuits, in turn, derive lighting current from a local energizing source designated by the terminals "plus" and "minus" and which may take the form of the before referred to control battery CB of Fig. 3.

The just named relays H and J respectively are "home" and "distant" decoding devices and they both receive pick-up energy from a decoding transformer DT. That transformer, in turn, is excited from the direct current source with which the terminals "plus" and "minus" are identified and it receives its exciting current over a circuit which is controlled by a pole changing contact 85 of the track relay NKE.

The secondary winding of this decoding transformer DT is connected in energy supplying relation with the first decoding relay H over a circuit which includes a second or rectifying contact 86 of the just named track relay. This first or "home" decoding relay is a direct current device and is associated with the decoding transformer in a manner disclosed and claimed in copending application Serial No. 210,744 filed May 28, 1938, by Frank H. Nicholson et al. on "Railway traffic controlling apparatus." It is adapted to pick up when the track relay NKE responds to operating energy of either the 75 or the 180 pulse per minute code rate.

The second or "distant" decoding relay J receives its pick-up energy through a resonant unit 180DU which is interposed between the relay winding and the primary of the decoding transformer. Under the selective action of this unit energy of pick-up intensity is transmitted to the decoding relay only when the track relay NKE responds to operating energy of the 180 pulse per minute code.

Hence, the elements just named cooperate to cause both the home relay H and the distant relay J to pick up when the track relay NKE is following the "master clear" (see Fig. 2) code of 180 energy pulses per minute; to allow only the home relay H to pick up when the track relay responds to the slower "master approach" code

of 75 pulses per minute; and to cause both of the relays H and J to release when the track relay NKE ceases to follow code. Relay H has a substantial period of release delay which is depended upon for performing a further control function later to be described.

In determining the aspect which is displayed by the controlled wayside signal SEI, the above described decoding relays make use of the previously named contacts 83 and 84. Further included in the lamp lighting circuits of which these contacts form a part are contacts 87 and 88 of a pair of relays RP and NP later to be described. For a purpose to be made evident presently both of these relays must be released in order that lighting current may be transmitted to the lamps G, Y and R of signal SEI.

When, under that condition, the track relay NKE is responding to the "master clear" or 180 code and both of the decoding relays H and J are picked up, lamp G then is lighted over a circuit which includes back contacts 87 and 88 of devices RP and NP, front contacts 83 and 84 of devices H and J and a conductor 89; when the track relay is responding to the "master approach" or 75 code and relay H only is picked up, lamp Y then receives lighting current over front contact 83, back contact 84 and a conductor 90; and when the track relay NKE is not following code and both of the relays H and J are released, lamp R is lighted over a circuit which includes back contact 88 and a conductor 91.

Considering next the westbound headblock signal SWIV at location IV of Fig. 1e, the indication which it displays is selected by the before described code following track relay NK through the medium of "home" and "distant" decoding relays HW and JW. These relays receive pick-up current from a decoding transformer DT which is controlled over contacts 85 and 86 of relay NK in a manner identical to that described for devices DT and NKE of Fig. 1a. That is, relays HW and JW both pick up when the track relay NK is following code at the 180 pulse per minute rate, relay HW only picks up on the 75 pulse per minute code and both of the decoding relays release when the track relay NK ceases to follow code.

In determining the aspect which is displayed by the controlled westbound signal SWIV, the two decoding relays HW and JW make use of contacts 83 and 84 which are included in the energizing circuit over which the lamps G, Y and R of that signal selectively receive lighting current from a local source with which the terminals "plus" and "minus" are identified. Further included in these circuits is a contact 92 of the relay HE that previously was described in connection with Fig. 8. For a purpose later to be made evident this contact must be released before any of the signal lamps G, Y and R can be lighted.

When, under that condition, the track relay NK of Fig. 1e is responding to code of the 180 pulse per minute rate and both of the relays HW and JW are picked up, lamp G of signal SWIV then is lighted over a circuit which includes back contact 92 of relay HE, front contacts 83 and 84 of devices HW and JW and conductor 89; when the track relay is responding to code of the 75 pulse per minute rate and relay HW only is picked up, lamp Y then receives lighting current over front contact 83, back contact 84 and conductor 90; and when the track relay ceases to follow code and both of the decoding relays HW

and JW are released, lamp R of the signal is lighted over a circuit which includes back contact 83 and the conductor 91.

Considering next the eastbound signal SEIV at the east headblock location IV of Fig. 1e, the indication which it displays is selected by the code following track relay TR at that location through the medium of "home" and "distant" decoding relays HE and JE. These relays are associated with a decoding transformer DT and controlling contacts 85 and 86 of relay TR in a manner comparable to that described in connection with devices HW and JW at the same location IV and devices H and J at location I. That is, both of them pick up when the track relay TR follows code at the 180 pulse per minute rate; relay HE only picks up in response to the 75 pulse per minute code; and both of the relays HE and JE release when the track relay TR ceases to follow code.

In determining the aspect which is displayed by the controlled eastbound signal SEIV, these two decoding relays make use of contacts 83 and 84 which are included in circuits over which the lamps G, Y and R of that signal selectively receive lighting current from the previously mentioned local source. Further included in these circuits is a contact 93 of a relay V. For a purpose to be made evident presently, this contact must be released before any of the signal lamps can receive lighting current.

When, under that condition, the track relay TR at location IV is responding to the "master clear" or 180 pulse per minute code and both of the relays HE and JE are picked up, lamp G of signal SEIV then is lighted over a circuit which includes back contact 93 of device V, front contacts 83 and 84 of devices HE and JE and conductor 90; when the track relay is responding to the "master approach" or 75 pulse per minute code and the relay HE only is picked up, lamp Y of the signal then receives lighting current over front contact 83, back contact 84 and conductor 90; and when the track relay TR ceases to follow code and both of the relays HE and JE are released, lamp R is lighted over a circuit which includes back contact 83 and conductor 91.

Considering next the westbound signal SWI at the west headblock location I of Fig. 1a, the indication which this signal displays is selected by code following track relays NKW and RKW at that location through the medium of repeater relays NP and RP. These relays NP and RP are slow releasing direct current devices and each receives pick-up current from the secondary of a transformer AT which is interposed, in the manner shown, between the relay winding and the terminals "plus" and "minus" of a local energizing source. The primary of the transformer which energizes relay NP is pole changed by a contact 94 of the track relay NKW while in the secondary circuit of the transformer a rectifying contact 95 is included. A similar arrangement is used for devices RP, AT and RKW.

Relay NP thus detects the code following operation on the part of track relay NKW while relay RP similarly detects code following operation on the part of track relay RKW. In both instances this detecting function is effected regardless of whether the controlling track relay is following code at the 180 pulse per minute rate or at the 75 pulse per minute rate. Hence, as long as track relay NKW follows either of the two named codes, repeater relay NP picks up its contacts.

Likewise, when track relay RKW follows either of the two named codes, repeater relay RP picks up its contacts. At all other times both of the devices NP and RP are released.

5 In determining the aspect which is displayed by the controlled westbound signal SWI, these two repeater relays NP and RP at location I make use of contacts 96 and 97 which are included in circuits over which the lamps G, Y and R of that signal selectively receive lighting current from the before described local control source. Further included in these circuits is a contact 93 of a relay V. For a purpose later to be made evident, this contact must be released before any of the signal lamps can receive lighting current.

When, under that condition, the track relay NKW is responding to coded energy and repeater relay NP is picked up, lamp G of signal SWI then

20 is lighted over a circuit which includes back contact 93 of device V, front contact 96 of device NP and conductor 90; when the track relay RKW is responding to coded energy and repeater relay RP is picked up (repeater NP now being released)

25 the signal lamp Y receives lighting current over back contact 96 of device NP, front contact 97 of device RP and conductor 90; and when both of the track relays NKW and RKW cease to follow code and both of the repeater devices NP and RP are released, lamp R of signal SWI is lighted over a circuit which includes back contacts 96 and 97 and conductor 91.

30 The signals at the intermediate locations II and III of Figs. 1b and 1c of the represented A. P. B. system will next be considered. In the particular system represented, these intermediate signals include eastbound devices SEII and SEIII and westbound devices SWIII and SWII.

35 For the control of both the eastbound and westbound signals SE and SW, each of the two intermediate locations II and III makes use of but a single set of decoding apparatus. As shown in each of Figs. 1b and 1c, this apparatus is responsive to code following action of the track relay TR and includes a decoding transformer DT and "home" and "distant" decoding relays H and J energized therefrom. The arrangement of the just named elements is a duplicate of that already described for correspondingly identified equipment at each of the headblock locations IV and I of Figs. 1e and 1a.

40 In this intermediate location decoding equipment, therefore, the elements just referred to cooperate to cause both the "home" relay H and the "distant" relay J to pick up when the track relay TR is following code at the 180 energy pulse per minute rate; to allow only the home relay H to be picked up when the track relay responds to the slower code of 75 pulses per minute; and to cause both of the relays H and J to release when the track relay TR ceases to follow code.

45 For the purpose of determining the aspect which is displayed by the controlled eastbound signal SE, the decoding relays H and J at each of the intermediate locations II and III make use of contacts 83 and 84 which are included in the lamp energizing circuits for that signal in the manner shown. In order also to determine the aspect which is displayed by the controlled west-

50 bound signal SW, the same decoding relays H and J at each of the intermediate locations make use of duplicate contacts 83a and 84a which are included in the lamp lighting circuits for the westbound signal.

55 At any particular time only one of these two

sets of signal lighting circuits can receive energizing current and selection between the two sets is effected by contact 99 of the before described traffic directional relay TD of the intermediate location equipment. Moreover, connection of the selected set of signal circuits with the local energizing source therefor (designated by the terminals "plus" and "minus") is possible only when a contact 100 of a relay V at the intermediate location is released. The purpose of this last named requirement will be made evident in a later portion of the specification.

Assuming that contact 100 of relay V is so released, the operation of the signal assigning circuits at each of the intermediate locations II and III is as follows: When relay TD holds contact 99 in the right-hand position, as under conditions of eastbound traffic authorization, the control of decoding relays H and J is assigned to the eastbound signal SE; however, when the relay TD maintains contact 99 in the left position, as under conditions of westbound traffic authorization, the control of the decoding relays is assigned to the westbound signal SW.

With the intermediate location relays H and J assigned to the eastbound signal SE in the manner set forth above, the control of that signal is as follows: When the track relay TR is responding to the 180 pulse per minute code and decoding relays H and J are both picked up, lamp G of signal SE then is lighted over a circuit which may be traced from the positive supply terminal through back contact 100 of device V, conductors 101 and 102, right biased contact 99 of device TD, conductor 103, front contact 83 of device H, front contact 84 of device J, conductor 89 and the signal lamp G back to the negative supply terminal. This, of course, produces the "clear" indication.

When the track relay TR at the intermediate location is responding to the 75 pulse per minute code and relay H only is picked up, lamp Y of the controlled signal SE is lighted over a circuit which includes back contact 100 of device V, right biased contact 99 of device TD, front contact 83 of device H, back contact 84 of device J and the conductor 90. This, of course, causes the signal to display the "approach" indication. Finally when the track relay TR at the intermediate location is continuously deenergized and both of the decoding relays H and J are released, lamp R of the controlled signal SE then is lighted over a circuit which includes back contact 100 of device V, right biased contact 99 of device TD, back contact 83 of device H and conductor 91. Under this condition the signal shows "stop."

With the intermediate location decoding relays H and J assigned to the westbound signal SW in the manner previously described (contact 99 of relay TD biased to the left), the control of that westbound signal is as follows. As already stated, this signal can receive energizing current only when contact 100 of relay V is released.

When, under that condition, the track relay TR at the intermediate location is following code at the 180 pulse per minute rate and both of the recoding relays H and J are picked up, lamp G of the controlled westbound signal SW then is lighted over a circuit which extends from the positive terminal of the control source, through back contact 100, conductors 101 and 102, left biased contact 99 of device TD, conductor 104, front contact 83a of device H, front contact 84a of device J, conductor 89 and the signal lamp G back to the negative terminal of the control

source. Under this condition the controlled signal shows "clear."

When the intermediate location relay TR is following code at the 75 code per minute rate and relay H only is picked up, lamp Y of the controlled signal SW then is lighted over a circuit which includes back contact 100, left biased contact 99, contact 83a of device H, back contact 84a of device J, and conductor 90. Under this condition the controlled signal shows "approach." Finally when the intermediate location relay TR ceases to follow code and both of these relays H and J are released, lamp R of the controlled signal SW is lighted over a circuit which includes contacts 100 and 99 in the last named position, back contact 83a of relay H and conductor 91. Under this condition the controlled signal shows "stop."

From a comparison of the diagrams of Figs. 1b and 1c, it will be seen that at all intermediate locations in the A. P. B. system the just described signal control circuits (where used) are the same. In each installation thereof the traffic directional relay TD so selectively connects (at contacts 65-66 and 27-18) the single sets of coding (devices CT, CR, TB and TA) and decoding (devices TR, H and J) equipment with the rails of the two there adjoining track sections and so selectively assigns (at contact 99) the decoding equipment control to one or the other of the two signals SE and SW that the need for duplicate sets of the named equipments is eliminated.

This, of course, reduces the quantity of the named apparatus which the system requires. Typically, as will be realized, most installations of A. P. B. signaling make use of more than the represented two locations (II and III) of intermediate signal installation and for this reason the saving just stated becomes all the more important.

Supply and coding of the trackway energy

Description now having been given of the "coded feed back" track circuits and the signal control facilities which are utilized in the A. P. B. system of two-direction signaling that is represented in Figs. 1a-e, attention will next be directed to the apparatus by which the trackway energy for that system is supplied and coded.

Considering first the energy supply facilities, these, quite obviously, are not restricted to the particular arrangement shown wherein each of the sections of track in the A. P. B. system is provided with a pair of track batteries TB and KB installed at opposite ends of the section for the purpose of supplying "master" and "feed back" code energy to the rails thereof. Instead of operating on direct current energy as represented, it will be apparent that these two-direction track circuits (see the simplified showings of Figs. 5 to 8) may readily be modified to operate on alternating current energy.

In the event of such modification the two track batteries for each section will be replaced by track transformers (not shown) together with facilities for supplying alternating current energy thereto. Conveniently, of course, such facilities may take the form of a transmission circuit (not shown) which extends along the right of way in the usual manner and which feeds energy to each of the locations I, II, III, etc. of system track section division. When such power distribution facilities are employed, each outlet location thereof may comprise terminals such as

are represented at B and C in Figs. 3 and 4. For applications in which train-carried cab signals of the character shown in Fig. 15 also are to be controlled, the coded signaling facilities of the A. P. B. system will still further comprise means (at the exit end of each track circuit) for additionally supplying the section rail with coded alternating current energy which is supplemental to the unidirectional current that those rails receive from the represented track batteries TB and KB. Conveniently, this cab signal control energy may be introduced into each "master" rail supply circuit through the medium of a transformer which is connected therein in the manner represented at 15 in each of the views of Figs. 1, 5, 6, 7 and 8.

As shown in Fig. 1, these transformers 15 may form parts of tuned alternators TA which generate the alternating current energy locally (from a direct current source in a manner to be described presently) or as shown in Fig. 4 each of the named transformers 15 may derive the necessary exciting current over a direct connection with terminals B and C of the before mentioned transmission circuit source. In the latter event, the primary winding of the transformer is at proper times connected with the source terminals over the back point of an approach relay contact 130 and at other times by-passed over the front point of the same contact for the purpose of reducing the secondary impedance of the transformer.

When it is desired to supply all of the track circuit energy from local batteries of the type shown at TB, KB and CB in Figs. 1 and 3, these cab signals transformer devices 15 will form parts of the before mentioned tuned alternators TA of Fig. 1. In that event they at proper times function to introduce alternating current energy of 100 cycle per second or other suitable carrier wave frequency into the rail supply circuit which the coding contact (element 6 or 9) of device CR completes during each "on" period of the direct current "master" code.

In the form shown in Fig. 1, each of these tuned alternators TA includes a reed type of vibrating member 131 which in well-known manner pole changes the primary energizing circuit over which the transformer 15 receives exciting current from the terminals "plus" and "minus" of the control battery CB (of Fig. 3) or other local source of direct current. This member 131 is of magnetic material and has a natural rate of vibration corresponding to the 100 cycle per second or other desired frequency of the output voltage of transformer 15.

Driving movement is imparted to the armature 131 by an electromagnet 132 having an energizing circuit which the armature periodically completes in a manner keeping the armature in vibration at its natural rate as long as the magnet driving circuit is connected with the local source. In this way an electromotive force of the 100 cycle or other cab signal control frequency is generated (as a result of the pole changing action of member 131 in the primary circuit of transformer 15) in the secondary winding of transformer 15 whenever the magnet driving circuit is connected with an energizing source.

Before such connection can be completed, in the arrangement of Fig. 1, the approach relay contact 130 not only must be released but a contact 133 of the associated coding device CR also must be picked up. This latter requirement in-

sures that each of the tuned alternators TA will draw energy from the local battery CB (Fig. 3) only during the "on" periods of the "master" trackway code and will be disconnected from the local battery during the "off" periods of that code (when the secondary of the alternator transformer 15 is disconnected from the section rails). The action just named reduces the drain on the local control battery CB. When this battery is of the primary cell type all expedients which will prolong its life are important and the one just described has this objective in view.

In other applications wherein an alternating current transmission circuit does parallel the right of way, the control source CB at each of the locations of track section division may take the form of a storage battery. In that case it may have associated therewith trickle charging facilities of conventional type. In Fig. 3 such facilities are represented as being connected with the battery by conductors that are shown dotted and as deriving battery charging energy from the alternating current terminals B and C.

The trackway energy coding facilities of my new non-line-wire A. P. B. system will next be examined in somewhat greater detail. From the previous inspection of the simplified diagrams of Figs. 5, 6, 7 and 8 it has already been seen that in each and every one of the "master" rail supply circuits of the system use is made of a device CR which is interposed between that circuit and the transmitters CT by which the circuit current is coded.

Each of these devices CR performs the usual "code repeating" function and thus it both simplifies and lowers the resistance of the connection of the associated track section rails with the source (TB or KB) of trackway energy therefor. Such simplification and resistance reduction results, of course, from the fact that through the illustrated "repeating" device CR the named connection may be made much more directly (over the single coding contact 6 or 9 of that device) than were it serially to include the code-selector contact (7, 61, 81 or 70) of the associated relay H and the selected coding contact (180 or 75) of the controlling transmitters CT180 and CT75.

In the coding facilities that are represented at each of the intermediate locations II and III, each of the transmitters CT180 and CT75 has only one coding contact (member 180 and member 75); only one code repeating device CR is used; one or the other of the named coding contacts 180 and 75 is at all times included in the driving circuit for that device; and selection between those two coding contacts is made by contact 7 of the relay H at the same location. These intermediate location facilities have already been described and their mode of operation will be self evident from an inspection of the diagrams.

At each of the headblock locations I and IV, however, the code selecting facilities are of a somewhat more extended form. Thus, the code transmitters CT75 and CT180 of both headblock equipments are provided with duplicate sets of coding contacts respectively designated as 75-75a and 180-180a. While the driving circuits (for device CR) in which the contacts 75a and 180a function correspond to those at the intermediate locations and have already been described in connection with Figs. 5b, 7a and 8, there remain for the circuits with which contacts 75 and 180 are associated certain features which require further explanation. This will now be given.

Looking first at the arrangement at the west headblock location I of Fig. 1a, the code repeating device CRW thereof is at times controlled (as shown in Fig. 5b) by one or the other of contacts 188 and 75 of transmitters CT180 and CT75 and at other times (as shown in Fig. 5a) by contact 12 of code following track relay NKE. Selection between these two forms of control is effected by contact 182 of a stick relay S. When that contact 182 is picked up the last named form of control (Fig. 5a) prevails while when contact 182 is released the form of control first named (Fig. 5b) prevails.

In the latter event, code repeating device CRW receives recurring pulses of pick-up current over 15 coding contact 180 when: (1) relay H is picked up; and also when (2) relay H is released at a time when relay NP is picked up. In the former case, the energizing circuit for the winding of device CRW includes coding contact 180, conductor 184, front contact 185 of device H, conductor 186, back contact 182 of device S, and conductor 31; in the latter case it includes coding contact 180, front contact 39 of device NP, conductor 187, back contact 185 of device H, conductor 186, back contact 182 of device S and conductor 31.

With the stick relay S released, the code repeating relay CRW is controlled over coding contact 75 when relays H and NP are both released. 30 In that event the operating circuit for device CRW includes coding contact 75, conductor 188, back contact 39 of device NP, conductor 187, back contact 185 of device H, conductor 186, back contact 182 of device S and conductor 31.

The just mentioned relay S at location I is a "stick" device which has slow releasing characteristics and which is governed by relays V and H at the same location. By means of control circuits later to be described, this west headblock 40 relay S normally is held picked up under conditions of eastbound traffic authorization and normally is released under conditions of westbound authorization.

Looking next at the special driving circuits for the code repeating device CRE at the east headblock location IV of Fig. 1e, the form of control there provided corresponds very closely to that just described for device CRW at the west headblock location I.

At times, the winding of this device CRE is controlled over contact 12 of code following track relay NK (as shown in Fig. 7c) and at other times the same winding receives recurring energizing pulses over one or the other of contacts 75 and 180 of transmitters CT75 and CT180. Selection between these two forms of control is effected by contact 182 of the stick relay S.

When this contact is picked up, the energizing circuit for device CRE is as represented in Fig. 7b and may be traced (in Fig. 1e) from the positive supply terminal, through front contact 12 of relay NK, conductor 183, front contact 182 of device S, conductor 31 and the winding of repeating device CRE back to the negative supply terminal.

When contact 182 of stick relay S is released, one or the other of coding contacts 180 and 75 is included in the energizing circuit of device CRE. Contact 180 is the included element: (1) when relay HW is picked up or; (2) when relay HW is released at a time that relays HE and JE are both picked up. In the former instance, the energizing circuit for device CRE includes coding contact 180, conductor 184, front contact 75

of device HW, conductor 186, back contact 182 of device S and conductor 31. In the latter case, the energizing circuit of device CRE includes coding contacts 180, front contacts 193 and 194 of devices JE and HE, conductor 187, back contact 67 of device HW, conductor 186, back contact 182 of device S, and conductor 31.

Under released conditions of relay S the energizing circuit for code repeating device CRE of Fig. 1e includes coding contact 75: (1) when devices HW and HE are both released; or (2) when devices HW and JE are released at a time that device HE is picked up. In the former instance the named energizing circuit includes coding contact 75, conductor 188, back contact 94 of device HE, conductor 187, back contact 67 of device HW, conductor 186, back contact 182 of device S and conductor 31; in the latter instance the circuit includes coding contact 75, conductor 188, back contact 193 of relay JE, front contact 194 of relay HE, conductor 187, back contact 67 of relay HW and back contact 182 of relay S.

The just mentioned relay S at location IV also is a slow release "stick" device and it is governed by relays V and H at the same location. By means of control circuits later to be described, this east headblock relay S normally is held picked up under conditions of westbound traffic authorization and normally is released under conditions of eastbound authorization.

The code transmitters CT which operate the just described code repeater relays CR will next be examined in still further detail. In the form represented at all of the signal locations I, II, III and IV in the system, these transmitters CT180 and CT75 are of an oscillating type and each makes use of a driving circuit that includes a contact 164. Current for energizing the transmitter must flow over the back point of this contact and in so doing it causes electromagnetic mechanism (not shown) within the transmitter to produce an upward movement of all of the transmitter contacts.

This movement is against a constantly exerted 45 opposing force (such as gravity or a spring) which returns the contacts to their downward position following an interruption in the driving circuit at contact 164. In this manner the code transmitter contacts are recurrently moved between their uppermost and their lowermost positions as long as the transmitter driving circuit is connected with the before mentioned battery CB (Fig. 3) or other local source of energization. In the event of disconnection therefrom the code transmitter contacts continuously occupy the downward position (that is represented for each of the devices CT75).

In order that the drain on the local control 60 energy sources (of the type shown at CB in Fig. 3) may still further be reduced, each of the signal locations I, II, III and IV in the complete A. P. B. system of Figs. 1a-e includes provision for energizing only the code transmitter CT180 or CT75 thereat which is actively performing a coding function. Looking first at the transmitters CT180 and CT75 which are installed at the intermediate locations II and III of Figs. 1b-e, the driving mechanisms of these transmitters are, for the purpose just stated, selectively energized over a contact 165 of the decoding relay H at the same location.

When that relay H is picked up (and selector contact 7 thereof is connecting coding contact 180 with the operating circuit of coding device CR), contact 165 connects the driving circuit of trans-

mitter CT180 with the local energizing source. When, however, relay H is released (and contact 7 has transferred the control of coding device CR to the coding contact 75), then contact 165 transfers the connection of the local source terminals "plus" and "minus" from the driving circuit of device CT180 to the driving circuit of device CT75.

In this manner only one of the two transmitters at each intermediate location is in operation at any given time and under all conditions that operating transmitter is the device which is needed to fulfill the coding requirements of the A. P. B. system. As previously stated, this feature of selective energization further contributes to the economy of control energy consumption and is of special advantage in an all-primary-battery installation.

Considering next the transmitters CT75 and CT180 at the west and east locations I and IV, these headblock code producing devices are controlled in a manner which is similar to that just explained for the corresponding transmitters at each of the intermediate locations II and III. The circuits over which these headblock transmitters receive selective energization are, however, slightly different and will now be described.

Looking first at the west headblock location I on Fig. 1a, the driving circuit for the transmitter CT180 at that location is set up under two different sets of conditions. First, when relay H at the transmitter location is picked up; a contact 166 thereof then connects the "plus" supply terminal with conductor 167 as shown. And second, when relay S is released at a time that relay NP is picked up; back contact 168 of device S then connects the "plus" supply terminal with conductor 169 and thence with conductor 167 over front contact 170 of device NP. Under either condition, the code transmitter CT180 is caused to operate.

Regarding the companion transmitter CT75 at location I, it also is brought into operation under two different conditions. First, when relay H is released; back contact 166 then connects the "plus" supply terminal with conductor 171. And second, when relays S and NP are both released; the "plus" supply terminal then is connected with conductor 171 over back contacts 168 and 170. In both instances the transmitter CT75 is brought into operation.

The selective energizing circuits for the code transmitters CT180 and CT75 at the east headblock location IV will next be examined. There the connection of the "plus" supply terminal with a conductor 173 which forms a part of all of these circuits is at times established by relay S over back contacts 168 and 174 thereof and at other times by relay HE over back contact 92 thereof and conductors 151 and 175. In the former instance relay S must be released while in the latter relay HE must be released at a time that relay S is picked up.

In either instance, the transmitter CT180 at location IV receives operating current when relay HW is picked up or when relay HW is released at a time that relays HE and JE are picked up. In the former case, the transmitter driving circuit includes front contact 166 of device HW and conductor 167; in the latter, it includes back contact 166, conductor 176 and front contacts 177 and 178 of devices HE and JE.

Under conditions when conductor 173 is con-

nected with the "plus" supply terminal (over either back contacts 168 and 174 of relay H or conductor 175 and back contact 92 of relay HE) the companion code transmitter CT75 at location IV receives operating current when relays HW and HE are both released or when relays HW and JE are both released at a time when relay HE is picked up. In the former case the transmitter driving circuit includes back contact 166 of device HW, conductor 176, back contact 177 of device HE and conductor 171; in the latter it includes back contact 166 of device HW, conductor 176, front contact 177 of device HE, back contact 178 of device JE and conductor 171.

Trackway codes and selecting means therefor

Further consideration will now be given to the trackway codes by which the non-line-wire A. P. B. system of Figs. 1a-e is operated. These codes are represented in Fig. 2.

As that drawing view shows, the previously described "coded feed back" track circuit combination for each of the track sections in the system utilizes a "master clear" code of 180 energy pulses per minute which under vacant track conditions is supplied to the rails of the section at the "master end" thereof; a "master approach" code of 75 pulses per minute which is supplied to the same end of the section under certain other conditions; "normal feed back" codes A and B comprised of positive or "normal" polarity energy and respectively consisting of 180 pulses per minute and 75 pulses per minute which are returned from the opposite or "feed back" end of the section under preselected conditions of system operation; and "reverse feed back" codes A and B comprised of negative or "reverse" polarity energy and consisting respectively of 180 pulses per minute and 75 pulses per minute which are returned from the section "feed back" end under certain further conditions of system operation.

At all times, as has been seen, the "on" periods of each of the two "master" codes are constituted of direct current energy from one or the other of track batteries TB and KB while at certain times this direct current "on" period energy is supplemented by alternating current energy introduced into the rail supply circuit by transformer 15 for the purpose of controlling train-carried cab signals such as are shown in Fig. 15 (later to be described). Except under certain very special conditions later to be detailed, each "on" period of each of the "feed back" codes is constituted only of direct current energy derived from one or the other of batteries TB and KB. Ordinarily, in other words, the transformer 15 (if included) in the "feed back" rail supply circuit is deenergized and hence inactive.

The manner in which the apparatus of Figs. 1a-e functions to select which of the codes Fig. 2 is supplied to which end of each of the track sections in the Fig. 1 system will now be considered. As is best indicated by the simplified track circuit showings of Figs. 5 to 8, the code selecting facilities differ somewhat at the different locations of track section division; for this reason the code selecting facilities for each of the track sections of the A. P. B. system will individually be examined.

Looking at section I-II which is diagrammed in Figs. 5a and 5b, it has already been seen that the contacts of the traffic directional relay TD at location II are biased to the right under condi-

tions of eastbound traffic authorization and to the left under conditions of westbound traffic authorization. In the former instance, (in which the east location II constitutes the "master" end of the "coded feed back" track circuit combination), the "home" decoding relay H of the previously described signal control scheme selects between the "clear" or 180 pulse per minute and the "approach" or 75 pulse per minute "master" code; in the latter instance (in which the west location I constitutes the "master" track circuit end) this master code selection is effected by previously described signal control relay NP. In the first instance, moreover, the feed back energy is always of "normal" polarity; in the second, however, it at times is of "normal" polarity and at other times of "reverse" polarity, as determined by the selector relay KS at location II.

Looking at section II-III which is diagrammed in Figs. 6a and 6b, it has already been seen that the traffic directional relay TD at each end of this section has its contacts biased to the right under conditions of eastbound traffic authorization and to the left when westbound traffic is authorized. In the former instance (in which the east location III constitutes the "master" track circuit end), selection between the 180 and 75 pulse per minute "master" codes is effected by the previously described decoding relay H at location III; in the latter instance (in which the west location II constitutes the "master" track circuit end) the selection between the "clear" and the "approach" master codes is made by decoding relay H at location II. In both instances the pulses of feed back code energy are at times of "normal" polarity and at other times of "reverse" polarity depending upon whether the feed back end relay KS is picked up or released.

Looking at track section III-IV which is diagrammed in Figs. 7a and 7b, it, like section I-II, makes use of only one traffic directional relay TD. Under conditions of eastbound authorization the contacts of this relay are biased to the right and the east location IV then constitutes the "master" track circuit end. Under conditions of westbound authorization the contacts of relay TD are biased to the left and the west location III then constitutes the "master" track circuit end. In the former instance master code selection is effected by the previously described relay HW of the signal control scheme; in the latter the corresponding relay H at the opposite end of the section performs the same selection. In the former instance, moreover, the feed back code may be either of normal or reverse polarity, as determined by relay KS at location III, while in the latter it may be only of normal polarity.

Looking finally at the track section of Fig. 8 which spans one of the passing sidings PS of the A. P. B. system, it will be seen that no traffic directional relays are utilized by the track circuits thereof and that the east location I is at all times the "master" track circuit end while the west location IV is at all times the "feed back" end. Selection of the master code pulse rate is effected by decoding relay H at the east location while the feed back code polarity is selected by corresponding relay HW at the west location. Under conditions of track section occupancy the second decoding relay HE at the west location releases and causes special cab signal control "frequency" code energy also there to be supplied to the section rails.

Except for devices KS, TD and S, all of the relays which perform code selecting functions

have previously been described in connection with the signal control scheme of Figs. 1a-e. Looking now at the relays KS which select the polarity of the "feed back" energy, each of these devices is a repeater for the code following relay NK at the same intermediate location and in the arrangement shown it is controlled in a manner closely corresponding to that described for relay NP at the west headblock location I. That is, its energizing circuit includes a transformer AT having primary and secondary circuits of which the contacts 94 and 95 of relay NK form a part.

The just named contact 94 pole changes the circuit over which the transformer primary receives exciting current (from a local supply source designated by the terminals "plus" and "minus") while the just named contact 95 rectifies the resulting wave of alternating current voltage which the transformer secondary impresses upon the winding of the direct current relay KS. At proper times, in consequence, relay KS receives pick-up energy whenever relay NK is following code. Its slow release characteristics are such that once picked up the contacts thereof there stay until the named code following operation ceases. When that happens the relay winding becomes deenergized and the contacts release.

At each intermediate signal location in the system (II and III of Fig. 1) this polarity selector relay KS is kept released whenever either of the relays H and V at the same location is released. This action is provided by carrying the exciting circuit for that selector relay supply transformer AT over a conductor 142 and front contacts 134 and 100 of the named devices H and V. It has a purpose which will be made evident in a later portion of the specification.

Alternatively, these polarity selector relays KS may be controlled in the simplified manner of Fig. 12. There one of the contacts 94 of relay NK is included in a circuit over which the winding of relay KS receives pick-up current directly from the local control source each time that contact 94 is in the uppermost position.

The manner in which the above-mentioned traffic directional and stick relays TD and S are controlled and the manner in which they select between the "eastbound" and "westbound" set-ups for the "coded feed back" track circuit combinations (previously described in connection with Figs. 5, 6, 7, 8, 9 and 10) forms the subject of a later section of this specification.

Scheme of approach energization

The previously mentioned relays V form a part of an approach energizing scheme which is incorporated in the non-line-wire A. P. B. system of Figs. 1a-e for the usual purpose of reducing the power consumption of the controlled traffic governing apparatus and for also prolonging the term of service of the signal lamps which that apparatus includes. The former function is especially important in applications which depend exclusively upon primary batteries for power supply.

In the arrangement of Fig. 1, the approach governing feature is shown as being applied to each and every one of the wayside signals SE and SW in the system and also to the tuned alternator TA which supply alternating current for cab signal control purposes. In consequence (and as is more clearly shown by the diagrams of Figs. 9 and 10), each of the system signals remains dark at all times except when the display of an indication thereby is actually needed

to advise an approaching train of the conditions of the track ahead.

From an inspection of the diagrams of Figs. 1b-c-d it will be seen that in the apparatus at each of intermediate locations II, III and IIIa both of the before named functions (lighting of the controlled wayside signal and supply of cab signal energy) are approach-governed by the relay V and through the respective medium of the contacts 100 and 130 thereof. As long as these contacts are picked up the circuits over which the wayside signal lamps receive lighting current and those over which the tuned alternators TA receive exciting current are disconnected from the "plus" terminal of the local control source. When, however, relay V becomes released (in response to approach of a train, as will be described presently) the named circuits become connected with the control source and both wayside and cab signal indications then are made available.

From an inspection of Fig. 1a, it will be seen that in a manner identical with that just described for the relay V of Figs. 1b-c-d, the apparatus at the west head-block location I approach governs the lighting circuits of signal SWI over contact 93 and approach controls tuned alternator TAW over contact 130.

From a further inspection of Fig. 1a it will also be seen that the approach energization of devices SEI and TAE at location I is effected by relays NP and RP through the medium of contacts 87-88 and 149-150 serially arranged in the manner shown. When either of the just named devices NP and RP is picked up, the lighting circuits for the wayside signal SEI are disconnected (at contact 87 or 88) from the "plus" terminal of the local control source and the exciting circuit for the tuned alternator TAE is similarly disconnected (at contact 149 or 150) from its source of direct current energization. Upon simultaneous release (produced by the approach of a train in a manner later to be described) of both of relays NP and RP, the selected lighting circuit for the wayside signal is completed over back contacts 87-88 in series while the exciting circuit for alternator TAE is completed over back contacts 149 and 150 in the series each time that contact 133 of the coding device CR is in the uppermost or "on" period position.

From an inspection of the diagram of Fig. 1e it will similarly be seen that in the apparatus at the east headblock location IV the approach relay V approach governs the lighting circuits of signal SEIV through the medium of contact 93 and approach governs the excitation of tuned alternator TAE through the medium of contact 130.

It will further be observed that the approach governing of devices SWIV and TAW at location IV is performed by a single contact 92 of relay HE. As long as this relay is picked up, the referred to contact maintains both of the named devices deenergized and hence inactive. When, however, relay HE releases (in response to the approach of a train as will be described later) contact 92 connects the "plus" terminal of the local control source with conductor 151 and thereby completes the selected lighting circuit of signal SWIV and causes alternator TAW to receive exciting current each time that contact 133 of coding device CRW occupies the uppermost or "on" period position.

The manner in which the above-mentioned

approach relays V are controlled will now be described. The named relay V at each and every one of the locations in the A. P. B. system has release characteristics which are sufficiently slow to bridge the "off" periods of the slowest (75 pulse per minute) trackway code which the system employs. For imparting such characteristics to the relay use may, of course, be made of any suitable means such as a snubbing impedance (not shown) or internal design expedients of equally well-known character.

As installed at each of the intermediate locations II, III and IIIa, the slow release approach relay V is energized in step with: (1) all responses of the "feed back" operated track relay RK ("reverse" polar) at the same location; and (2) all responses of the companion "feed back" operated track relay NK ("normal" polar). This energization is effected through the medium of a circuit in which contacts 153 and 155 of the just named track relays are included in parallel relation. When either of these two contacts is picked up relay V is supplied with energizing current over a circuit which extends from the positive terminal of the local control source through the picked-up contact (153 or 155), conductor 154 and the winding of relay V back to the negative terminal of the control source.

In the event, therefore, that either of the track relays RK or NK is following code, the contacts of the slow release approach relay V will be picked up and there continuously held as long as that code following action continues. Hence, it is only when both of the controlling track relays RK and NK cease to follow code that the contacts of relay V are permitted to release.

For a purpose later to be made evident, the approach relay V at each of the headblock locations I and IV is arranged to pick up less quickly than does the associated relay H. For each of these headblock relays V, moreover, a somewhat more extended scheme of control is provided. In each of these extended schemes the named slow release device is energized in step with: (1) all responses of the "reverse" polar track relay RK at the same location; (2) certain responses of the companion "normal" polar track relay NK; and (3) certain of the operations of the associated code repeating relay (device CRW at location I and device CRE at location IV).

The just named control by relay RK is effected by contact 153 thereof and the flow of approach relay current which is incident thereto is over the front point of that contact and conductor 154; the above named control by relay NK is effected by contact 152 thereof and the flow of approach relay current which is incident thereto is over the front point of that contact, conductor 153, a back contact 150 of device S, conductor 152, and back contact 153 of device RK; and the above named control by the code repeating relay CR is effected by contact 133 thereof and the flow of approach relay current which is incident thereto is over the front point of that contact, conductor 151, front contact 150 of device S, conductor 152 and back contact 153 of device RK.

It will thus be seen that the slow release approach relay V at each of the headblock locations I and IV maintains its contacts continuously picked up as long as: (1) the "reverse" polar track relay RK at the same location follows code; or (2) the companion "normal" polar track relay NK follows code at a time when devices S and RK at the same location are both released; or

(3) the associated code repeating relay (CRW at location I and CRE at location IV) is operating at a time when device S is picked up and device RK is released. Hence it is only when all three of the above stated conditions of relay energization are inactive that the contacts of the controlled headblock relay V are permitted to release.

For the purpose of reducing the minimum release delay period of the approach relays V and thereby quickening the response of each of these devices to the approach of a train, each of the "feed back" energized track relays RK and NK at every location in the A. P. B. system is provided with a second or "stick" winding 157 and a supplemental energizing circuit therefor. In the illustrative form shown, each of these "stick" circuits: (1) includes the back point of the before described contact 133 of the coding device CR at the relay location and the front point of a contact 158 of the relay (RK or NK) itself; and (2) functions in a manner comparable to that disclosed and claimed in a related Patent No. 2,172,893 which issued September 12, 1939, to Edward U. Thomas on "Approach control apparatus for railway signaling systems."

Looking first only at the intermediate location apparatus of Figs. 1b-c-d, it will be seen that when either of the relays RK and NK is picked up (by "feed back" energy received over the back point of contact 6 of coding device CR), back contact 133 of device CR completes for the picked-up relay the before referred to "stick" circuit. As illustratively represented, that circuit extends from the positive terminal of the local control source, through back contact 133 of device CR, conductor 159, front contact 158 of the relay and the stick winding 157 thereof back to the negative terminal of the local source. Once completed, the just traced stick circuit holds the relay picked up until contact 133 of device CR is again moved to the uppermost position.

That movement takes place at the end of the master code "off" period during which the relay (RK or NK) received its original pick-up current ("feed back" energy) from the track rails. This pick-up current, of course, is in the form of a pulse of one of the "feed back" energy codes of Fig. 2 and hence is of the comparatively short duration there indicated at f. In the case of the 75 pulse per minute codes, particularly, that fixed shortness prolongs the spacing between recurrent pulses of the feed back energy and thus would, in the absence of the supplemental "hold-up" provision now being described, require that the release delay period of the approach relay V be made objectionably long. Because, however, of the just explained "stick" action, this release delay period can be substantially shortened without allowing the approach relay to drop out between the recurrent pulses of feed back energy by which the relay NK or RK is operated.

Once either of these relays is picked up by a feed back pulse the above traced stick circuit causes it to remain in that condition continuously until the end of the master code "off" period during which the pick-up occurred. When that happens contact 133 of device CR returns to the uppermost or master code "on" period position and thereby allows the code following device NK or RK to release in the usual manner.

At the headblock locations I and IV the stick circuits for devices NK and RK differ slightly from those at the just described intermediate loca-

tions. In the main these differences are accounted for by the use in the capacity of contact 158 (of the intermediate location) of some other contact of the code following device.

Thus, in the case of devices NKW and RKW at the west headblock location I of Fig. 1a, this other or substituted contact takes the form of member 94 of the just named relays. In addition the stick circuits therefor are rearranged to the extent that 10 the positive terminal of the supply source is connected with the heel of this contact 94 while the negative terminal of the source receives its connection with the stick circuit over a conductor 160 and the back point of contact 133 of coding device CR. In the case of code following track relay NKE at the same location I, the circuit therefor is still further modified to include the back point of contact 133 of coding device CRW, back contact 158 of companion relay RKE and the front point of contact 85 of relay NKE.

A similar modification is shown in the case of the stick circuit for relay NK at the east headblock location IV. In that circuit, as in the one last described for location I, the complete path 25 for the stick current may be traced from the positive terminal of the control source, through back contact 133 of coding device CRE (device CRW in Fig. 1a), conductor 159, back contact 158 of relay RK, conductor 162, the stick winding 157 of relay NK, conductor 161 and front contact 85 of relay NK back to the negative supply terminal.

At all locations in the A. P. B. system, the just described stick circuits for the track relays NK and RK make possible such a reduction in the release time of the controlled approach relay V that it may respond to the entry of a train into the associated track section with a quickness which avoids objectionable "flips" in train carried cab signals when the signal carrying train first passes over the insulated rail joints 3 at the section entrance.

Control of traffic directional and stick relays

As has already become evident, the traffic directional relays TD (which are installed at the intermediate locations II, III, IIIa of the A. P. B. system but not at the headblock locations I and IV thereof) select between the "eastbound" and "westbound" set-ups (which Figs. 5a-6a-7a and 45 Figs. 5b-6b-7b respectively show) for the "coded feed back" track circuits of the several sections into which the two-direction running track stretch of Figs. 1a-e is divided. The manner in which these traffic directional relays are controlled will now be described.

Each and every one of the traffic directional relays TD in the A. P. B. system is provided with a direct current energizing circuit which includes a back contact 134 of the relay H at the same location, a back contact 135 of the associated stick relay S, and a front contact 100 of the approach relay V. Also included in the energizing circuit is a contact 136 of the controlled relay TD.

The winding of each of these relays TD consists of two parts and with these two parts conductors 137 and 138 are respectively joined. When the just named contact 136 is in either the right or the left position and energy is supplied to the associated winding portion, the relay shifts its contacts to the opposite position and there holds them continuously until the winding portion associated with that opposite position is energized.

When, therefore, the contacts of relay TD are

biased to the right as shown in each of Figs. 1b, 1c and 1d, they there remain continuously until relays H and S at the same location release at a time that relay V is picked up. When that happens there is completed for the right winding portion of relay TD an energizing circuit which extends from the positive terminal of the local supply source through front contact 109 of relay V, conductor 139, back contact 134 of relay H, conductor 140, back contact 135 of relay S, conductor 141, right biased contact 136 of relay TD, conductor 137 and the relay winding portion back to the negative terminal of the control source.

Because of this energization relay TD now shifts its contacts to the left where they there remain continuously until the energizing circuit for the left winding portion of the relay is completed. As will later be seen, this shift so changes the track circuit connections that one or another of the contacts 109, 135 and 134 of relays V, S and H breaks the before traced connection of the positive supply terminal with conductor 141 and so prevents what otherwise would result in a pumping action of the traffic directional relay.

At the later time, however, when predeterminedly changed traffic conditions do complete the just mentioned connection, the left portion of the winding of relay TD receives energy over a circuit extending from the positive supply terminal through front contact 108 of relay V, conductor 139, back contact 134 of device H, conductor 140, back contact 135 of device S, conductor 141, left biased contact 136 of relay TD, conductor 138 and the left winding portion back to the negative supply terminal. This energization causes the relay to shift its contacts back to the right position where they remain continuously until traffic conditions later change in a predetermined manner.

Each of the just mentioned intermediate location relays S is a "stick" device which has slow releasing characteristics and which is controlled by relays V and H at the same location. Normally all of the controlled devices S (at the intermediate locations) are released, as is shown in Figs. 1b-c-d. At certain times, however, each one is picked up in response to a release of the controlling relay at a time when the associated relay H is still picked up. The then completed pick-up circuit extends from the positive terminal of the control source through back contact 109 of device V, conductor 101, a front contact 143 of device H, conductor 144 and the winding of relay S back to the negative terminal of the control source.

Once relay S is picked up, its energizing circuit may be interrupted momentarily without releasing the relay. Following each of the just described pick-ups, the conditions (later to be described) which produced that pick-up change in such manner that relay H drops out. This action completes for relay S a stick circuit which extends from the positive terminal of the control source through a stick contact 145 of the relay, conductor 146, back contact 143 of device H, conductor 144 and the winding of relay S back to the negative supply terminal.

This now completed stick circuit holds the contacts of relay S in their uppermost position until such times as the controlling relay H picks up and interrupts the circuit at contact 143. When that happens relay S releases and there stays until later changing traffic conditions cause the before traced pick-up circuit again to be completed.

Alternatively the pick-up and stick circuits for the relay S may take one or the other of the two slightly different forms which Figs. 13 and 14 represent. In the modified arrangement of Fig. 13 the pick-up circuit includes front contact 143 of relay H and back contact 109 of relay V, while the stick circuit includes back contact 143 of relay H and front contact 145 of the controlled relay S. In operation, the circuits of Fig. 13 are the full equivalent of the corresponding ones shown in Fig. 1. That is, relay S is picked up in response to a release of device V at a time when device H is picked up; it picks itself up over contact 145 in response to the release of device H (which takes place more quickly than does the drop-out of relay S); and once stuck up it there stays until changed traffic conditions produce a response on the part of device H.

In the further modified control scheme of Fig. 14, back contact 109 of device V and front contact 143 of device H are again included in the pick-up circuit of the stick relay S. The stick circuit, however, includes not only front contact 145 of relay S and back contact 143 of relay H but also a back contact 147 of device V. In the arrangement of Fig. 14, therefore, the relay pick-up control remains the same as in the earlier described schemes. The stick control however, is modified to the extent that the stick circuit for relay S is completed under a further condition wherein both the devices H and V are picked up.

From the foregoing description of the energizing circuits for devices TD, it will be seen that the function of the stick relay S at each of the intermediate locations II, III, etc. is to prevent a false completion of the energizing circuit of the there located traffic directional relay TD. This purpose is accomplished by contact 135 which maintains the directional relay circuit closed at the point of its insertion when the stretch of A. P. B. track is vacant, as represented in the composite diagram of Figs. 1a-e, and which keeps the named circuit open under certain occupied conditions of the stretch.

Assume, for example, that under the eastbound authorization conditions of Figs. 5a, 6a, and 7a an eastbound train approaches location II of Fig. 1b. The resulting drop of relay V at that location picks up the associated relay S over back contact 109 of device V and front contact 143 of device H. Once established, this pick-up circuit continues intact until the leading vehicle of the train passes location II and causes relay H also to release. When that happens, back contact 143 completes for relay S the stick circuit which previously was set up by contact 145.

Once established, this stick circuit is maintained intact as long as any part of the train remains in section II-III. When, however, the train clears location III, relay H once more picks up and the interruption at contact 143 thereof in the before described stick circuit allows relay S at location II again to release. In the manner just stated, therefore, this relay S is picked up by the entry of an eastbound train into the section I-II and there held continuously until the rear of the train has cleared the east end of section II-III.

During all of this time contact 135 introduces a break in the energizing circuit of the traffic directional relay TD at location II. Because of this break that device TD is prevented from being falsely energized at the instant that the rear of the eastbound train clears location II and allows the approach relay V to pick up at a

time when the decoding relay H is released. Such a false energization of device TD would, of course, effect a shift in the device contacts to the left biased position and thereby interfere with the desired form of A. P. B. system operation.

The action just described in connection with the stick relay S at the intermediate location II is repeated at each of the remaining intermediate locations III, IIIa, etc. in the complete A. P. B. system. A similar action, moreover, takes place under conditions of westbound traffic authorization. This westbound action will now be explained.

Assume that when the contacts of all of the traffic directional relays TD are biased to the left as shown in Figs. 5b, 6b and 7b, a westbound train approaches location II of Fig. 1b. As the leading vehicle of this train enters section III-II it drops relay V at location II and thereby picks up the associated relay S over back contact 100 of device V and front contact 143 of device H. Once established this pick-up circuit is continued intact until the forward portion of the train enters section II-I. When that happens, relay H at location II drops and completes for the relay S a stick circuit which previously was set up at contact 145.

Once established this stick circuit continues intact until the rear of the westbound train clears location I. This action, of course, returns relay H at location II to the picked-up position and by breaking the before named stick circuit at contact 143, allows relay S at location II once more to release. In the manner just stated, therefore, this stick relay S at location II picks up in response to the entry of the westbound train into location III-II and there stays continuously until the train has cleared the west end of section II-I.

During all of this time, contact 135 of the relay introduces a break in the circuit over which energy may be supplied to the winding of traffic directional relay TD at location II. Because of this break, the device TD is prevented from being falsely energized at the time when the westbound train has just cleared location II and allowed relay V to pick up at a time when relay H is released. Such a false energization would obviously cause the traffic directional device TD at location II to return its contacts to the right and thereby interfere with the intended form of operation of the A. P. B. system.

The action of the stick relay S at the intermediate location II which has just been explained for conditions of westbound train movement is repeated at each of the remaining intermediate locations in the system. Once, as a result, the track stretch has been set up for westbound train movement, it so remains until vacated by all westbound traffic and entered by an eastbound train. From the earlier given description, moreover, it will seem that once the track stretch is set up for eastbound train movement, it so remains continuously until all eastbound traffic has vacated the stretch and a westbound train starts to enter it.

The facilities by which the traffic directional relays TD are controlled now having been described, attention will next be directed to the manner in which those facilities respond to the passage of trains through the stretch of two-direction running track of Figs. 1a-e.

Following the passage of each eastbound train through the single track stretch, the signaling apparatus therefor has the condition before de-

scribed in connection with Fig. 9a. As is more fully shown by the eastbound set-up representations of Figs. 5a, 6a and 7a (and also by the composite diagram of Figs. 1a-e), the contacts of all of the traffic directional relays TD in the system are biased to the right and the "master" end of each of the section track circuits is at the section east end. These conditions, moreover, are not altered by the passage of succeeding eastbound trains through the stretch.

However, upon entry of a westbound train into the east end of the stretch, as shown at WT in Fig. 9d, the contacts of all of the traffic directional relays TD are immediately shifted to the left and the track circuit set-ups for all of the sections within the stretch are thereby changed to the westbound authorized conditions which are represented in Figs. 5b, 6b and 7b. As has already been pointed out in connection with Figs. 10a-b-c, the "master" end of each track circuit is at the section west end under such conditions of westbound authorization.

The manner in which the entry of a westbound train into the stretch causes the traffic directional relays TD to shift their contacts from the right to the left as shown in Fig. 9d, will now be described. In passing the east headblock location IV and shunting the rails of section IV-III, the westbound train deenergizes relay TR at location III and by dropping the associated decoding relay H completes (at contact 134) a circuit which causes the traffic directional relay at location III to shift its contacts to the left. This circuit has already been traced in detail and includes front contact 100 of device V, back contact 135 of device S, back contact 134 of device H and right biased contact 136 of device TD.

The named shift of traffic directional relay contact at location III transfers the connection (by way of conductors 19 and 26) of the rails of section III-II from the master track battery TB and coding relay CR to the feed back apparatus which includes devices TR, KR, KS and KB at location III. This transfer interrupts the previous supply of master code energy to section III-II and thereby causes the track relay TR at location II to become deenergized and inactive. That action drops the associated decoding relay H and completes (at contact 134) for the traffic directional relay TD at the same location a circuit which causes that relay to shift its contacts to the left. As was the case at location III, this circuit includes front contact 100 of device V, back contact 135 of device S, back contact 134 of device H and right biased contact 136 of device TD.

The just named shift of traffic directional relay contact at location II transfers the connection (by way of conductors 19 and 26) of the rails of section II-I from the master track battery TB and coding relay CR at location II to the companion feed back apparatus which includes elements TR, KR, KS and KB. As at location III, this discontinues the transmission of master code energy to the west headblock location I and there deenergizes relay NKE. That action drops the associated decoding relay H and interrupts (at contact 143) the hold-up circuit for the stick relay S at the same location thereby allowing that relay also to release.

In the manner just described, therefore, the original entry of the westbound train into the single track stretch at the east headblock location IV caused all of the traffic directional relays TD within the stretch to shift their contacts to the

left position and caused the stick relay S at the west headblock location I to release. As has been seen, these actions took place successively and accompanying each one there was a transfer of track circuit set-up to the westbound authorized conditions respectively shown in Figs. 7b, 6b and 5b. Because of these transfers the direction of "master" code transmission over the rails of each section is shifted to from west to east and the direction of "feed back" code transmission is now from east to west as shown in Figs. 10a-b-c.

Attention will next be directed to what happens when an eastbound train enters the stretch after a westbound move therethrough has been completed. After such a westbound move the several sections in the stretch have the westbound track circuit set-up conditions which are represented in Figs. 5b, 6b and 7b and which produce the combination of codes and signal indications that is shown by Fig. 10a.

Under these conditions the rails of each section between headblock locations transmit "master" code energy in the direction of from west to east and "feed back" code energy in the direction of from east to west. As a further incident to this westbound set-up the contacts of each of the traffic directional relays TD are biased to the left, as shown in each of Figs. 5b, 6b and 7b.

As an eastbound train enters the so conditioned (Fig. 10a) stretch by advancing to the position ETI of Fig. 10d, it sets up a series of operations whereby each of the relays TD returns its contact to the right position and the stick relay S at location IV releases. The first step in this series is a discontinuance (by the rail shunting action of the train) of transmission of "master" code energy eastwardly over the rails of section I-II to location II.

There relay TR becomes inactive and releases contact 134 of the associated decoding relay H; contact 134 of relay completes for the traffic directional device TD at the same location an energizing circuit which includes front contact 100 of device V, back contact 135 of device S, back contact 134 of device H and left biased contact 136 of device TD; and under the influence of this energization, relay TD at location II returns all of its contacts to the right, as shown by the full lines in Fig. 10d.

A succeeding step in the above referred to series of operations is an interruption in the supply of master code energy to the rails of section II-III produced by the just named shift of traffic directional relay contacts at location II. This interruption deenergizes relay TR at location III and causes the associated decoding relay H to release; that release completes (at contact 134) for the traffic directional relay TD at the same location an energizing circuit which includes front contact 100 of device V, back contact 135 of device S, back contact 134 of device H, and left biased contact 136 of device TD; and that energization causes relay TD at location III to return all of its contacts to the right.

A further step in the above-mentioned series of operations is an interruption in the supply of master code energy to the rails of section III-IV which the shift in directional relay contacts at location II produces. As a result of this interruption, the code following device NK at location IV becomes deenergized and releases the associated decoding relays HW and JW; that release interrupts (at contact 143) the stick circuit for relay S at the same location; and that interrupt-

tion allows relay S to return its contacts to the released position, as represented in Fig. 1e.

In the manner just described, therefore, the entry of an eastbound train into the stretch of single track immediately after the completion of a westbound movement therethrough, causes all of the traffic directional devices TD which are identified with the stretch to shift their contacts from the left to the right position and causes the stick relay S at the east headblock location IV to release. The responses by the several relays TD are, of course, successive and they progress in the direction of west to east. Accompanying each is a restoration of the track circuit to the immediate west to the eastbound set-up conditions which are represented in Figs. 5a, 6a and 7a. Hence, the operations which have just been explained serve to condition the signaling apparatus at all of the locations in the system for taking care of eastbound moves such as are identified with Figs. 9a-b-c.

In the just described control of the traffic directional relays TD, it has been seen that the stick relay S at each intermediate location (II, III and IIIa) of the system prevents (by the action of its contact 135) the energizing circuit for the associated device TD from being improperly completed when the rear of each authorized-direction train clears the location of the relay. At each of the headblock locations I and IV, however, the corresponding stick device S operates in a somewhat different manner and the form of response which is incident to that operation will now be described.

Under conditions of eastbound authorization, the device S at the west headblock location I only is picked up (with the track vacant) while under conditions of westbound authorization the device S at the east headblock location IV only is similarly picked up. Looking first at the eastbound responsive stick relay S at the west headblock location I, the relays H and V by which it is controlled are both picked up only in response to energy that is received from the east over the rails of section I-II. Under the eastbound set-up conditions of vacant track which are shown in Fig. 9a, this energy is of the "master clear" code variety and in operating the positive polar track relay NKE, it holds decoding relay H picked up in the usual manner.

With relay S picked up as shown in Fig. 1a and relay RKE inactive, the approach relay V is also maintained picked up by the code following action of contact 133 of the feed back coding device CRW which is operated over contact 12 of relay NKE. Under this condition there is completed for stick relay S a hold-up circuit which includes front contact 100 of the relay, front contact 100 of device V and front contact 143 of device H. As long as the track stretch remains vacant therefore, relay S at location I stays picked up under the eastbound set-up conditions.

Assume that an eastbound train enters the section to the immediate west of location I. Until it reaches the named location it has no effect upon relay S. As, however, the moving vehicle enters and shunts the rails of section I-II, all of the devices NKE, RKE and CRW become inactive. This releases decoding relays H and J and also drops the contacts of relay V. The hold-up circuit for the stick device S now being broken at contact 143, that device releases and performs certain functions in the signaling system which will have become apparent from earlier portions of this specification.

As the eastbound train advances through and clears the east end of section I-II, the transmission of master code energy westwardly from location II to location I is again restored; positive polar track relay NKE responds to this energy and picks up decoding relay H; and that pick-up completes at contact 143 a pick-up circuit for relay S which includes back contact 100 of relay V. Relay S now again picks up and sets up at contact 168 the before described stick circuit.

This pick-up restores the control of feed back coding device CRW to contact 12 of relay NKE and reestablishes (at contact 190) a circuit over which contact 133 of that device supplies recurring pulses of energy to the winding of relay V. Under the influence of those pulses, that relay V now picks up (but not until after the quicker responding relay H has picked up) and completes at contact 100 the before described stick circuit for relay S. In this manner the picked-up condition of that relay S is again restored and continuously maintained until either another eastbound train passes through section I-II or the track circuit set-up of the signaling system is changed to the westbound movement authorization.

Looking further now at the corresponding stick relay S at the east headblock location IV, this device (as has been mentioned) is normally picked up only under conditions of westbound authorization such as are represented in Fig. 10a. Moreover, the relays HW and V by which this device S is controlled respond only to trackway energy that is received from the west over the rails of section IV-III.

Under the westbound set-up conditions of vacant track which are shown in Fig. 10a, this energy is of the "master clear" variety and in operating the positive polar track relay NK it holds relay HW picked up in the usual manner and causes the feed back coding device CRE to respond to the code following operation of contact 12 of device NK.

This response is under picked up conditions of relay S which (over contact 190) connects relay V (over back contact 153 of device RK) in energy receiving relation with the front point of contact 133 of device CRE. By virtue of this connection relay V also is picked up and there is completed for relay S a stick or hold-up circuit which includes front contact 168 of that relay, front contact 109 of device V and front contact 143 of device HW. In this manner the stick relay S is held picked up under the westbound set-up of the vacant track.

Assume that a westbound train now approaches location IV from the east. Until it reaches that location it has no effect upon relay S. When, however, the leading vehicle enters and shunts the rails of section IV-III all of the devices NK, RK and CRE are rendered inactive and relay HW now releases, thereby breaking at contact 143 the just described stick circuit and allowing relay S also to release. Once effected, this release continues until the westbound train clears the east end of section IV-III. When that happens the supply of master code energy to location IV is again resumed; device NK responds in the before described manner and picks up relay HW; and contact 143 of that relay completes for relay S a pick-up circuit which includes back contact 100 of relay V. Relay V being slower to pick up than is relay HW, this completion picks up relay S. That relay, in turn, now continues to receive

energization over the just described circuit until such time as the feed back coding device CRE responds to the operation of contact 12 of device NK and once more picks up relay V over contact 133 thereof. When that happens contact 100 completes for relay S the stick circuit which contact 168 has previously set up and thereby restores that stick device to its original condition.

10 *Operation of complete system of Figs. 1a-e*

The apparatus and circuits which the non-line wire system of A. P. B. signaling utilizes now having been described, the manner in which this system operates to provide both directional and following protection for trains which move through the stretch of single track between the passing sidings WPS and EPS (and also approach energization of the system signals) will next be explained. As an aid to this explanation, reference will first be had to the code and signal indication diagrams of Figs. 9 and 10.

Figs. 9a and 10a apply, as has been seen, to vacant track conditions respectively following the passage of an eastbound train and of a westbound train through the stretch I-IV; Figs. 9b and 10b show the manner in which an eastbound train and a westbound train respectively alter the conditions of Figs. 9a and 10a and thereby establish their own directional protection; Figs. 9c and 10c illustrate the manner in which the eastbound train and the westbound train sets up its own following protection in advancing through the stretch; and Figs. 9d and 10d (already described) show certain preliminary steps which are incident to a reversal of authorized train movement through the stretch.

40 The eastbound set up diagram of Fig. 9a summarizes the system operation under the particular apparatus conditions which are shown by Figs. 1a to 1e and it will first be described. Under the particular conditions which are there represented, the "coded feed back" track circuits for the several sections of the stretch have the eastbound set-ups which have already been described in connection with Figs. 5a, 6a, 7a and 8.

45 As further reference to those drawing views will show, the "master" end of each of the "coded feed back" track circuit combinations in the stretch is at the east end of the circuited section 50 while the "feed back" end is at the opposite or west end of the section. As already seen, moreover, this relation results from all of the intermediate location traffic directional relays TD holding their contacts in the right biased position; at the west headblock location I it is further accompanied by a picked up condition of stick relay S and at the east headblock location IV by a released condition of the similarly designated device S.

55 Under these conditions of eastbound traffic authorization, the "coded feed back" track circuits for the several sections of the single track stretch form a part of a "frequency code" system which controls the eastbound signals SE for those sections in customary automatic block manner. As 60 illustratively represented, this signal control system is of the three-indication variety; it is operated by the "master clear" (180 pulse per minute) and the "master approach" (75 pulse per minute) 65 trackway codes of Fig. 2 that selectively are supplied to the track rails at the east end of each section (see again Figs. 5a, 6a, 7a and 8); and at the west end of each section it makes use of decoding apparatus which governs the indication 70 of the signal SE at that location and which selects

the coding of the master track circuit energy that is supplied to the section to the west. Supplementing this "frequency code" system of eastbound signal control are the already described approach energizing facilities which are operated by the "feed back" codes of Fig. 2.

Under the vacant track stretch condition of Fig. 9a, "master clear" code of 180 pulses per minute is transmitted westwardly over the rails of each of the sections in the stretch while "normal feed back A" (180 pulses of normal polarity feed back energy per minute) code is returned eastwardly over the same section rails during the master code "off" periods. Each of the eastbound signals SE is, in consequence, set up to display the green or "clear" indication; the westbound signal SW at each of the headblock locations I and IV is similarly set up; and both of the intermediate location signals SWII and SWIII are totally inactive (due to the disconnection of lamp circuit conductor 104 from supply conductor 102 at contact 99 of relay TD). As long as the track stretch remains vacant, however, no indication is actually given by any of the system signals for the reason that the feed back energized approach governing facilities now keep all of them dark.

Referring next to Fig. 10a, I have there represented the code and the signal indications which are in effect when the several "coded feed back" track circuits of the stretch sections are set up as shown in Figs. 5b, 6b and 7b to accommodate westbound train movements therethrough. Under such conditions of westbound authorization the traffic directional relays TD at all of the intermediate locations hold their contacts in the left biased position, the stick relay S at headlock location IV is picked up and the corresponding device S at headlock location I is released. This places the "master" end of each track circuit at the west end of the particular section with which it is identified and locates the "feed back" track circuit end at the opposite or east end of the section.

Under this set-up the "coded feed back" track circuits for the several sections into which the stretch of single track is divided form a part of a "frequency code" system which controls the westbound signals SW for those sections in customary automatic block manner. As in the eastbound set-up previously described, this westbound signal control system is of the three-indication variety; it is operated by the "master clear" and "master approach" trackway codes of Fig. 2 that selectively are supplied to the track rails at the west end of each section; and at the east end of each section it makes use of decoding apparatus which governs the indication of the signal SW at that location and which selects the coding of the master track circuit energy that is supplied to the section to the east. Supplementing this westbound system of automatic block control are the before described approach governing facilities which are operated by the "feed back" codes of Fig. 2.

Under the just described conditions of westbound traffic set-up, the track circuits of and the signals for the stretch between headblock locations have (as long as that stretch remains unoccupied) the condition represented in Fig. 10a. That is, "master clear" code of 180 pulses per minute is transmitted eastwardly over the rails of each section while "normal feed back A" code (of 180 normal polarity pulses per minute) is simultaneously transmitted westwardly over the

same section rails during the master code "off" periods. Under the control of the just referred to master code, each of the signals SW is set up to display the green or "clear" indication and the eastbound signals SE at the headblock locations are similarly set up. Due, however, to the approach governing action of the feed back track circuits all of these signals are maintained dark as long as the track stretch remains vacant.

10 In order that a train which enters either end of the A. P. B. stretch of single track will automatically establish its own directional protection therethrough, the complete system of my invention includes provision whereby advancement of the leading vehicle of the train past the entering headblock location (I or IV of Figs. 1a-e) successively conditions the track circuits ahead in such manner as to set the headblock signal for opposing traffic at "stop." As already indicated, moreover, the same system further includes provision whereby every train that travels through the stretch in either direction automatically sets up its own following protection (by controlling the wayside signals therebehind in the usual automatic block system manner) and also approach energizes the wayside signals and the cab signal control facilities in advance.

30 To explain further how the just mentioned forms of signal control and train protection are provided under various operating conditions of the complete system of Figs. 1a-e, representative eastbound train moves will first be traced through the A. P. B. stretch of that composite diagram and following this a similar tracing of 35 representative westbound train moves will be made.

Eastbound train moves

40 It will first be assumed that preceding each of these moves the track circuits throughout the entire length of the stretch have the eastbound set-up previously described in connection with Fig. 9a and that the stretch is vacant. Under such conditions it has been seen that the rails of each of the sections in the stretch repeatedly transmit first a pulse of "master clear" (180 pulse per minute) code energy in the direction of from east to west and then a pulse of "normal feed back A" (positive polar) code energy in 45 the direction of from west to east.

50 At the west headblock location I this positive polar feed back energy which is received from the west operates the positive polar track relay NKW and holds the repeating device NP therefor picked up. That action, in turn, keeps (at contact 88) the eastbound headblock signal SEI deenergized. However, the "master clear" code energy which is received at the same location from the east operates the positive polar track relay NKE and thereby holds decoding relays H and J both picked up. This action sets up (at contacts 83 and 84) the "clear" indication circuit for the just named headblock signal SEI.

55 At location II the positive polar feed back energy which is there received from the west, operates the positive polar track relay NK and thus causes (through contacts 94 and 95) the feed back selector relay KS to be picked up and (through contact 155) the approach relay V also to hold its contacts in the uppermost position. That action maintains (at contact 100) the eastbound signal SEII disconnected from its energizing source. However, the "master clear" energy which is received at the same location from the east operates the track relay TR and thereby

holds both of the decoding relays H and J picked up. That action, in turn, sets up (at contacts 83 and 84) the "clear" indication circuit for the just named signal SEII.

At location III the positive polar feed back energy received from the west operates the positive polar track relay NK and thereby holds (over contacts 94 and 95) the polar selector relay KS picked up and also maintains (through contact 155) the approach relay V picked up. The latter device keeps (at contact 100) the lighting circuits for the eastbound signal SEIII disconnected from their energizing source. However, the "master clear" code energy which is received at the same location from the east operates the track relay TR and thus holds both of the associated decoding relays H and J picked up. That action sets up (at contacts 83 and 84) the "clear" indication circuit for the just named signal SEIII.

At location IIIa, the pulses of both the westwardly flowing master code energy and the eastwardly flowing feed back code energy are repeated around the rail joints 3 in a manner which is described in greater detail in a later portion of this specification. Because of this repeating action the "coded feed back" track circuits which are identified with block III-IV operate in the same manner as were the cut IIIa not present therein.

At the east headblock location IV, accordingly, the positive polar feed back energy which is received from the west operates the code following track relay NK and thereby holds both of the associated decoding relays HW and JW picked up and also recurrently completes (over contact 12) for the approach relay V an energizing circuit which includes back contacts 190 and 153 of devices S and RK and which holds relay V continuously picked up. That action disconnects (at contact 93) the lighting circuits of eastbound signal SEIV from their energizing source.

However, the "master clear" code which is received at the same location from the east operates track relay TR and thereby holds the associated decoding relays HE and JE both picked up. That action sets up (at contacts 83 and 84) the "clear" indication circuit for the just named signal SEIV. Concurrently the pick-up of relay HW, which was described in the preceding paragraph, maintains (at contacts 71 and 78) the feed back battery KB connected in positive polarity supplying relation with the rails of the section to the immediate east of location IV.

In the manner just detailed, therefore, the eastbound signals SE for the stretch of single track between passing sidings WPS and EPS have the condition which is represented in Fig. 9a when that stretch is vacant and when all of the track circuits therein have the eastbound set up which is represented in Figs. 5a, 6a and 7a.

Each eastbound train which now enters the stretch at location I automatically sets up its own directional protection by causing the westbound headblock signal SWIV to go to "stop." The manner in which this action takes place will now be explained by reference to Fig. 9b.

As the eastbound train approaches the vacant A. P. B. stretch from the west, it gets a "clear" indication from the eastbound headblock signal SEI as soon as the forward portion of the train first enters the section to the immediate west of location I. That entry, of course, shunts the rails of the mentioned section and by deenergizing both of the relays NKW and RKW at the

named location effects the release of both of the repeater devices NP and RP; that release, in turn, completes (over contacts 87 and 88) the previously set up circuit over which the lamp G of signal SEI receives lighting current and causes that signal to display the just mentioned "clear" indication.

As the leading vehicle of the eastbound train advances to the position represented at ET¹ in Fig. 9b (wherein it has passed the west headblock location I and shunted the rails of section I-II), it cuts off the transmission of feed back code energy to both of the polar track relays NK and RK at location II and causes the there associated relays V and KS both to release. Contact 100 of relay V now completes the previously set up "clear" indication circuit for eastbound signal SEII. At the same time contacts 47 and 48 of the polarity selector relay KS now reverse the connections of battery KB with the rails of section II-III and thereby cause the recurring pulses of feed back energy received by those rails to have the negative or "reverse" polarity.

At location III this "reverse feed back A" code energy is ineffective for operating the positive polar track relay NK and instead produces a response on the part of the negative polar device RK. That device holds (over contact 153) the approach relay V picked up and thereby maintains the eastbound signal SEIII in the dark condition which is represented in Fig. 9b.

At the same time the now inactive positive polar device NK allows the relay KS at location III which it controls to release and thereby reverse (at contacts 47 and 48) the connection of the feed back battery KB with the rails of section III-IV. In consequence the rails of that section now receive energy of the "reverse feed back A" code. The pulses of this reverse polarity energy are repeated around the cut section IIIa and hence reach the east headblock location IV in regular manner.

At the east headblock location these negative polar pulses are ineffective for operating the positive polar track relay NK and instead they produce a response on the part of the companion device RK. It, in turn, now maintains (over contact 153) the approach relay V picked up and thus keeps (at contact 93) the eastbound signal SEIV disconnected from its lighting source.

The now inactive positive polar relay NK at location IV allows both of the associated decoding relays HW and JW to release and thereby sets up (over contacts 83 and 84) the "stop" indication circuit for the westbound headblock signal SWIV. If a westbound train, such as is represented at WEI in Fig. 9b, now comes into the section to the immediate east of location IV the resulting deenergization of relay TR at that location and the dropping of the associated decoding relays HE and JE completes (at contact 92) the just set up lighting circuit for lamp R of signal SWIV and thereby causes that signal actually to show "stop."

This "stop" indication thus warns approaching westbound traffic that an eastbound train has entered the west end of the A. P. B. stretch and is proceeding therethrough; it constitutes the before mentioned directional protection for eastbound train moves; and, as has been seen, it is provided without the aid of line wires for signal control purposes. Once set up in the manner stated, moreover, the named indication is continued as long as any part of the eastbound train remains in the A. P. B. stretch. That con-

tinuance results, as will be seen, from the fact that each advance of the train into the succeeding track section to the east does not alter the previously effected supply of reverse polarity feed back energy to the rails of the track section ahead.

Thus, as the eastbound train ET₁ of Fig. 9b advances past location II it merely removes all feed back code energy from section II-III and by releasing relay V at location III it causes signal SEIII at that location to display the previously set up "approach" indication. As previously stated the positive polar track relay NK continues inactive so that selector relay KS at location III remains released thereby causing the feed back energy supplied to section III-IV to retain its previous reversed polarity and thereby continue to hold the westbound headblock signal SWIV at "stop."

Similarly, as the eastbound train ET₁ of Fig. 9b advances past location III it merely removes all feed back energy from the rails of section III-IV and by releasing the approach relay V at location IV causes the eastbound signal SEIV to display the previously set up indication of "stop" (produced when as represented at WT₁ a westbound or other train is in the section to the immediate east of location IV). As before, however, the positive polar relay NK remains inactive and causes decoding relay HW to continue to hold the westbound headblock signal SWIV at "stop."

In the manner just described, therefore, once the "stop" indication by the westbound headblock signal SWIV has been set up by the entry of an eastbound train into the single track stretch between passing sidings, this set-up continues uninterruptedly as long as any portion of the train remains within the stretch.

In addition to providing the just explained directional protection for eastbound train moves, the improved non-line-wire A. P. B. system of my invention further affords the usual following protection for eastbound trains and does this, moreover, wholly by means of coded energy which is transmitted through the track rails. This following protection results from a functioning of the earlier described "frequency code" system of automatic block control for the eastbound signals SE (which under the eastbound track circuit set-up conditions of Figs. 9a-b-c is operated by "master" code energy transmitted over the rails of each track section in the direction of from east to west).

Referring to the eastbound set-up representations of Figs. 9a-b-c and also to the corresponding apparatus representations of the composite diagram of Figs. 1a-e, the following actions will be seen to accompany the passage of an eastbound train through the single track stretch. In entering the stretch from the west and advancing past locations I, II, III and IV thereof, this train successively deenergizes (as previously pointed out) the master code operated track relay at those locations (device NKE at I; TR at each of II, III and IV) and thus successively conditions: (1) each of the eastbound wayside signals SEI, SEII, SEIII and SEIV to show "stop"; and (2) each associated master coding relay CR and track battery TB to supply the rails of the section to the west with energy of the 75 pulse per minute "master approach" code.

Once established, each of these "stop" aspect conditionings persist until the trailing vehicle of the train clears the next location to the east. When that happens: (1) The rails of the just

vacated section transmit this "master approach" code energy to the relay TR (or NKE) at the west end thereof; (2) the wayside signal SE at that west end is thereby conditioned to show "approach"; and (3) the track battery TB and master coding relay CR at the same location are caused to supply the rails of each section to the west with energy of the 180 pulse per minute "master clear" code.

At the west end of that section the track relay TR (or NKE) responds in the usual manner and: (1) conditions the wayside signal SE which it controls to display "clear"; and (2) causes the track battery TB and master coding relay CR to supply "master clear" code energy to the rails of the succeeding section to the west. At the west end of that section (and also at the west end of each succeeding section of vacant track still further to the west) these same actions are repeated. It will thus be seen that in the eastbound set-up of track circuits which I have represented in Figs. 1a-e, 5a, 6a, 7a, 8 and 9a-b-c, the "frequency code" scheme of automatic block signaling provides the conventional form of following protection for eastbound train moves. That is, as long as an eastbound train occupies (and shunts the rails of) a section of the system track, the wayside signal SE at the west (eastbound entrance) end of that section is conditioned to show "stop"; the next signal SE to the west is conditioned to show "approach"; and succeeding signals SE to the west are conditioned to show "clear." As, moreover, the train moves eastwardly along the rails the above stated combination of signal indications continues to be maintained behind it and in this way following protection for eastbound moves is at all times provided.

In the event, for example, that a leading eastbound train occupies the position shown at ET₁ in Fig. 9c, a following eastbound train in position ET₂ will get the "approach" indication from signal SEII. Should this following train advance into section II-III while the leading train is still in section III-IV, it will then get the "stop" indication from signal SEIII; if, however, the following train is only approaching the west headblock location I while the leading train is in section III-IV, it will then get the "clear" indication from signal SEI; and so on.

Westbound train moves

Following the passage of each eastbound train through the single track stretch, the signaling apparatus therefor has the condition before described in connection with Fig. 9a. However, upon entry of a westbound train into the east end of the stretch (as shown at WT₁ in Fig. 9d), the contacts of all of the traffic directional relays TD are (in the manner previously described in detail) shifted to the left and the track circuit set ups for all of the sections within the stretch are thereby changed to the westbound authorized conditions which are represented in Figs. 5b, 6b and 7b.

To facilitate explanation, it will first be assumed that the original westbound train advances through and out of the stretch at the west end thereof. This advancement causes the vacant track and associated wayside signals to assume the conditions which are represented in Fig. 10a. These conditions have already been described generally and they will now be examined in somewhat greater detail.

Under them the track circuits for the sec-

tion extending to the west of headblock location I and also to the east of headblock location IV remain the same as under conditions of eastbound authorization (Figs. 9a-b-c) and are represented in Fig. 8. There it will be seen that the "master" track circuit end remains at the east end of the section while the "feed back" end remains at the west end of the section. Hence, in the diagram of Fig. 10a, the "master clear" code is transmitted to the west away from location I and is received from the east at location IV. In the case of each of the track sections between these headblock locations, however, the direction of "master" code energy transmission is from west to east, while the direction of "feed back" code transmissions is from east to west.

Looking more closely at the east headblock location IV, when the track stretch is vacant and the track circuits for the sections thereof have the westbound set-up of Fig. 10a, the stick relay S at the named location is held picked up over front contact 168 thereof, front contact 100 of device V and front contact 143 of device HW. Prior to completion of this stick circuit the original pick-up action of the relay S resulted from an initially released condition of the approach relay V which was preceded by a pick-up of relay HW, whereby stick relay S was energized over back contact 100 of device V and front contact 143 of device HW.

At this location IV the 180 pulse per minute "master clear" code (which is there received from the west) operates the positive polar track relay NK and by maintaining the associated polar relays HW and JW picked up establishes (at contacts 83 and 84) the "clear" indication set-up for the westbound headblock signal SWIV. At the same time the "master clear" code which is received at the named location from the east operates track relay TR and by holding the associated decoding relay HE picked up keeps the just named signal SWIV disconnected (at contact 92) from its source of lamp lighting current.

At location III the "master clear" code which is there received from the west similarly operates the track relay TR at that location and by holding the associated decoding relays H and J both picked up completes (at contacts 83a and 84a) the "clear" indication set up for westbound signal SWIII. At the same time, the "normal feed back A" code energy which is received at the named location from the east operates the positive polar track relay NK, and thus holds (at contact 175) the approach relay V picked up. Contact 100 of that relay now keeps the just named signal SWIII disconnected from its lamp lighting source.

At location II the "master clear" code energy which is there received from the west operates the track relay TR and by holding the associated decoding relays H and J both picked up completes (at contacts 83a and 84a) the "clear" indication set-up for the westbound signal SWII. Like the devices SWIV and SWIII, however, this signal remains dark due to the reception at location II of "normal feed back A" code energy from the east and response thereto by devices NK and V.

And finally, at the west headblock location I, the reception of the "normal feed back A" code energy from the west causes the normal polarity track relay NKW there to respond and pick up the repeater device NP. The companion positive polar device RKW is now inactive so that

its repeater RP remains released. Contact 96 of relay NP thus completes the "clear" indication set-up for westbound signal SWI. Due, however, to the response by track relay NKE at location I to coded feed back energy received from the east, the approach relay V is maintained pick up (under the action of contact 12 of device NKE and over a circuit which includes back contact 190 of device S and back contact 153 of device RKE) and contact 93 keeps the lighting circuits of the just named signal SWI disconnected from their energizing source.

Thus, under the westbound traffic set-ups for the system track circuits and with the entire length of the single track stretch vacant, the condition of the several westbound signals SW is as shown in Fig. 10a. Each westbound train which now enters the track stretch automatically sets up its own directional protection. It does this by causing the eastbound headblock signal SEI at the advance location I to go to "stop" in a manner which will now be explained by reference to Fig. 10b.

As the westbound train enters the section to the immediate east of the east headblock location IV, the shunting action of its wheels and axles deenergizes the track relay TR at the named location; that action releases the associated decoding relays HE and JE; and that release connects (at contact 92) the lighting circuits of the westbound headblock signal SWIV with their energizing source. The latter action, of course, causes the just named signal to display the previously set up indication of "clear."

As the westbound train advances to the position shown at WT¹ in Fig. 10b and shunts the rails of section IV-III, the feed back operated track relay NK at location III becomes deenergized and releases both the approach relay V and the polar selector relays KS at the same location; this release of relay V causes (at contact 100) the westbound signal SWIII to display the previously set up indication of "clear"; and the named release of relay KS reverses (at contacts 47 and 48) the connection of feed back battery KB with the rails of section III-II and thereby causes those rails to transmit "reverse" feed back code westwardly to location II.

At that location II this reverse feed back energy operates the negative polar track relay RK and allows the companion positive polar device NK to remain inactive. That relay RK now holds the approach relay V at the same location picked up and thereby maintains the westbound signal SWII dark. At the same time the continuous deenergization of device NK causes the polarity selector relay KS to release and so shift (at contacts 47 and 48) the connection of battery KB with the rails of section II-I that the coded feed back energy now received by those rails is of "reverse" polarity.

In feeding westwardly over the section rails to the west headblock location I, that "reverse feed back" energy operates the there located negative polar track relay RKE and allows the companion positive polar device NKE to be inactive. In consequence, the associated decoding relays H and J both release and thereby set up (at contacts 83 and 84) the "stop" indication circuit for the eastbound headblock signal SEI. If, as is shown at ET¹ in Fig. 10b, an eastbound train is in the section to the immediate west of location I both of the devices RKW and NKW will be released and contacts 87 and 88 thereof

will complete the previously set up "stop" indication circuit for the just named signal SEI.

The resulting showing of "stop" by this eastbound headblock signal warns approaching eastbound traffic that a westbound train has entered the east end of the A. P. B. stretch and is proceeding therethrough; it constitutes the before mentioned directional protection for westbound train moves; and, as has been seen, it is provided without the aid of line wires for signal control purposes. Once thus set up, moreover, the just named signal indication is uninterruptedly continued as long as any part of the westbound train remains in the A. P. B. stretch. That continuance results, as will be seen, from the fact that each advance of the train into a succeeding track section to the west does not disturb the previously set up supply of reverse polarity feed back energy to the rails of the track section still further to the west.

Thus, as the westbound train WT¹ of Fig. 10b advances into section III-II, it merely discontinues the supply of feed back energy to location II. While this action there releases relay V and lights the signal SWII, it does not interfere with the previously established supply of reverse feed back energy to the rails of section II-I. Hence, the "stop" indication set-up for the eastbound headblock signal SEI is continued.

Finally, as the westbound train WT¹ of Fig. 10b further advances into section II-I, it merely discontinues the westward transmission of all feed back energy to location I. While that action releases V and thus completes the preselected lighting circuit for the westbound signal SWI, it does not disturb the "stop" indication showing by the eastbound headblock signal SEI. In the manner just explained, therefore, the westbound directional protection which this indication affords is continued uninterruptedly as long as any part of the westbound train remains in the A. P. B. stretch.

The manner in which following protection for westbound train moves is provided will now be explained. This following protection is automatically set up behind every westbound train that travels through the stretch and it results from the functioning of the earlier described "frequency code" system of automatic block control for the westbound signals SW (which is operated by "master" code energy transmitted over the rails of each track section in the stretch in the direction of from west to east, as represented by Figs. 10a-b-c).

During westbound moves the automatic block control scheme for the westbound signals functions in a manner which will now be explained by reference to the above mentioned views of Fig. 10. In entering the stretch from the east and advancing past locations IV, III, II and I thereof, a westbound train successively deenergizes (as previously pointed out) the master code operated track relays at those locations (device NK at IV, and TR at III, II and I) and thus successively conditions: (1) each of the westbound signals SWIV, SWIII, SWII and SWI to show "stop"; and (2) each associated track battery TB and master coding relay CR to supply the rails of the section to the east with energy of the 75 pulse per minute "master approach" code.

Once established, this "stop" aspect conditioning persists until the trailing vehicle of the train clears the next location to the west. When that happens: (1) The rails of the just vacated sec-

tion transmit this "master approach" code energy to the track relay (TR or NK) at the east end thereof; (2) the wayside signal SW at that end is thereby conditioned to show "approach"; and (3) the track battery TB and the master coding relay CR at the same location are caused to supply the rails of the section to the immediate east with energy of the 180 pulse per minute "master clear" code.

At the east end of that section, the track relay TR (or NK) responds in the usual manner and: (1) conditions the westbound signal SW which it controls to display "clear," and (2) causes the track battery TR and the master coding relay CR to supply "master clear" code energy to the rails of the succeeding section to the east. At the east end of that section (and also at the east end of each succeeding section of vacant track still further to the east) these same actions are repeated.

It will thus be seen that the "frequency code" scheme of automatic block control for the westbound signals SW provides the conventional form of following protection for westbound trains. That is, as long as a westbound train occupies (and shunts the rails of) a section of the single track, the wayside signal SW at the east (westbound entrance) end of that section is conditioned to show "stop"; the next signal SW to the east is conditioned to show "approach"; and succeeding signals SW to the east are conditioned to show "clear." As, moreover, the train moves westwardly along the rails the above stated combination of signal indications continues to be maintained behind it and in this way following protection for westbound moves is at all times provided.

In the event, for example, that a leading westbound train occupies the position shown at WT¹ in Fig. 10c, a following westbound train in position WT² will get the "approach" indication from signal SWIII. Should this following train advance into section III-II while the leading train is still in section II-I, it will then get the "stop" indication from signal SWII; if, however, the following train is only approaching location IV while the leading train is in section II-I, it will then get the "clear" indication from signal SWIV; and so on.

Following the passage of each westbound train through the single track stretch, the signaling apparatus therefor has the condition already examined in connection with Fig. 10a. However, upon entry of an eastbound train into the west end of the stretch (as shown in Fig. 10d) the contacts of all of the traffic directional relays are (in the manner previously described in detail) shifted to the right. This returns the track circuit set ups to the eastbound authorized conditions of Figs. 1, 5b, 6b and 7b and so prepares the stretch for the passage of eastbound traffic.

The improved non-line-wire A. P. B. system of my invention also provides the usual protection of the siding spanning section (such as IV-I of Fig. 8) from improper entry by a train whenever the track switch at either end of the siding track is thrown to the "take siding" position. In each of Figs. 1a and 1e such a track switch is represented by the symbol W. For the purpose of putting both the eastbound signal SE at the west end of the section and the westbound signal SW at the section east end at "stop" when either of the switches W of Fig. 8 is thrown to the "take siding" position, each of these switches W is equipped with the usual contact 208 which by-

passes the rails of the main track 1—2 under the conditions just stated.

Assume, for example, that after having passed completely through the single track stretch of Figs. 1a—e an eastbound train is switched upon the passing siding EPS (of Fig. 1e) for the purpose of freeing the main track 1—2 to carry opposing or westbound trains into the east end (headblock location IV) of the single track stretch. Such a switching movement is of course, preceded by the usual shifting of the track switch W at the siding west end to the "take siding" position; this causes the switch contact 208 to shunt the rails of the section (see Fig. 8) of which location IV marks the west end and thereby deenergize the master code track relay TR at the section west end and the feed back code track relays RKW and NKW at the section east end. The former action sets up the red or "stop" indication circuit for eastbound 15 signal SEIV of Fig. 1e while the latter similarly sets up the "stop" circuit for the westbound signal SW which is positioned at the opposite or east end of the section and which corresponds to device SW1 of Fig. 1a.

Once all of the vehicles of the eastbound train are upon the passing siding EPS, switch W is returned to the illustrated "through traffic" position. Contact 208 now removes the shunt from the rails of the siding spanning section (IV—I of Fig. 8); the associated master track relay TR and the feed back track relays RKW and NKW again resume normal operation; and both of the signals SE and SW at the section ends are once more restored to the "clear" indication set up 35 of their lamp circuits.

Cab signal operation

The improved non-line-wire A. P. B. system of the composite diagram of Figs. 1a—e is adapted to control not only the wayside signals SE and SW in the manner just described, but also to produce corresponding indications on board each train (when within the protected territory) that is equipped with cab signaling apparatus of conventional "frequency selective" character. Such train carried cab signaling and/or brake control apparatus is well known in the art (see Paul N. Bossart Patent No. 1,773,472 dated August 19, 1930) and the circuits of one illustrative 40 form thereof are represented in Fig. 15.

In those illustrative circuits use is made of the usual pick-up windings 200 and 201 mounted on the locomotive front; an amplifier 202 which strengthens the energy which these windings inductively receive from the track rails 1 and 2; a code following master relay MR which is energized (through a transformer 203) by the output of this amplifier and which responds to each pulse of the received trackway energy regardless of its relative instantaneous polarity; a decoding transformer DT which is supplied with code step pulses of exciting current over a pole changing contact 85a of the master relay; a pair of transformer output circuits which respectively include a rectifier contact 86a of relay MR and a frequency selective unit 180DU; decoding relays DRH and DRJ which respectively receive pick-up current from those two output circuits; and a cab signal CS and/or train control device (not shown) having a plurality of indicating units which are selectively energized under the control of the decoding relays.

The elements just named cooperate in such a way that: (1) When the master relay MR fol-

lows trackway code of the 180 pulse per minute variety, both of the decoding relays DRH and DRJ pick up and light (over front contacts 83 and 84) the green or "clear" indication lamp G of the cab signal CS; (2) when the master relay follows trackway code of the 75 pulse per minute variety, only the first decoding relay DRH picks up and front contact 83 and back contact 84 then complete the lighting circuit for the yellow or "approach" indication lamp Y of the signal; and (3) when the master relay ceases to follow code both of the decoding relays release and light (over back contact 83) the red or "stop" indication lamp R of the cab signal.

For the purpose of operating cab signaling apparatus of the conventional type of Fig. 15, the previously described trackway apparatus of my invention includes facilities which at times superimpose upon each direct current pulse of "master" code (see Fig. 2) energy a wave of alternating current energy of 100 cycles per second or other preselected carrier wave frequency. In the disclosed arrangement of that apparatus, the alternating current potential necessary to produce this superimposed cab signal control wave is introduced into each "master" rail supply circuit by a transformer 15; that transformer, in turn, may be energized either over a direct connection with alternating current power source terminals B and C (as shown in Fig. 4) or it may form a part of a locally excited tuned alternator TA (as shown in the composite diagram of Figs. 1a—e).

In the latter instance, as already explained, it is preferable that each of the alternators TA be brought into action only when cab signal control energy actually is needed in the section rails. To this end each of the represented alternator exciting circuits is arranged to be completed only when an approach relay contact (member 130 of device V at all locations; also members 149—150 of devices NP and RP at headblock location I; also member 92 of device HE at headblock location IV) releases in response to the entry of a train into the section with which the alternator is identified.

In the further interest of conserving local control energy, moreover, each of the alternator supply circuits of Figs. 1a—e is shown as including the front contact 133 of the associated coding device CR. Under active conditions of the alternator this contact allows the exciting circuit therefor to be deenergized during the "off" periods of the "master" code which the coding contact (6 or 9) of the device produces. Still further, this superimposed cab signal control energy is supplied by the represented devices TA only in connection with the "master" codes of Fig. 2 and with but a single exception (later to be described for headblock location IV) it is never supplied to the "feed back" end of any of the track circuits.

Hence, under the conditions of eastbound traffic authorization which are represented in Figs. 9a—b—c, the supply of this cab signal control energy is at the east or "master" end of each of the track sections in the system and it flows westwardly toward the locomotive or other leading vehicle of each approaching eastbound train; under the conditions of westbound traffic authorization which are shown in Figs. 10—a—b—c the cab signal energy is supplied at the west end of each section and it flows eastwardly toward the locomotive or other leading vehicle of each westbound train which passes through the stretch.

When, therefore, this leading train vehicle is provided with the cab signaling equipment of Fig. 15, the signal CS thereof will show "clear" when the vehicle is in a section which is receiving 180 pulse per minute "master clear" code energy at the exit end thereof; the signal CS will show "approach" when the vehicle is in a section which is receiving 75 pulse per minute "master approach" code energy at the exit end; and the train carried unit CS will show "stop" when the leading vehicle is in a section across the rails of which an advance train vehicle places a shunt between the section exit end and the signal carrying vehicle.

In this way the cab device CS on the leading vehicle of each train that passes along the A. P. B. stretch of Fig. 1 is caused to display an indication which bears a definite relation to that being given by the wayside signal (SE or SW) which is immediately in advance of the device carrying train. If, for example, this train is an eastbound one the rails of each section into which it advances will, as indicated in Figs. 9a-b-c, be supplied at the east end of that section (by devices TB and TA in the manner previously described) with recurring pulses of "master" code energy which include a superimposed alternating current component and which recur at one or the other of the 180 "clear" and 75 "approach" pulse per minute rates. When received by the train pick-up devices this energy causes the cab signal CS to display whichever one of the "clear" or "approach" indications advance traffic conditions in the eastward direction may make appropriate.

This action takes place not only at each of the sections between the two headblock locations I and IV but also in the case of sections, such as that represented in Fig. 8, which parallel the passing sidings PS. In each of these (as in each of those between headblock locations), the "master" code energy is supplied at the east end of the section which marks the exit for eastbound traffic and during all of the time that the train is within the section each pulse of this master code energy has superimposed thereon a wave of cab signal control current produced by device TA.

Accordingly, with a leading eastbound train at position ET₁ in Fig. 9c, the cab signal indication on a following eastbound train will be: (1) "clear" when the following train is approaching location I from the west (over rails that are transmitting "master clear" code thereto) and after it has advanced to position ET₂ in section I-II (the rails of which also are transmitting "master clear" code energy); (2) "approach" when the following train has further passed on into section II-III where it receives energy of the "master approach" code from the rails thereof; and (3) "stop" when the following train has still further advanced into section III-IV and by the shunting action of the advance eastbound train ET₁ is there prevented from receiving coded energy from location IV.

The manner in which the same cab signaling apparatus of Fig. 15 is operated when carried aboard a westbound train will now be considered. Under the conditions of westbound authorization which are shown in Figs. 10a-b-c, the rails of each of the sections between headblock locations I and IV are supplied with "master" code energy at the west end of the section; upon entry of a westbound train into the section each pulse of this master code energy has superimposed thereon a wave of alternating current which is suitable

for the control of the cab signals; and, depending upon the traffic conditions in advance (still further to the west), these pulses recur either at the 180 "clear" or the 75 "approach" rate.

5 In the manner stated, therefore, the cab signal CS aboard each westbound train is caused to display one or another of the before described indications of "clear," "approach" and "stop" as long as the train is in any of the sections between 10 headblock locations IV and I.

An equivalent form of control, moreover, takes place when the westbound train advances beyond location I and enters the siding spanning section immediately to the west thereof. As shown in 15 Fig. 8 (and as has already been explained), the west end of each of these siding spanning sections includes provision whereby the presence of a train in the section releases relay HE and causes contact 73 thereof to transfer the control of coding device CRW to contacts 180a and 75a of transmitters CT180 and CT75 at that section west end. As is shown in greater detail at location IV in Fig. 1e, selection between the two just named coding contacts is effected by relay HW over contact 81 thereof and in accordance with advance traffic conditions to the west of the location.

Hence, when the westbound train enters section 30 I-IV of Fig. 8 there is supplied at the section west end special cab signal control pulses which include the required alternating current component introduced by transformer 15 of device TAE (see Fig. 1e) and which recur either at the 180 or the 175 rate, as determined by advance traffic conditions. By the aid of this special energy, cab signals (of the type shown in Fig. 15) 35 aboard the westbound train are controlled in the desired manner while the train is passing through the section of track which spans each passing siding PS, as shown in Fig. 8.

40 Hence, when a following westbound train is equipped with cab signaling apparatus of the type shown in Fig. 15, signal CS thereof will display: (1) "clear" as long as the leading vehicle of the train is in the section that is supplied (at its 45 west end) with 180 pulse per minute trackway energy having the alternating current cab signal control wave superimposed thereon; (2) "approach" when the signal carrying vehicle is in a section that is supplied with 75 pulse per minute 50 energy of similar character; and (3) "stop" when the leading train vehicle is in a section that is shunted by an advance westbound train.

When, therefore, a leading westbound train is 55 in position WT₁ of Fig. 10c, the cab signal indication on a following westbound train will be: (1) "clear" when the following train is approaching location IV (over rails from which it receives specially generated 180 pulse per minute code) and after it has advanced to position WT₂ in section 60 IV-III (over rails from which it receives the "master clear" code of Fig. 2); (2) "approach" when the following train has further passed on into section III-II (over rails from which it receives energy of the "master approach" code); and (3) "stop" when the following train has still 65 further advanced into section II-I that already is occupied by the advance westbound train WT₁.

Cut section facilities

70 All of the description so far given has assumed that the rails of each of the main signal block lengths (I-II, II-III, III-IV, etc.) of track in the A. P. B. system are electrically continuous and thus constitute the conductors of but a single track section. In the composite diagram of Figs.

1a-e, such a condition is in fact shown for each of the sections I-II and II-III.

My improved non-line wire scheme of A. P. B. signaling is, however, not restricted to applications of this type alone, but may also be applied to stretches of track wherein one or more of the main signal blocks is, because of excessive length or other reasons, divided into two or more track circuit sections. In such situations I propose to equip each point of signal block subdivision with cut section facilities of the type represented in Fig. 1d. There a subdividing location, designated by the character IIIa, is shown as being produced by interposing insulated rail joints 3 between the west and the east ends of the signal block III-IV of Figs. 1c-e. Obviously, of course, the same facilities may be used in a comparable manner in any of the remaining signal blocks in the A. P. B. system.

When so installed, the cut section facilities of Fig. 1d perform functions which are comparable to those performed by the equipment at each of the intermediate signal locations II and III of Figs. 1b and 1c. At the cut location IIIa, however, these functions differ in that no wayside signals are there controlled and also in that no trackway codes are there independently generated.

Looking more closely at Fig. 1d, it will be seen that the apparatus utilized at the cut location IIIa includes: (1) a traffic direction relay TD which is a duplicate of the similarly identified device at each of the intermediate locations II and III; (2) track circuit apparatus comprising elements TR, KR, KS and KB also arranged as at the intermediate signal locations; (3) other track circuit apparatus comprising elements TB, RK, NK and TA which correspond to similarly identified devices at the intermediate locations; and (4) decoding, approach and stick relays H, V and S which likewise function in the same manner as at the intermediate locations.

Instead, however, of forming a part of a separate coding relay CR, the contact 6 over which the track battery TB and tuned alternator TA are periodically connected with the track rails is carried by the impulse relay KR. This same relay also operates the companion contact 133 which prolongs the hold-up time of each of devices NK and RK and which breaks the exciting circuit for alternator TA during the "off" periods of the master code.

Under conditions of eastbound traffic authorization the contacts of relay TD at the cut location IIIa are biased to the right, as at the intermediate signal locations II and III. Contacts 65 and 66 now connect elements TR, KR and KB with the rails which extend to the east of the cut while contacts 27 and 18 connect elements TB, TA, RK and NK with the rails which extend to the west of the cut.

"Master" code energy now received from location IV to the east operates relay TR and thus causes elements KR and KB at the cut location IIIa to return feed back energy to the eastwardly extending rails during the master code "off" periods. If relay KS is picked up, this feed back energy will be of "normal" polarity, while if relay KS is released it will have the opposite or "reverse" polarity.

In so recurrently picking up and releasing, the impulse relay KR at the cut section causes contact 6 thereof: (1) to complete for the rails which extend to the west a "master" code energy repeating circuit each time that the contact is

picked up; and (2) to connect the polar track relays NK and RK in energy receiving relation with those rails each time that the contact is released. The just named "master energy" repeating circuit may be traced from the positive terminal of battery TB through conductor 14, transformer 15 of device TA, conductor 16a, front contact 6 of relay KR, conductor 16, right biased contact 18 of device TD, conductor 19, the westwardly extending rails 2 and 1, conductor 26, right biased contact 27, conductor 28, and impedance 29 back to the negative terminal of battery TB. The just named "feed back" energy receiving circuit for relays NK and RK extends from track rail 2 through conductor 19, right biased contact 18 of device TD, conductor 16, back contact 6 of device KR, conductor 16b, the control windings 8 of relays NK and RK, conductors 36 and 28, right biased contact 27 of relay TD, and conductor 26 back to rail 1.

If approach relay V is released (as it is when section III-IIIa is occupied), each of the resulting pulses of repeated "master" code energy from battery TB has superimposed thereon alternating current cab signal control energy from device TA. This is because the now released contact 130 of device V sets up for the tuned alternator TA an exciting circuit which is completed each time that contact 133 of the impulse relay KR is picked up to produce a master code "on" period. If, however, section III-IIIa is vacant, then the apparatus at location III responds to the master code energy there received from the east end returns "feed back" energy which operates one or the other of the polar track devices NK and RK, depending upon the polarity of that energy.

If this polarity is "normal" then relay NK responds to hold (at contact 155) the approach relay V picked up and to supply (over contacts 94 and 95) pick-up energy to the polarity selector relay KS at the cut location. If the feed back pulses which are there received from the west are of "reverse" polarity then relay RK only responds. While this response keeps (at contact 153) the approach relay V picked up and the tuned alternator TA inactive, it is ineffective for energizing relay KS and contacts 47 and 48 thereof now release. This release reverses the connections of battery KB with the eastwardly extending rails and thereby causes to be repeated into those rails the same "reverse feed back" code which was received from the west.

It will, therefore, be seen that under conditions of eastbound authorization the facilities at the cut section IIIa of Fig. 1d: (1) repeat around the insulated joint 3 and into the rails of the westwardly extending section each of the "master" codes which is received from the eastwardly extending rails; (2) similarly repeat into the rails of the section extending to the east each of the "feed back" codes which is received from the westwardly extending rails; and (3) supplement each pulse of repeated direct current "master" code energy by a superimposed wave of alternating current which is suitable for cab signal control when such control is occasioned by the entry of an eastbound train into the westwardly extending section. In view of these functions, the main signal block of which the cut location facilities form a part operates under eastbound authorized conditions in the same manner were the cut not to be present therein.

Under conditions of westbound authorization, the traffic directional relay TD at the cut loca-

tion IIIa of Fig. 1d holds its contacts in the left position (as does the corresponding device at each of the intermediate signal locations II and III); contacts 27 and 28 thereof now connect the "feed back" end devices TR, KR and KB with the rails which extend to the west of the cut; and contacts 65 and 66 now connect the "master" end devices TB, TA, NK and RK with the rails which extend to the east of the cut.

Master code energy now received from the west 10 location III operates the track relay TR in the customary manner and causes elements KR and KB to supply the westwardly extending rails with a pulse of "feed back" energy during each of the master code "off" periods. Depending upon 15 whether relay KS at the cut location is picked up or released, the polarity of this feed back energy will be "normal" or "reverse."

In recurrently picking up and releasing under 20 the control of relay TR, the impulse relay KR causes contact 6 thereof recurrently to connect the eastwardly extending rails first with track battery TB and alternator TA and then with the polar track relays NK and RK. In this manner 25 the "Master" code energy which is received from the west is repeated around the rail joints 3 of the cut and into the rails of the section to the east thereof.

If the "feed back" energy received from the 30 east has "normal" polarity and operates track relay NK, then contacts 94 and 95 of that relay hold selector relay KS picked up and cause the "feed back" energy which elements KR and KB repeat into the westwardly extending rails also to have "normal" polarity. If, however, the feed 35 back energy received from the east is of "reverse" polarity, relay NK becomes inactive, relay KS releases and under this condition the "feed back" energy repeated into the westwardly extending rails also is of "reverse" polarity.

As long as the section to the east of the cut 40 IIIa is vacant and one or the other of devices NK and RK is following "feed back" code, the approach relay V at the cut location stays picked up and thus maintains the tuned alternator TA inactive. When, however, a westbound train passes location IV and approaches the cut location IIIa the rail shunt which it produces deenergizes both of relays NK and RK and allows the 45 approach relay V to release. This release brings alternator TA into action and causes each of the pulses of "master" code energy which are repeated into the eastwardly extending rails to include an alternating current wave of cab signal control energy.

Under conditions of westbound traffic authorization, therefore, the cut section facilities of Fig. 1d allow the main signal block in which they are included to duplicate the same "coded feed back" track circuit operations as were the cut not present.

Moreover, under conditions of both westbound and eastbound traffic authorization and during changes from one traffic direction to the other, the traffic directional relay TD at the cut location IIIa responds in the same manner as has already been explained for the corresponding device at each of the intermediate signal locations II and III. That is, it shifts its contacts to the right in response to the entry of an eastbound 70 train into the stretch and to the left when a westbound train enters the stretch.

Comparing the cut location diagram of Fig. 1d with that (Figs. 1b and 1c) for each of the intermediate locations II and III, it will be seen 75

that in all three instances the energizing circuits for this traffic directional relay TD are identical. In view of this identity it is not deemed necessary here to repeat any description of how devices V, S and H at location IIIa function to control the associated relay TD in the manner above stated.

Searchlight signals of Fig. 16

Instead of employing signals of the color-light type as represented in Fig. 1, the improved non-line-wire A. P. B. control scheme of my invention is equally well adapted for use with installations wherein signals of other types are used. Thus in Fig. 16 I have represented an adaptation of the apparatus of Fig. 1 to the control of signals of a well-known "searchlight" type. As compared with the color-light devices of Fig. 1, such searchlight signals have the advantage of considerably lower power consumption and hence in certain instances may be preferred.

In the illustrative form represented in Fig. 16 each of these searchlight signals SE and SW utilizes a single lamp 106 in front of which one or another of three colored lenses G, R and Y may selectively be positioned for the purpose of imparting the colors of green, red and yellow to the rays of light which a reflector (not shown) directs into the line of vision of the approaching engineman. These lenses are supported by a member 107 which is positionally adjusted by an electromagnetic unit 108. When this unit is de-energized, the governed member 107 occupies the central position shown wherein the red lens R is aligned with the lamp 106; when the terminals of unit 108 are supplied with direct current of one polarity the green lens G is moved into alignment with lamp 106; and when the unit terminals receive direct current of the opposite polarity the yellow lens Y is similarly moved into alignment with the signal lamp.

In the particular arrangement shown, the referred to polarized energy is transmitted to each of the signal control units 108 over conductors 110 and 111. When conductor 110 is rendered 45 positive with respect to conductor 111, the controlled signal shows "clear"; when conductor 111 is rendered positive with respect to conductor 110, the control signal shows "approach"; and when no energy is supplied to the conductor the signal shows "stop" (as already indicated).

In addition to the indication-giving lamp 106, each of the headblock signals SEI and SWIV (at the west and at the east headblock locations I and IV respectively) of Fig. 16 is provided with a constantly illuminated marker lamp M, which identifies this signal as a headblock device. Similarly, each of the intermediate signals SEII and SWII (and the corresponding devices at additional locations which the A. P. B. system may include but which are not represented) is equipped with an offside auxiliary lamp X which is arranged in well-known manner to be illuminated only when the signal of which it forms a part is displaying the red or "stop" indication. In certain cases it is desirable to use such an auxiliary lamp to give a "stop and proceed" indication as distinguished from the usual "stop and stay" aspect.

The main lamp 106 of each of the searchlight signals may, if desired, be illuminated continuously or, as shown in Fig. 16, it may be arranged to receive lighting current only when the section of track which the signal guards is actually being approached by a train. This feature of approach energization is incorporated in the complete

A. P. B. system of Fig. 1 for the purpose of conserving the power drain on the local control sources (CB of Fig. 3) with which the terminals "plus" and "minus" are identified. As already pointed out, the scheme makes use of an approach relay V at all locations, of devices RP and NP at headblock location I, and of device HE at headblock location IV.

Looking first at the control circuits for the intermediate location signals SEII and SWII of Fig. 16, these make use of the before described decoding relays H and J at the intermediate location, the companion traffic directional relay TD and the approach relay V. Under the vacant track conditions which are represented in Fig. 16, contact 100 of relay V is picked up, contact 99 of relay TD is to the right and contacts 112-113 and 114-115 of relays H and J also are picked up. This assigns to signal SEII a lighting circuit for lamp 106 thereof which when completed (by a release of device V) extends from the positive terminal of the local control source through back contact 100 of device V, conductor 102, left biased contact 99 of device TD, conductor 103 and the lamp 106 back to the negative terminal of the direct current source.

In the particular condition of the relays which is shown at location II, however, this circuit is interrupted at contact 100 and signal SEII is dark. The same interruption causes unit 108 of the signal to be deenergized and thereby accounts for the represented positioning of lens R in front of the lamp 106. The westbound signal SWII also is dark and is set up for the "stop" indication for a similar reason. This lamp lighting circuit is, however, additionally interrupted at contact 99 of directional relay TD.

Were relay V to be released (as by the entry of an eastbound train into section I-II) lamp 106 of signal SEII then would be lighted over the circuit previously traced and indication selecting unit 108 would then receive positive polarity current over a circuit extending from the positive terminal of the supply source through back contact 100 of relay V, conductor 102, front contacts 112 and 114 of relays H and J, conductor 110, the unit 108, conductor 111 and front contacts 115 and 113 of relays J and H back to the negative supply terminal. Under this condition, lens G will be moved into alignment with lamp 106, causing the signal to display the green or "clear" indication.

If relay J releases, contacts 114 and 115 will reverse the relative polarity of conductors 110 and 111 and thereby cause unit 108 to move lens Y into alignment with lamp 106. This, of course, gives the "approach" indication. Finally, if relay H also releases the supply of energy is cut off from conductors 110 and 111 and lens R returns to the illustrated position of alignment with lamp 106. This, of course, produces the "stop" indication on the part of signal SEII.

In the event that contact 99 of relay TD is shifted to the left position (as under conditions of westbound traffic authorization) the control of the relays at location II is transferred to westbound signal SWII. When released, device V now sets up a lighting circuit for lamp 106 of that signal which circuit may be traced from the positive terminal of the supply source through back contact 100, conductor 102, left biased contact 99, conductor 104 and the lamp 106 back to the negative supply terminal.

If decoding relays H and J are both picked up, unit 108 (connected in parallel with the corre-

sponding unit of the before-described signal SEII) moves lens G into alignment with the lamp 106 of signal SWII and thereby produces the "clear" indication. If relay J only is released, unit 108 moves lens Y to the active position and thereby produces the "approach" indication. And finally if both of these relays H and J are released, unit 108 is deenergized and lens R occupies the represented position of alignment, causing signal SWII to show "stop".

Examining next the eastbound headblock signal SEI at the west headblock location I, the indication displayed by this signal is controlled by decoding relays H and J at the named location while the approach energization thereof is controlled by relays RP and NP. When these last two named relays are released there is completed for the lamp 106 of the signal a lighting circuit which may be traced from the positive terminal of the local supply source through back contacts 87 and 88 of devices RP and NP, conductor 117 and the lamp 106 back to the negative supply terminal.

If decoding relays H and J are both picked up, the selector unit 108 of the signal receives positive polarity direct current over a circuit extending from the positive supply terminal before named, through back contacts 87 and 88 of devices RP and NP, front contacts 83 and 84 of devices H and J, conductor 110, the unit 108, conductor 11, and front contacts 118 and 119 of device H back to the negative supply terminal. Under the influence of this energization, unit 108 moves lens G into alignment with lamp 106 and thus produces a "clear" indication on the part of signal SEI.

If decoding relay J is released contacts 84 and 118 thereof reverse the polarity of conductors 110 and 111 and thereby cause unit 108 to bring lens Y into alignment with lamp 106, thereby producing the "approach" indication. And finally, if both of the decoding relays H and J are released, unit 108 becomes deenergized and allows lamp R to assume the represented position of alignment, thereby causing the signal SEI to show "stop".

Looking next at the westbound signal SWI at the west headblock location I, the indication which this signal displays is selected by relays NP and RP while the approach energization of the signal is controlled by relay V. In the event that this relay V is released, there is completed for lamp 106 of signal SWI a lighting circuit which extends from the positive terminal of the local supply source through back contact 93 of device V, conductor 20 and the lamp 106 back to the negative terminal of the supply source.

If relay NP is picked up, the selector unit 108 of the signal receives positive polarity direct current over a circuit extending from the positive terminal of the mentioned source, through back contact 93 of relay V, front contact 96 of device NP, conductor 110, the unit 108, conductor 111 and front contact 121 of device NP, back to the negative supply terminal. Under the influence of this energization, unit 108 moves lens G into alignment with lamp 106 and thereby causes signal SWI to display the "clear" indication.

If relay RP is picked up and relay NP is released, the combined action of contacts 97-122 and 96-121 of the two named devices is to reverse the polarity of conductors 110 and 111. This causes unit 108 of signal SWI to bring lens Y into alignment with lamp 106 and thereby produce the "approach" indication. And finally, if both of the relays NP and RP are released, unit

108 becomes deenergized and allows lamp R to assume the represented position of alignment, thereby producing the "stop" indication on the part of signal SWI.

Looking next at eastbound signal SEIV at the east headlock location IV, the indication which this signal displays is controlled by decoding relays HE and JE at the named location while the approach energization of the signal is controlled by the relay V. In the event that this relay V releases, there is completed for lamp 106 of signal SEIV a lighting circuit which extends from the positive terminal of the local supply source through back contact 93 of device V, conductor 123, and the lamp 106 back to the negative terminal of the local source.

If decoding relays HE and JE are both picked up selector unit 108 of the signal is supplied with "positive" polarity direct current over a circuit extending over the positive terminal of the before named local source through back contact 93 of device V, front contacts 83 and 84 of devices HE and JE, conductor 110, the unit 108, conductor 111 and contacts 124 and 125 of devices JE and HE, back to the negative terminal of the supply source. Under the influence of this energization unit 108 moves lens G into alignment with lamp 106 and thereby causes signal SEIV to display "clear."

If the decoding relay JE is released, the contacts 84 and 124 thereof reverse the polarity of conductors 110 and 111 and thereby cause unit 108 to move lens Y into alignment with lamp 106. This, of course, causes signal SEIV to display "approach." And finally, if both of the decoding relays HE and JE are released, unit 108 becomes deenergized and allows lens R to assume the represented position of alignment. Under this condition signal SEIV shows "stop."

Looking finally at the west bound headblock signal SWIV at the east headblock location IV, the indication which this signal displays is controlled by decoding relays HW and JW at the named location while the approach energization of the signal is controlled by relay HE. When this device HE is released there is completed for lamp 106 of signal SWIV a lighting circuit which may be traced from the positive terminal of the local supply source through back contact 92 of device HE, conductor 126, and the lamp 106 back to the negative terminal of the supply source.

If both of the decoding relays HW and JW are picked up, selector unit 108 of the signal is supplied with "positive" polarity direct current over a circuit which extends from the positive terminal of the named supply source through back contact 92 of device HE, front contacts 83 and 84 of devices HW and JE, conductor 110, the unit 108, conductor 111 and front contacts 127 and 128 of devices JW and HW back to the negative terminal of the supply source. This energization causes unit 108 to move lens G into alignment with lamp 106 and thereby produce the "clear" indication on the part of signal SWIV.

If decoding relay JW is released contacts 84 and 127 thereof reverse the polarity of conductors 110 and 111 and thereby cause unit 108 to move lens Y into alignment with the signal lamp. This causes signal SWIV to show "approach." And finally, if both of these decoding relays JW and HW are released, unit 108 becomes deenergized and allows the lens R to assume the represented position of alignment, thereby producing the "stop" indication showing on the part of the just named signal.

Further forms of protection

In addition to performing all of the signal control functions which are incident to conventional systems of A. P. B. signaling, the improved non-line-wire scheme of my invention provides certain extended forms of protection which will now be described.

From an inspection of the complete diagram of Figs. 1a-e it will be noted that the polarities of adjacent track circuits have, in all instances, been staggered. This staggering is an optional feature and its purpose is to render the system self protecting against the giving of a false "proceed" signal indication in the event that the insulated rail joints 3 at any of the locations I, II, III, IIIa and IV in the system should fail. The "plus" and "minus" polarity designations which appear in the diagram of Fig. 1 to show this staggering apply to the polarity of the "master" code energy by which the track relays TR are operated.

For cooperating in the provision of the just-named broken down joint protection, these track relays TR are given polar responsive characteristics. When the received master code energy impressed thereon makes the left terminal of the relay positive with respect to the right, then the relay responds and follows code in the intended manner. Should, however, the polarity of the impressed energy be reversed, then the relay does not respond and the wayside signal (SE or SW) controlled thereby through the medium of decoding devices H and J is set up to give the "stop" indication.

Such a "stop" set-up will quite obviously result in the event of breakdown of the insulated rail joints 3 at any one of the intermediate locations II, III and IIIa in the system. In such an event the energy leaking over the faulty joint from the adjacent track section directly opposes and tends to neutralize the master code energy which the relay TR is receiving from the rails of the section with which that relay is identified. In consequence the relay now ceases to follow code and allows both of the associated decoding relays H and J to release, thereby putting the controlled wayside signal at "stop."

A still further form of protection which the improved non-line-wire system of A. P. B. control of my invention is capable of providing is also represented in Fig. 1d as involving the conventional highway crossing signal XS. As shown, this signal is occasioned by the highway 4 which intersects the stretch of single track at the location of the cut IIIa in the main signal block III-IV and it performs the usual function of warning the users of highway 4 when a train is approaching the intersection along the track.

By means of the signal control circuits herein disclosed this signal XS is automatically brought into operation in response to the approach of a train from either direction. This desired form of control is effected in a very simple manner by carrying the operating circuit for signal XS over the back point of a contact 205 of the approach relay V which already is included in the cut location equipment.

As long as relay V remains picked up, the highway crossing signal XS is continued inactive. When, however, relay V releases there is completed for signal XS an operating circuit which extends from the "plus" terminal of the local supply source through back contact 205, conductor 206, and the operating mechanism of de-

vice XS back to the "minus" terminal of the local supply source. Under this condition the signal operates and thus warns the users of highway 4 that a train is approaching the intersection.

As long as both of the sections of track which extend away from the cut location IIIa are vacant, relay V is picked up and signal XS is kept inactive. This inactive condition, moreover, is maintained regardless of whether the track circuits of those sections are set up to accommodate eastbound movements or are set up to accommodate westbound movements of trains between the headblock locations I and IV of the complete A. P. B. system. In the former event the polar track devices NK and RK by which relay V is maintained picked up receive "feed back" operating energy from the rails of the westwardly extending section IIIa-III over right biased contacts 18 and 27 of device TD; in the latter the same polar track relays NK and RK receive their operating energy from the rails of the eastwardly extending section IIIa-IV over left biased contacts 65 and 66 of the device TD.

Looking first at the eastbound set-up conditions which are shown in Fig. 1d (and which also are more generally represented in Figs. 7a and 9a-b-c), it will be evident that as long as the cut containing signal block III-IV is vacant one or the other of the polar track relays NK and RK at the cut location will be following "feed back" code energy transmitted thereto from the west location III and will (over contact 155 or 153) keep the approach relay V picked up and the crossing signal XS inactive. As, however, an eastbound train passes location III and shunts the rails of the section to the immediate west of the cut location IIIa, both of the devices NK and RK there become deenergized and release the approach relay V. Contact 205 of that released relay now completes the before traced operating circuit for signal XS and thereby brings the crossing protective device into action.

This action continues as long as any part of the eastbound train remains within the signal block which is intersected by highway 4. When, however, the train moves past the cut location IIIa and out of the section which extends eastwardly therefrom, the coded feed back track circuits of the signal block III-IV once more resume operation and cause one or the other of the polar devices NK and RK at the cut to follow "feed back" code. This action picks up the approach relay V and restores (at contact 205) the crossing protective signal XS to its normally inactive state.

A similar form of crossing signal control takes place under the conditions of westbound traffic operations which are generally represented in Figs. 7b and 10a-b-c. As long, under those westbound authorized conditions, as the cut containing signal block IV-III remains vacant, one or the other of the polar track relays NK and RK at the cut location IIIa is operated by "feed back" code energy transmitted thereto from the east location IV. That action holds (over contact 155 or 153) the approach relay V picked up and keeps (at contact 205) the crossing protective signal XS inactive.

As a westbound train advances past location IV and shunts the rails of the section to the immediate east of the highway 4, both of the devices NK and RK at the cut location IIIa become deenergized and cease to follow code. This action allows the approach relay V to release and to complete (at contact 205) for the crossing pro-

tective signal XS the before described circuit which brings the signal into action and thereby warns users of the highway that a train is approaching. Once initiated, this warning continues as long as any part of the westbound train remains within the signal block that is intersected by highway 4.

When, however, the westbound train moves past the cut location IIIa and out of the section which extends westwardly therefrom, the coded feed back track circuits of the signal block IV-III resume their operations and one or the other of devices NK and RK at the cut is again caused to follow "feed back" code. That action once more picks up the approach relay V and thereby interrupts (at contact 205) the operating circuit for the crossing protective device XS.

From the foregoing, therefore, it will be seen that the highway crossing control scheme of Fig. 1d functions in conjunction with the remaining portions of the complete non-line-wire A. P. B. system of Figs. 1a-e to provide the desired control of the intersection protective device XS under conditions of both eastbound and westbound train movement.

Referring finally to Fig. 17, I have there represented an extension in the basic non-line-wire A. P. B. control scheme of Figs. 1a-e whereby certain of the intermediate signals may be arranged to display an extra or fourth indication. In Fig. 17 such signals are shown in the form of devices SEII and SWII at intermediate location II.

In certain situations such an extra indication is desirable to prevent a train which passes a "clear" signal at the entering end of a track section from encountering a "stop" indication at the exit end of the same section. Such situations are so well known in the art as to require no further explanation here and it is to take care of them that the supplemental facilities of Fig. 17 are intended.

In those facilities use is made of four indication signals SEII and SWII that are of the color-light type and that comprise an upper unit of three lamps G, Y and R and a lower unit of two lamps G and R. The lighting circuits for these lamps are selectively completed by decoding relays H and J which are duplicates of the correspondingly identified devices of Fig. 1 and which are aided by a third decoding relay J120 that responds only when the controlling track relay TR follows code at the 120 pulse per minute rate. This added 120 pulse per minute code originates at one or the other of headblock locations I and IV where it is there produced by a third or added code transmitter CT120.

Comparing the diagram of Fig. 17 with the complete composite showing of Figs. 1a-e, it will be seen that only those devices which perform direct functions in connection with the production and utilization of this added 120 pulse per minute code have been represented in Fig. 17. At location I, these include devices CRW, KB, NP, RP, H, S, CT75 and CT180 all of which operate in the same manner as at location I of Fig. 1a. At location IV, likewise, Fig. 17 shows devices CRE, TB, S, HW, HE, JE, CT180 and CT75 which are duplicates of and which operate in the same manner as the correspondingly identified devices at location IV of Fig. 1e. A similar identity, moreover, exists between devices TD, KR, TR, DT, H, J and V which are shown at location II in Fig. 17 and the correspondingly identified devices of Fig. 1b.

Looking further at the four indication signals SEII and SWII of Fig. 17, the aspects displayed thereby are as follows. When relay TR at the intermediate location II follows code of the 180 pulse per minute rate, decoding relays H and J are both picked up and relay J120 is released. This causes the controlled signal at the same location to show "clear" as a result of its top lamp G and its bottom lamp R receiving lighting current over circuits which respectively include: (1) front contact 210 of device H, back contact 211 of device J120, front contact 212 of device J and a conductor 213; and (2) front contact 210 of device H, conductor 214, back contact 215 of device J120, and a conductor 216.

When the relay TR is responding to code of the 120 pulse per minute rate, decoding relays H and J120 then are picked up and decoding relay J is released. Under this condition the controlled signal shows the "approach medium" indication as a result of its upper lamp Y and its lower lamp G receiving lighting current over circuits which respectively include: (1) front contact 210 of device H, front contact 211 of device J120, and a conductor 217; and (2) front contact 210 of device H, conductor 214, front contact 215 of device J120 and a conductor 218.

When the track relay TR is following code at the 75 pulse per minute rate, decoding relay H only is picked up and relays J120 and J are both released. Under that condition the controlled signal gives the "approach" indication as a result of its upper lamp Y and its lower lamp R receiving lighting current over circuits which respectively include: (1) front contact 210 of device H, back contact 211 of device J120, back contact 212 of device J, and the previously named conductor 217; and (2) front contact 210 of device H, conductor 214, back contact 215 of device J120 and conductor 216, as previously described.

And finally when the track relay TR at location II of Fig. 17 fails to follow code, all three of the decoding relays H, J120 and J are released. Under that condition the controlled signal shows "stop" as a result of its upper lamp R and its lower lamp R receiving lighting current over circuits which respectively include: (1) back contact 210 of device H, and a conductor 219; and (2) back contact 220 of device H, back contact 215 of device J120 and the previously named conductor 216.

As in the previously described system of Fig. 1, contact 99 of the traffic directional relay TD assigns the just described decoding relay control to the eastbound signal SEII when the authorized direction of train movement through the single track stretch is eastbound and to the westbound signal SWII when the authorized direction of train movement is westbound. In Fig. 17 this contact 99 is included in a slightly different portion of the lamp lighting circuits for the two signals. Instead of being interposed between the "plus" terminal of the local source of lamp lighting energy and the decoding relay contacts, as in Fig. 1, it is interposed between the common conductors 222 and 223 of the lamp circuits for the two signals SE and SW and the "minus" terminal of the local supply source. In both instances, however, exactly the same function is performed.

As in the system of Fig. 1 also, the control circuits for the signals SEII and SWII of Fig. 17 are approach energized under the control of a contact 100 of the approach relay V at the signal

location. Under conditions of eastbound traffic movement this relay is picked up as long as the section I-II to the west of signal SEII is vacant and it releases only when a train enters that section. Similarly under conditions of westbound train movement this approach relay V is picked up at all times except when the track section to the east of signal SWII is occupied by a train.

In operation of the extended-indication facilities of Fig. 17, relay TR and its associated decoding apparatus is operated by "master" code energy received from the location IV to the east when the authorized direction of train movement is eastbound and by "master" code energy received from the location I to the west when the authorized direction of train movement is westbound.

In both instances traffic conditions of the track beyond the code supply location will determine which of the three available "master" codes (of 75, 120 and 180 pulses per minute respectively) is transmitted over the track rails to the intermediate location II for the purpose of operating the relay TR and thus selecting which of the four before described indications is to be displayed by the controlled signal (SE or SW).

Looking first at the apparatus at location IV, this apparatus supplies the signal controlling code under conditions of eastbound authorization. Incident to that supply the master coding relay CRE receives operating current over: (1) contact 180 of the transmitter CT180 when relay HW (see Fig. 1e) is picked up at a time that relay S is released; (2) contact 120 of the added transmitter CT120 when relays S, HW and JE are released at a time when device HE is picked up; and (3) contact 75 of transmitter CT75 when relays S, HW and HE are all released.

Looking next at the code selecting circuits at the west headblock location I, these circuits are in action under conditions of westbound traffic authorization. Incident to that action the coding relay CRW receives operating current from: (1) contact 180 of transmitter CT180 when relay H (see Fig. 1a) is picked up at a time when relay S is released; (2) contact 120 of the added transmitter CT120 when relay RP is picked up at a time that relays NP, H and S are all released; and (3) from contact 75 of transmitter CT75 when devices RP, NP, H and S are all released.

In the manner just described, therefore, the system of my invention readily adapts itself to the use of intermediate signals which have an extra indication and which are arranged to prevent trains passing through the stretch of single track from encountering a "stop" indication immediately after passing an intermediate wayside signal which is displaying "clear."

Summary

While the improvements of my invention have been disclosed in connection with an A. P. B. system (Figs. 1a—e) which includes only two intermediate signal locations (II and III) and which provides for only three indications ("clear," "approach" and "stop") on the part of the controlled signals, it will be apparent that these same improvements may also be applied to systems: (1) Wherein the single track stretch includes either more or less than two intermediate locations; and/or (2) wherein the signals identified with the stretch are controlled to either more or less than three indications.

To adapt, for example, the herein disclosed three-indication system for the provision of four-

indication signal control only the following supplements to the present apparatus thereof are necessary: (1) add facilities for another distinctive-rate code (such as 120 energy pulses per minute) to the "frequency code" scheme in which the "master" track circuits of the "coded feed back" combinations are utilized and by which the following protection signals are controlled during both eastbound and westbound moves. (For certain portions of the system such facilities are already shown in Fig. 17.) In this way it will be seen that the obtainable signal indications may readily be extended to almost any number desired.

Likewise, while the several "coded feed back" track circuit combinations in the system have been shown as receiving operating energy from the direct current sources TB and KB, it will further be apparent that these same track circuits (see the simplified showings of Figs. 5, 6, 7 and 8) may readily be modified to operate on alternating current energy.

From the foregoing, therefore, it will be seen that I have made highly practical improvements in absolute permissive block (A. P. B.) signalling systems for stretches of railway track over which traffic may move in either direction.

In particular I have provided a fully automatic system of A. P. B. signaling: (1) that requires no line wires for signal control purposes; (2) that affords both directional and following protection wholly by means of coded energy which is transmitted through the track rails; (3) that approach energizes all signals and otherwise economizes power; (4) that requires a minimum of decoding and signal control apparatus; (5) that retains all of the advantages of continuously coded track circuits; (6) that is adapted to control either or both wayside signals and train carried cab signals; (7) that can provide almost any number of signal indications desired; (8) that may include signal blocks which both do and do not contain cut sections; and (9) that facilitates the control of highway crossing signals.

These advantageous features are, as has been seen, attained by equipping each of the track sections in the two-direction running stretch with track circuit facilities of the "coded feed back" type; providing means that are responsive to the direction of train movement through the stretch and that at all times causes the recurring pulses of "master" code energy to be supplied to the train exit ends of the stretch sections; imparting "normal" polarity to the master code "off" period pulses of "feed back" energy under vacant conditions of the stretch and using those normal polarity pulses to hold at "proceed" the headblock signals which guard the stretch ends; reversing the polarity of the "feed back" pulses when a train comes into the stretch and using those "reverse" polarity pulses to put the opposing headblock signal at "stop" and thereby establish directional protection; using the feed back pulses of both "normal" and "reverse" polarity to keep the system signals deenergized at all times except when indications must be displayed to an approaching train; and using the recurring pulses of "master" code energy to control the signals behind each train in customary automatic block manner whereby to provide following protection.

Although I have herein shown and described only a few form of A. P. B. signaling apparatus embodying my invention, it is understood that various changes and modifications may be made therein within the scope of the appended claims

without departing from the spirit and scope of my invention.

Having thus described my invention, what I claim is:

1. In combination, a stretch of railway track that is arranged into a plurality of consecutive track sections, means at a given end of each of said sections for supplying the rails thereof with master code energy in the form of recurring pulses that are separated by "off" period intervals, means located at the opposite end of each of said sections and controlled by the there received pulses of said master code energy for further supplying the section rails with pulses of feed back energy which recur in step with the said master code "off" periods, means at each point of track section division in said stretch for causing the there supplied pulses of said feed back energy to have normal polarity when all sections between that point and the extreme opposite end of the stretch are vacant and to have reverse polarity when any one of these sections is occupied, a headblock signal positioned at the extreme given end of the stretch to govern the entry of traffic into the stretch by way of that given end, and means controlled by the said feed back energy pulses which are received at the location of said signal for conditioning that signal to show "proceed" when those pulses have said normal polarity and "stop" when those pulses either have said reverse polarity or are discontinued whereby the latter indication conditioning is produced by the entry of a train into the extreme opposite end of said stretch and is continued as long as any part of the train remains within the stretch.

2. In combination, a stretch of railway track that is arranged into a plurality of consecutive track sections, signals positioned at the several points of track section division in said stretch to govern given direction train movements there-through, means at the given direction exit end of each of said sections for supplying the rails thereof with master code energy in the form of recurring pulses that are separated by "off" period intervals and that are distinctive of traffic conditions beyond that exit end, means at the given direction entrance end of each of said sections which respond to the said master code energy pulses that are there received and which control the said signal at that location in a manner to provide following protection for given direction trains, means also located at said given direction entrance end of each section and controlled by said there received pulses of master code energy for further supplying the section rails with pulses of feed back energy which recur in step with said master code "off" periods, means at each of said points of track section division for causing the there supplied pulses of said feed back energy to have normal polarity when all sections between that point and the extreme given direction entrance end of said stretch are vacant and to have reverse polarity when any one of those sections is occupied, a headblock signal positioned at the extreme given direction exit end of said stretch to govern the entry of opposite direction traffic thereto, and means controlled by the said feed back energy pulses which are received at the location of said headblock signal for conditioning that signal to show "proceed" when those pulses have said normal polarity and "stop" when those pulses either have said reverse polarity or are discontinued whereby each given direction train which enters the stretch produces the latter

indication conditioning and thereby sets up its own directional protection.

3. In combination, a stretch of railway track that is arranged into a plurality of consecutive track sections, means at each of the several points of track section division in said stretch for governing given direction train movements therethrough, means at the given direction exit end of each of said sections for supplying the rails thereof with pulses of frequency code energy that are separated by "off" period intervals and that recur at one or another of a plurality of different rates which are distinctive of traffic conditions beyond that exit end, means at the given direction entrance end of each section which respond to the rate of recurrence of the said frequency code energy pulses that are there received and which control the said train governing means at that location in a manner to provide following protection for given direction trains, means also located at said given direction entrance end of each section and controlled by said there received pulses of frequency code energy for further supplying the section rails with pulses of feed back code energy which recur in step with said frequency code "off" periods, means at each of said points of track section division for causing the there supplied pulses of said feed back energy to have normal polarity when all sections between that point and the extreme given direction entrance end of said stretch are vacant and to have reverse polarity when any one of those sections is occupied, a headblock signal positioned at the extreme given direction exit end of said stretch to govern the entry of opposite direction traffic thereinto, and means controlled by the said feed back energy pulses which are received at the location of said headblock signal for conditioning that signal to show "proceed" when those pulses have said normal polarity and "stop" when those pulses either have said reverse polarity or are discontinued whereby each given direction train which enters the stretch produces the latter indication conditioning and thereby sets up its own directional protection.

4. In combination, a stretch of railway track that is arranged into a plurality of consecutive track sections, means at each of the several points of track section division in said stretch for governing given direction train movements therethrough, means at the given direction exit end of each of said sections for supplying the rails thereof with master code energy in the form of recurring pulses that are separated by "off" period intervals and that are distinctive of traffic conditions beyond that exit end, means at the given direction entrance end of each of said sections which respond to the said master code energy pulses that are there received and which control the said train governing means at that location, means also located at said given direction entrance end of each section and controlled by said there received pulses of master code energy for further supplying the section rails with pulses of feed back energy which recur in step with said master code "off" periods, means controlled by the said pulses of feed back energy which are received at said given direction exit end of each section for maintaining the said train governing means at that location deenergized at all times except when a train enters the section and cuts off the supply of those pulses, means at each of said points of track section division for causing the there supplied pulses of feed back energy to have normal polarity when all sections between that point and the extreme given direction end of said stretch are vacant and to have reverse polarity when any one of those sections is occupied, a headlock signal positioned at the extreme given direction exit end of said stretch to govern the entry of opposite direction traffic thereinto, and means controlled by the said feed back energy pulses which are received at the location of said headlock signal for conditioning that signal to show "proceed" when those pulses have said normal polarity and "stop" when those pulses either have said reverse polarity or are discontinued.

5. In combination, a stretch of railway track that is arranged into a plurality of consecutive track sections, means at each of the several points of track section division in said stretch for governing given direction train movements therethrough, means at the given direction exit end of each of said sections for supplying the rails thereof with master code energy in the form of recurring pulses that are separated by "off" period intervals and that are distinctive of traffic conditions beyond that exit end, means at the given direction entrance end of each of said sections which respond to the said master code energy pulses that are there received and which control the said signal at that location, means also located at said given direction entrance end of each section and controlled by said there received pulses of master code energy for further supplying the section rails with pulses of feed back energy which recur in step with said master code "off" periods, means controlled by the said pulses of feed back energy which are received at said given direction exit end of each section for maintaining the said signal at that location deenergized at all times except when a train enters the section and cuts off the supply of those pulses, means at each of said points of track section division for causing the there supplied pulses of feed back energy to have normal polarity when all sections between that point and the extreme given direction end of said stretch are vacant and to have reverse polarity when any one of those sections is occupied, a headlock signal positioned at the extreme given direction exit end of said stretch to govern the entry of opposite direction traffic thereinto, and means controlled by the said feed back energy pulses which are received at the location of said headlock signal for conditioning that signal to show "proceed" when those pulses have said normal polarity and "stop" when those pulses either have said reverse polarity or are discontinued.

6. In combination, a stretch of railway track that is arranged into a plurality of consecutive track sections, means at each of the several points of track section division in said stretch for governing given direction train movements therethrough, means at the given direction exit end of each of said sections for supplying the rails thereof with pulses of frequency code energy that are separated by "off" period intervals and that recur at one or another of a plurality of different rates which are distinctive of traffic conditions beyond that exit end, means at the given direction entrance end of each of said sections which respond to the rate of recurrence of the said frequency code energy pulses that are there received and which control the said train governing means for that location, means also located at said given direction entrance end of each section and controlled by said there received pulses of frequency code energy for further supplying the section

rails with pulses of feed back energy which recur in step with said frequency code "off" periods, means controlled by the said pulses of feed back energy which are received at said given direction exit end of each section for maintaining the said train governing means at that location deenergized at all times except when a train enters the section and cuts off the supply of those pulses, means at each of said points of track section division for causing the there supplied pulses of feed back energy to have normal polarity when all sections between that point and the extreme given direction entrance end of said stretch are vacant and to have reverse polarity when any one of those sections is occupied, a headblock signal positioned at the extreme given direction exit end of said stretch to govern the entry of opposite direction traffic thereinto, and means controlled by the said feed back energy pulses which are received at the location of said headblock signal for conditioning that signal to show "proceed" when those pulses have said normal polarity and "stop" when those pulses either have said reverse polarity or are discontinued.

7. In a railway signaling system for a stretch of single track over which traffic may move in either direction, a plurality of insulated sections of said track, master code equipment at each point of track section division in said stretch for supplying the rails of one or the other of the two sections which there adjoin with master energy in the form of recurring pulses that are separated by "off" period intervals, feed back equipment also at each of said points of track section division for further supplying the rails of one or the other of said there adjoining sections with pulses of feed back energy which are timed by the said master energy pulses that are there received from the supplied rails to recur in step with the said "off" period intervals of that received energy, means effective during the passage of first direction traffic through said stretch for connecting each of said master code equipments with the said equipment adjoining section over which said first direction traffic must travel in reaching the equipment location and each of said feed back equipment with the other of said there adjoining sections, means effective during the passage of second direction traffic through said stretch for interchanging the just stated connections of said master code and said feed back equipments, means at each of said junction points for causing the rate of recurrence of the there supplied pulses of master code energy to be distinctive of traffic conditions beyond the section end of that energy supply, means also at each of said junction points for causing the polarity of the there supplied pulses of feed back energy to be distinctive of traffic conditions beyond the section end of that energy supply, means controlled by the rail transmitted pulses of said feed back energy and selectively responsive to the polarity thereof for governing the passage of opposing trains through said stretch, and means controlled by the rail transmitted pulses of said master code energy and selectively responsive to the rate of recurrence thereof for governing the passage of following trains through said stretch.

8. In combination with a stretch of two-direction running railway track, a track section included in said stretch, a master code equipment positioned at each of the two ends of said section and selectively operable to supply the section rails with master energy in the form of recurring pulses that are separated by "off" period

intervals, a feed back equipment also positioned at each of the two ends of said section and likewise selectively operable further to supply the section rails with feed back energy in the form of pulses that are controlled by the rail transmitted pulses of said master energy and that recur in step with the "off" period intervals of that master energy, means selected by first direction traffic passing through said stretch for rendering effective said master code equipment at the first direction exit end of the section and said feed back equipment at the opposite end thereof, means selected by second direction traffic passing through said stretch for rendering effective said master code equipment at the second direction exit end of the section and said feed back equipment at the opposite end thereof, traffic governing apparatus controlled by the rail transmitted pulses of said master code energy, and other traffic governing apparatus controlled by the rail transmitted pulses of said feed back energy.

9. In combination with a stretch of two-direction running railway track, a track section included in said stretch, master code equipments positioned at the two ends of said section and selectively operable to supply the section rails with master code energy in the form of pulses that are separated by "off" period intervals and that recur at a rate which is distinctive of traffic conditions beyond the location of that master energy supply, feed back equipments also positioned at said two section ends and likewise selectively operable further to supply the section rails with feed back energy in the form of pulses that recur in step with the "off" periods of said supplied master code and that have a polarity which is distinctive of traffic conditions beyond the location of that feed back energy supply, means rendered effective by first direction traffic passing through said stretch for placing in operation the said master code equipment which is at the first direction exit end of the section and the said feed back equipment which is at the opposite end thereof, means rendered effective by second direction traffic passing through said stretch for placing in operation the said master code equipment which is at the second direction exit end of the section and the said feed back equipment which is at the opposite end thereof, traffic governing apparatus controlled by the rail transmitted pulses of said master code energy, and other traffic governing apparatus controlled by the rail transmitted pulses of said feed back energy.

10. In combination with a stretch of two-direction running railway track, a track section included in said stretch, master code equipments at the two ends of said section selectively connectible with the section rails and operable to supply those rails with master energy in the form of recurring pulses that are separated by "off" period intervals, feed back equipments also at said section two ends likewise selectively connectible with said section rails and operable further to supply those rails with feed back energy in the form of pulses that are controlled by the rail transmitted pulses of said master energy and that recur in step with the "off" period intervals of that master energy, means effective during the passage of first direction traffic through said stretch for connecting said section rails with the said master code equipment at the first direction exit end of the section and with the said feed back equipment at the opposite end thereof, means effective during the passage of second direction traffic

through said stretch for connecting said section rails with the said master code equipment at the second direction exit end of the section and with the said feed back equipment at the opposite end thereof, traffic governing apparatus controlled by the rail transmitted pulses of said master code energy, and other traffic governing apparatus controlled by the rail transmitted pulses of said feed back energy.

11. In combination with a stretch of two-direction running railway track, a track section included in said stretch, master code equipments positioned at the two ends of said section and selectively connectible with the section rails for the purpose of supplying those rails with master code energy in the form of pulses that are separated by "off" period intervals and that recur at a rate which is distinctive of traffic conditions beyond the location of the master energy supply, feed back equipment also positioned at said two section ends and likewise selectively connectible with the section rails for the purpose of further supplying those rails with feed back energy in the form of pulses that recur in step with the "off" periods of said supplied master code and that have a polarity which is distinctive of traffic conditions beyond the location of the feed back energy supply, means effective during the passage of first direction traffic through said stretch for connecting said section rails with the said master code equipment at the first direction exit end of the section and with the said feed back equipment at the opposite end thereof, means effective during the passage of second direction traffic through said stretch for connecting said section rails with the said master code equipment at the second direction exit end of the section and with the said feed back equipment at the opposite end thereof, traffic governing apparatus controlled by the rail transmitted pulses of said master code energy, and other traffic governing apparatus controlled by the rail transmitted pulses of said feed back energy.

12. In combination with a stretch of two-direction running railway track, a track section include in said stretch, master code equipments at the two ends of said section selectively connectible with the section rails and operable to supply those rails with master energy in the form of recurring pulses that are separated by "off" period intervals, feed back equipments also at said two section ends likewise selectively connectible with said section rails and operable further to supply those rails with feed back energy in the form of pulses that are controlled by the rail transmitted pulses of said master energy and that recur in step with the "off" period intervals of that master energy, a traffic directional relay positioned at each of said two section ends for the purpose of responding selectively to first direction trains and to second direction trains which enter said stretch, means including said traffic directional relays and effective during the passage of first direction traffic through said stretch for connecting said section rails with the said feed back and master code equipments which respectively are at the first direction entrance and exit ends of said section, means also including said traffic directional relays but effective during the passage of second direction traffic through said stretch for connecting said section rails with the said feed back and master code equipments which respectively are at the second direction entrance and exit ends of said section, traffic governing apparatus controlled by the rail

transmitted pulses of said master code energy, and other traffic governing apparatus controlled by the rail transmitted pulses of said feed back energy.

- 5 13. In combination with a stretch of two-direction running railway track, a track section forming a part of said stretch and including a headblock end and an intermediate end, a master code equipment at said intermediate section end connectible with the section rails and operable to supply those rails with master energy in the form of recurring pulses that are separated by "off" period intervals, a feed back equipment also at said intermediate section end likewise connectible 10 with the section rails and operable when master code energy is received therefrom further to supply those rails with pulses of feed back energy which recur in step with the "off" periods of the received master code, combined master code and 15 feed back apparatus positioned at said headblock section end and there capable of supplying the section rails either with recurring pulses of master code energy or with "off" period pulses of feed back energy, means effective during the passage 20 through said stretch of traffic in the direction of from said headblock section end for connecting said section rails with the said intermediate end master code equipment and for conditioning said headblock end apparatus to supply those rails with "off" period pulses of feed 25 back energy, means effective during the passage through said stretch of traffic in the opposite direction for conditioning said headblock end apparatus to supply said section rails with recurring 30 pulses of master code energy and for connecting those rails with the said intermediate end feed back equipment, traffic governing apparatus controlled by the rail transmitted pulses of said master code energy, and other traffic governing 35 apparatus controlled by the rail transmitted pulses of said feed back energy.

40 14. In combination with a stretch of two-direction running railway track, a track section forming a part of said stretch and including a headblock end and an intermediate end, a master code equipment at said intermediate section end connectible with the section rails and operable to supply those rails with master energy in the form of recurring pulses that are separated by 45 "off" period intervals and that recur at a rate which is distinctive of traffic conditions beyond said intermediate end, a feed back equipment also at said intermediate section end likewise connectible with the section rails and operable 50 when master code energy is received therefrom further to supply those rails with pulses of feed back energy that recur in step with the "off" periods of the received master code and that have a polarity which is distinctive of traffic conditions beyond said headblock end, combined master code and feed back apparatus positioned at said headblock section end and there capable of supplying the section rails either with pulses of master code energy that recur at a rate which 55 is distinctive of traffic conditions beyond said headblock end or with "off" period pulses of feed back energy, means effective during the passage through said stretch of traffic in the direction of from said headblock section end for connecting 60 said section rails with the said intermediate end master code equipment and for conditioning said headblock end apparatus to supply those rails with "off" period pulses of feed back energy, means effective during the passage through said 65 stretch of traffic in the opposite direction for connecting

ditioning said headblock end apparatus to supply said section rails with recurring pulses of master code energy and for connecting those rails with the said intermediate end feed back equipment, traffic governing apparatus controlled by the rail transmitted pulses of said master code energy, and other traffic governing apparatus controlled by the rail transmitted pulses of said feed back energy.

15. In combination: a stretch of two-direction running railway track; a track section forming a part of said stretch and including a headblock end and an intermediate end; combined master code and feed back apparatus positioned at the said headblock end of said section and including a source of trackway energy, a code following track relay, a code repeating device for repeatedly connecting the section rails first to said track relay and then to said energy source, a code transmitter for at times controlling said device, and a circuit over which said track relay at other times controls said device; a master code equipment installed at the said intermediate end of said section and at times operable to supply the section rails with master energy in the form of recurring pulses that are separated by "off" period intervals; a feed back equipment also installed at the said intermediate section end and operable when master code energy is received over the section rails from said headblock end further to supply those rails with pulses of feed back energy which recur in step with the "off" periods of the received master code; means effective during the passage through said stretch of traffic in the direction of from said intermediate section end for placing said headblock end code repeating device under the control of said code transmitter whereby to cause said headblock energy source to supply the section rails with master code energy which is in the form of recurring pulses that are separated by "off" periods and which cause said intermediate end feed back equipment further to supply those rails with "off" period pulses of feed back energy; means effective during the passage through said stretch of traffic in the direction of from said headblock section end for placing said intermediate end master code equipment in operation and for placing said headblock end code repeating device under the control of said track relay whereby master code energy now is transmitted from said intermediate end to said track relay at said headblock end and whereby said associated code repeating device now causes said headblock source to supply feed back energy to the section rails during the "off" periods of the received master code; traffic governing apparatus controlled by the rail transmitted pulses of said master code energy; and other traffic governing apparatus controlled by the rail transmitted pulses of said feed back energy.

16. In combination: a stretch of two-direction running railway track; a track section included in said stretch; master code equipment installed at a given end of said section and operable to supply the section rails with master code energy in the form of pulses that are separated by "off" period intervals and that recur at a rate which is distinctive of traffic conditions beyond that given end; combined feed back and special energy apparatus installed at the opposite end of said section and including a source of trackway energy, a code following track relay, a code repeating device for repeatedly connecting the section rails first to said track relay and then to

5 said energy source, a circuit over which said track relay at times controls said device, and code producing means for at other times causing said device to operate at a rate which is distinctive of traffic conditions beyond said opposite section end; means effective under vacant conditions of said section for placing said opposite end code repeating device under the control of said track relay whereby the responses of that relay to the said master code energy that is received over the section rails from said given section end operate said device in a manner which causes said opposite end source to supply the section rails with feed back energy during the "off" periods of the received master code; means effective under occupied conditions of said section for placing said opposite end code repeating device under the control of said code producing means whereby to cause said opposite end source then to supply the section rails with special energy in the form of pulses that recur at a rate which is distinctive of traffic conditions beyond said opposite section end; traffic governing apparatus controlled by the rail transmitted pulses of said master code energy; other traffic governing apparatus controlled by the rail transmitted pulses of said feed back energy; and further traffic governing apparatus controlled by the rail transmitted pulses of said special energy.

17. In combination, a control circuit that includes a pair of conductors which normally are capable of transmitting energy between given and opposite ends of the circuit but which at times are rendered incapable of such transmission, master code equipments positioned at said given and opposite ends of said circuit and selectively operable to supply said circuit conductors with master code energy in the form of pulses that are separated by "off" period intervals and that recur at one or another of a plurality of distinctive rates, feed back equipments also positioned at said given and opposite circuit ends and likewise selectively operable further to supply said circuit conductors with feed back energy in the form of pulses that recur in step with the "off" periods of said supplied master code and that are of positive polarity at times and of negative polarity at other times, means effective under certain conditions for placing in operation the said master code equipment which is at said given end of the circuit and the said feed back equipment which is at said opposite end thereof, means effective under other conditions for placing in operation the said master code equipment which is at said opposite end of the circuit and the said feed back equipment which is at said given end thereof, traffic governing apparatus controlled by the circuit transmitted pulses of said master code energy, and other traffic governing apparatus controlled by the circuit transmitted pulses of said feed back energy.

18. In combination, a control circuit that includes a pair of conductors which normally are capable of transmitting energy between given and opposite ends of the circuit but which at times are rendered incapable of such transmission, master code equipments at said given and opposite circuit ends selectively connectible with said circuit conductors and operable to supply those conductors with master energy in the form of recurring pulses that are separated by "off" period intervals, feed back equipments also at said given and opposite circuit ends likewise selectively connectible with said circuit conductors and operable further to supply those conductors

with feed back energy in the form of pulses that are controlled by the circuit transmitted pulses of said master energy and that recur in step with the "off" period intervals of that master energy, means effective under certain conditions for connecting said circuit conductors with the said master code equipment at said given circuit end and with the said feed back equipment at said opposite circuit end, means effective under other conditions for connecting said section rails with the said master code equipment at said opposite circuit end and with the said feed back equipment at said given circuit end, traffic governing apparatus controlled by the circuit transmitted pulses of said master code energy, and other traffic governing apparatus controlled by the circuit transmitted pulses of said feed back energy.

19. In combination with a stretch of two-direction running railway track that includes adjoining first and second track sections, a first direction signal positioned at the junction of said sections to govern the passage of trains from said first section into said second section, a second direction signal positioned at said junction to govern the passage of trains from said second section into said first section, a code following track relay also installed at said junction, decoding apparatus associated with and governed by said track relay, signal control circuits which include contacts of said apparatus and over which operating current may be supplied to one or the other of said two signals, means effective during the passage of first direction traffic through said stretch for connecting said signal control circuits with said first direction signal only and said track relay with the rails of said second section only and for supplying those rails with coded energy which is distinctive of traffic conditions beyond the remote end of that second section, and means effective during the passage of second direction traffic through said stretch for connecting said signal control circuits with said second direction signal only and said track relay with the rails of said first section only and for supplying those rails with coded energy which is distinctive of traffic conditions beyond the remote end of that first section.

20. In combination, a stretch of two-direction running railway track, adjoining first and second track sections forming a part of said stretch, a first direction signal positioned at the junction of said sections to govern the passage of trains from said first section into said second section, a second direction signal positioned at said junction to govern the passage of trains from said second section into said first section, signal control means also installed at said junction and including a code following track relay together with decoding apparatus that is governed thereby and signal control circuits that include contacts of said apparatus, means effective during the passage of first direction traffic through said stretch for connecting said signal control circuits in energy supplying relation with said first direction signal only and said track relay in energy receiving relation with the rails of said second section only, means also effective during the passage of first direction traffic through said stretch for supplying the rails of said second section with coded energy which is distinctive of traffic conditions beyond the remote end of that section, means effective during the passage of second direction traffic through said stretch for connecting said signal control circuits with said second direction signal only and said track relay with the rails of said first section only and for supplying those first section rails with coded energy which is distinctive of traffic conditions therebeyond, an approach relay for maintaining said signal control circuits deenergized at all times except when the relay is released, means effective during the passage of first direction traffic through said stretch

5 the rails of said first section only, and means also effective during the passage of second direction traffic through said stretch for supplying the rails of said first section with coded energy which is distinctive of traffic conditions beyond the remote end of that section.

21. In combination, a stretch of two-direction running railway track, adjoining first and second track sections forming a part of said stretch, a first direction signal positioned at the junction of said sections to govern the passage of trains from said first section into said second section, a second direction signal positioned at said junction to govern the passage of trains from said second section into said first section, signal control means also installed at said junction and including a code following track relay together with decoding apparatus that is governed thereby and signal control circuits that include contacts of said apparatus, a traffic directional relay positioned at said junction and selectively responsive to first direction trains and to second direction trains that enter said stretch, means including contacts of said traffic directional relay and effective whenever said stretch is carrying first direction traffic for connecting said signal control circuits with said first direction signal only and said track relay with the rails of said second section only, means also effective during the passage of first direction traffic through said stretch for supplying the rails of said second section with coded energy which is distinctive of traffic conditions beyond the remote end of that section, further means including said traffic directional relay and effective whenever said stretch is carrying second direction traffic for connecting said signal control circuits with said second direction signal only and said track relay with the rails of said first section only, and means also effective during the passage of second direction traffic through said stretch for supplying the rails of said first section with coded energy which is distinctive of traffic conditions beyond the remote end of that section.

22. In combination, a stretch of two-direction running railway track, adjoining first and second track sections forming a part of said stretch, a first direction signal and a second direction signal positioned at the junction of said sections respectively to govern the passage of trains from said first section into said second section and from said second section into said first section, signal control means also installed at said junction and including a code following track relay together with decoding apparatus that is governed thereby and signal control circuits that include contacts of said apparatus, means effective during the passage of first direction traffic through said stretch for connecting said signal control circuits with said first direction signal only and said track relay with the rails of said second section only and for supplying those second section rails with coded energy which is distinctive of traffic conditions therebeyond, means effective during the passage of second direction traffic through said stretch for connecting said signal control circuits with said second direction signal only and said track relay with the rails of said first section only and for supplying those first section rails with coded energy which is distinctive of traffic conditions therebeyond, an approach relay for maintaining said signal control circuits deenergized at all times except when the relay is released, means effective during the passage of first direction traffic through said stretch

for holding said approach relay picked up at all times except when said first section is occupied whereby said first direction signal is energized only when being approached by a first direction train, and means effective during the passage of second direction traffic through said stretch for holding said approach relay picked up at all times except when said second section is occupied whereby said second direction signal is energized only when being approached by a second direction train.

23. In combination, a stretch of two-direction running railway track, adjoining first and second track sections forming a part of said stretch, first direction and second direction signaling equipments positioned at the junction of said sections respectively to govern the passage of trains from said first section into said second section and from said second section into said first section, control means for said equipments also installed at said junction and including a code following track relay together with decoding apparatus that is governed thereby and signal control circuits that include contacts of said apparatus, a traffic directional relay positioned at said junction and selectively responsive to first direction trains and to second direction trains that enter said stretch, means including said traffic directional relay and effective whenever said stretch is carrying first direction traffic for connecting said signal control circuits with said first direction signaling equipment only and said track relay with the rails of said second section only and for supplying those second section rails with coded energy which is distinctive of traffic conditions therebeyond, other means including said traffic directional relay and effective whenever said stretch is carrying second direction traffic for connecting said signal control circuits with said second direction signaling equipment only and said track relay with the rails of said first section only and for supplying those first section rails with coded energy which is distinctive of traffic conditions therebeyond, an approach relay for maintaining said signal control circuits deenergized at all times except when the relay is released, further means effective during the passage of first direction traffic through said stretch for holding said approach relay picked up at all times except when said first section is occupied whereby said first direction signaling equipment is energized only when a first direction train approaches said junction, and further means effective during the passage of second direction traffic through said stretch for holding said approach relay picked up at all times except when said second section is occupied whereby said second direction signaling equipment is energized only when a second direction train approaches said junction.

24. In combination, a section of railway track, means including a coding device at the section exit for supplying the rails of said section with master code energy in the form of recurring pulses that are separated by "off" period intervals, means effective under vacant conditions of said section for further supplying said rails with feed back energy in the form of pulses that recur in step with said master code "off" periods and that are of normal polarity at times and of reverse polarity at other times, a pair of code following track relays also installed at said section exit and respectively operable by normal polarity energy and by reverse polarity energy, means

controlled by said coding device for connecting said track relays in energy receiving relation with said rails during said master code "off" periods whereby as long as said track section remains vacant both of those track relays receive said pulses of feed back energy and one or the other of them is recurrently picked up by those received pulses, an approach relay having a slowness of release which is sufficient to bridge the spacing between consecutive pulses of said feed back energy, a first energizing circuit for said approach relay which is completed in step with all of the said recurrent pick-ups of a given one of said track relays, a second energizing circuit for said approach relay which is completable only when said given track relay is released and which then at certain times is completed in step with the said recurrent pick-ups of the other one of said track relays, a third energizing circuit for said approach relay which also is completable only when said given track relay is released and which then at further times is recurrently completed over a contact of said coding device, and traffic governing apparatus controlled by said approach relay and rendered active when that relay becomes released.

25. In combination, a section of railway track, means including a coding device at the section exit for supplying the rails of said section with master code energy in the form of recurring pulses that are separated by "off" period intervals, means effective under vacant conditions of said section for further supplying said rails with feed back energy in the form of pulses that recur in step with said master code "off" periods and that are of normal polarity at times and of reverse polarity at other times, a pair of code following track relays also installed at said section exit and respectively operable by normal polarity energy and by reverse polarity energy, means controlled by said coding device for connecting said track relays in energy receiving relation with said rails during said master code "off" periods whereby as long as said track section remains vacant both of those track relays receive said pulses of feed back energy and one or the other of them is recurrently picked up by those received pulses, an approach relay having a slowness of release which is sufficient to bridge the spacing between consecutive pulses of said feed back energy, a first energizing circuit for said approach relay which includes a front contact of a given one of said track relays and which is completed in step with all of the said recurrent pick-ups of that track relay, a second energizing circuit for said approach relay which includes a back contact of said given track relay and which under certain released conditions of that given relay is completed in step with the said recurrent pick-ups of the other one of said track relays, a third energizing circuit for said approach relay which also includes a back contact of said given track relay and which under further released conditions of that given relay is recurrently completed over a contact of said coding device, and traffic governing apparatus controlled by said approach relay and rendered active when that relay becomes released.

26. In combination, a section of railway track, a source of trackway energy and a code following track relay at a given end of said section, a similarly located coding device provided with a driving circuit and having a contact that is slightly slow in releasing, circuits over which said contact connects the section rails in energy receiv-

ing relation with said source when picked up and in energy supplying relation with said track relay when released, a code transmitter which at times controls the said coding device driving circuit and thereby causes said trackway source then to supply said section rails with recurring pulses of first direction master code energy, means located at the opposite end of said section and effective at other times for supplying the section rails with second direction master code energy in the form of recurring "on" period pulses that are separated by "off" period intervals and that recurrently pick up the said track relay at the given section end, further means effective at those other times for energizing the said driving circuit of said coding device in step with the said pick-ups of said track relay whereby to cause said trackway source then further to supply the section rails with feed back energy in the form of pulses that recur in step with the "off" periods of said second direction master code, traffic governing apparatus controlled by said first direction master energy, other traffic governing apparatus controlled by said second direction master energy, and further traffic governing apparatus controlled by said feed back energy.

27. In combination, a section of railway track, a source of trackway energy and a code following track relay at a given end of said section, a similarly located coding device provided with a driving circuit and having a contact that is slightly slow in releasing, circuits over which said contact connects the section rails in energy receiving relation with said source when picked up and in energy supplying relation with said track relay when released, a code transmitter which at times controls the said coding device driving circuit and thereby causes said trackway source then to supply said section rails with recurring pulses of first direction master code energy, means located at the opposite end of said section and effective at other times for supplying the section rails with second direction master code energy in the form of recurring "on" period pulses that are separated by "off" period intervals and that recurrently pick up the said track relay at the given section end, further means effective at those other times for energizing the said driving circuit of said coding device in step with the said pick-ups of said track relay whereby to cause said coding device to pick up its said contact during each of said master code "on" periods and there to hold it until after the beginning of the succeeding "off" code period, still further means effective at said other times for keeping said track relay connected with the section rails for the full continuance of each of said "on" periods and for preventing the picked up contact of said coding device from connecting said trackway source with said section rails until the beginning of the said succeeding "off" code period whereby said source is caused then further to supply said rails with a pulse of feed back energy during the early portion of each of said second direction master code "off" periods, traffic governing apparatus controlled by said first direction master energy, other traffic governing apparatus controlled by said second direction master energy, and further traffic governing apparatus controlled by said feed back energy.

28. In combination with adjoining first and second sections of railway track, means at the junction end of said first section for supplying the first section rails with master code energy

5 in the form of recurring pulses that are separated by "off" period intervals, means located at the remote end of said first section and operated by the there received pulses of said master code energy for further supplying said first section rails with feed back energy in the form of pulses which recur in step with said master code "off" periods and which have normal polarity at certain times and reverse polarity at other times, 10 a selector relay installed at the junction end of said second section and controlled by the pulses of said first section feed back energy which are received at said first section junction end, means at the remote end of said second section for supplying the second section rails with master code energy in the form of recurring pulses that are separated by "off" period intervals, means located at said second section junction end and operated by the there received pulses of said second section master code energy for further supplying said second section rails with pulses of feed back energy which recur in step with the "off" periods of said second section master code, means including said selector relay for causing the said pulses of second section feed back energy to have normal polarity when said received pulses of first section feed back energy are of normal polarity and to have reverse polarity at all other times, and traffic governing apparatus controlled by said pulses of second section feed back energy and selectively responsive according as those pulses are of normal or reverse polarity.

29. In combination with adjoining first and second sections of railway track, means at the junction end of said first section for supplying the rails thereof with master code energy in the form of recurring pulses that are separated by "off" period intervals, means located at the remote end of said first section and operated by the there received pulses of said master code energy for further supplying said first section rails with feed back energy in the form of pulses which recur in step with said master code "off" periods and which have normal polarity at certain times and reverse polarity at other times, 35 a code following track relay located at said first section junction end and operated only by the normal polarity pulses of said feed back energy which are there received, a polarity selector relay at the junction end of said second section which is controlled by said first section track relay and which is picked up when that relay is following code and released at all other times, means at the remote end of said second section for supplying the rails thereof with master code energy in the form of recurring pulses that are separated by "off" period intervals, means located at said second section junction end and operated by the there received pulses of said second section master code energy for further supplying said second section rails with pulses of feed back energy which recur in step with the "off" 40 periods of said second section master code, means including said selector relay for causing the polarity of said second section feed back pulses to be normal when that relay is picked up and reversed when that relay is released, and traffic governing apparatus controlled by said pulses of second section feed back energy and selectively responsive according as those pulses are of normal or reverse polarity.

30. In combination, a stretch of railway track which includes adjoining first and second sections and through which traffic passes in the

direction of from said first to said second section, means at the remote end of said second section for supplying the rails thereof with master code energy in the form of recurring pulses that are separated by "off" period intervals, a code following track relay at the junction end of said second section which is connected with said rails and which is picked up by each of the there received pulses of said master code energy and released during each of said "off" periods of that received code, a similarly located source of feed back energy, a slow release impulse relay which is controlled by said track relay and which responds to the said pick-ups and releases thereof in such manner that during each of the said "off" periods of the received master code it transfers the said connection of the second section rails from said track relay to said feed back source and thereby causes those rails to be supplied with pulses of feed back energy which recur in step with said "off" periods, a selector relay at said second section junction end which when picked up causes said thus supplied pulses of feed back energy to have normal polarity and which when released causes those pulses to have reverse polarity, means responsive to traffic conditions in and beyond said first section for holding said selector relay picked up at times and for allowing it to release at other times, and traffic governing apparatus controlled by said pulses of second section feed back energy and selectively responsive according as those pulses are of normal or reverse polarity.

31. In combination, a stretch of railway track which includes a pair of adjoining track sections and through which traffic may pass in either direction, a traffic directional relay installed at the junction of said track sections and provided with first and second operating windings together with contacts which shift from a first to a second position when said first winding is energized and from said second to said first position when said second winding is energized, energizing circuits for said first and second windings which include one of said relay contacts and which respectively are set up only when that contact occupies its said first position and only when that contact occupies its said second position, means rendered effective by each first direction train that comes into said stretch at a time when said first winding energizing circuit is set up for completing that circuit and thereby shifting all of said relay contacts from said first to said second position, means controlled by other of said traffic directional relay contacts for now preventing said second winding energizing circuit from being completed until after the first direction train leaves said stretch, means rendered effective by each second direction train that comes into said stretch at a time when said second winding energizing circuit is set up for completing that circuit and thereby shifting all of said relay contacts from said second to said first position, means also controlled by said other traffic directional relay contacts for now preventing said first winding energizing circuit from being completed until after the second direction train leaves said stretch, and traffic governing apparatus controlled by the said contacts of said traffic directional relay.

32. In combination, a stretch of railway track which includes adjoining first and second track sections and through which traffic may pass either in a first direction of from said first to said second section or in a second direction of from

said second to said first section, a traffic directional relay installed at the junction of said track sections and provided with first and second operating windings together with contacts which shift from a first to a second position when said first winding is energized and from said second to said first position when said second winding is energized, energizing circuits for said first and second windings which include one of said relay contacts and which respectively are set up only when that contact occupies its said first position and its said second position, a train detecting relay also at said section junction, coded track circuit means of which further of said traffic directional relay contacts form a part for normally holding said detecting relay picked up and for allowing it to release upon entry of a second direction train into said stretch at a time when said further contacts occupy their said first positions or upon entry of a first direction train into said stretch at a time when those further contacts occupy their said second position, a contact of said train detecting relay which when released as aforesaid completes the particular one of said traffic directional relay winding energizing circuits which then is set up and thereby shifts said traffic directional relay contacts to the opposing position, further means controlled by said traffic directional relay contacts for preventing the now set up opposing winding energizing circuit from being completed until after the detecting relay releasing train leaves said stretch and an opposing train enters thereinto, and traffic governing apparatus controlled by still further of said contacts of the traffic directional relay.

33. In combination: a stretch of railway track which includes adjoining first and second track sections and through which traffic may pass either in a first direction of from said first to said second section or in a second direction of from said second to said first section; a traffic directional relay installed at the junction of said track sections and provided with first and second operating windings together with contacts which shift from a first to a second position when said first winding is energized and from said second to said first position when said second winding is energized; energizing circuits for said first and second windings which include one of said relay contacts and which respectively are set up only when that contact occupies its said first position and its said second position; a train detecting relay also at said section junction; coded track circuit means of which further of said traffic directional relay contacts form a part for normally holding said detecting relay picked up and for allowing it to release upon entry of a second direction train into said stretch at a time when said further contacts occupy their said first position, or upon entry of a first direction train into said stretch at a time when said further contacts are in said second position, or upon advancement of a second direction train into said first section when said further contacts are in the second position, or upon advancement of a first direction train into said second section when said further contacts are in the first position; a back contact of said train detecting relay which at proper times completes the particular one of said traffic directional relay winding energizing circuits which then is set up and thereby shifts said traffic directional relay contacts to the opposing position; a stick relay at said section junction which also is governed by said coded track circuit means

and which prevents the completion of either of said traffic directional relay winding circuits whenever a first direction train advances into said second section or whenever a second direction train advances into said first section; further means controlled by said traffic directional relay contacts for preventing whichever of said winding energizing circuits is newly set up as aforesaid from being completed until after the set-up producing train leaves said stretch and an opposing train enters thereinto; and traffic governing apparatus controlled by still further of said contacts of the traffic directional relay.

34. In combination, a stretch of railway track which includes adjoining first and second track sections and through which traffic may pass either in a first direction of from said first to said second section or in a second direction of from said second to said first section, means rendered effective by each first direction train that comes into said stretch for supplying to each of said first and second sections at the first direction exit end thereof master code trackway energy in the form of recurring pulses that are separated by "off" period intervals and for further impressing upon the rails of each of those sections at the opposite end thereof feed back energy in the form of pulses that recur in step with said master code "off" periods, means rendered effective by each second direction train that comes into said stretch for impressing master code energy upon the rails of each of said second and first sections at the second direction exit end thereof and for further impressing "off" period pulses of feed back energy upon the rails of each section at the opposite end thereof, a master code responsive track relay positioned at the junction of said two sections and operated by the said pulses of master code energy that there are received from said second section rails during passage of first direction traffic through said stretch and from said first section rails when the stretch carries second direction traffic, a feed back responsive track relay also positioned at said junction but operated by the said pulses of feed back energy that there are received from said first section rails during passage of first direction traffic through said stretch and from said second section rails when the stretch carries second direction traffic, a normally released stick relay also installed at said section junction and provided with a pick-up circuit and with a stick circuit, control means for said pick-up circuit which include both of said master and feed back track relays and which complete the pick-up circuit whenever said feed back track relay becomes continuously deenergized at a time when said master track relay is following code whereby said stick relay is picked up by each movement past its location of either a first direction train or a second direction train, control means for said stick circuit which include said master track relay and a front contact of said stick relay and which complete the stick circuit whenever the master track relay ceases to follow code at a time when the stick relay is already picked up whereby the relay hold-up period is prolonged until both of said track sections have become vacated, and traffic governing apparatus controlled by said stick relay.

35. In combination, a stretch of railway track which includes adjoining first and second track sections and through which traffic may pass either in a first direction of from said first to said second section or in a second direction of from said second to said first section, means rendered effective by each first direction train that comes into said stretch for supplying to each of said first and second sections at the first direction exit end thereof master code trackway energy in the form of recurring pulses that are separated by "off" periods and for further impressing upon the rails of each of those sections at the opposite end thereof feed back energy in the form of pulses that recur in step with said master code "off" periods, means rendered effective by each second direction train that comes

into said stretch for impressing master code energy upon the rails of each of said second and first sections at the second direction exit end thereof and for further impressing "off" period pulses of feed back energy upon the rails of each section at the opposite end thereof, a master code responsive track relay positioned at the junction of said two sections and operated by the said pulses of master energy that there are received from said second section rails during passage of first direction traffic through said stretch and from said first section rails when the stretch carries second direction traffic, a feed back responsive track relay also positioned at said section junction but operated by the said pulses of feed back energy that there are received from said first section rails during passage of first direction traffic through said stretch and from said second section rails when the stretch carries second direction traffic, a normally released stick relay also installed at said section junction and provided with a pick-up circuit and with a stick circuit, control means for said pick-up circuit which include both of said master and feed back track relays and which complete the pick-up circuit whenever said feed back track relay becomes continuously deenergized at a time when said master track relay is following code whereby said stick relay is picked up by each movement past its location of either a first direction train or a second direction train, control means for said stick circuit which include said master track relay and a front contact of said stick relay and which complete the stick circuit whenever the master track relay ceases to follow code at a time when the stick relay is already picked up whereby the relay hold-up period is prolonged until both of said track sections have become vacated, and traffic governing apparatus controlled by said stick relay.

36. In combination: a stretch of railway track which includes adjoining first and second track sections and through which traffic may pass either in a first direction of from said first to said second section or in a second direction of from said second to said first section; means rendered effective by each first direction train that comes into said stretch for (1) supplying the remote end of said second section with master code trackway energy in the form of recurring pulses that are separated by "off" period intervals, (2) repeating into the rails of said first section each pulse of said second section master code energy that is received at the section junction from the second section rails, (3) further supplying the remote end of said first section with recurring pulses of feed back energy that coincide with the "off" period intervals of said repeated master code, and (4) repeating into the rails of said second section in time coincidence with the "off" period intervals of said second section master code the pulses of said first section feed back energy that are received at said section junction from said first section rails; means rendered effective by each second direction train that comes into said stretch for (1) supplying the remote end of said first section with master code trackway energy in the form of recurring pulses that are separated by "off" period intervals, (2) repeating into the rails of said second section each pulse of said first section master code energy that is received at said section junction from the first section rails, (3) further supplying the remote end of said second section with recurring pulses of feed back

energy that coincide with the "off" period intervals of said repeated master code, and (4) repeating into the rails of said first section in time coincidence with the "off" period intervals of said first section master code the pulses of said second section feed back energy that are received at said section junction from said second section rails; traffic governing apparatus controlled by the rail transmitted pulses of said repeated master code energy; and other traffic governing apparatus controlled by the rail transmitted pulses of said repeated feed back energy.

37. In combination, a stretch of railway track which includes adjoining first and second track sections and through which traffic passes in the direction of from said first to said second section, means at the remote end of said second section for supplying the rails thereof with master code energy in the form of recurring pulses that are separated by "off" period intervals; a code following track relay connected at the junction end of said second section with said second section rails and operated by the there received pulses of said master code energy, a source of feed back energy also at said second section junction end, a similarly located impulse relay which is controlled by said track relay and which during each of the "off" periods of said there received master code transfers the connection of the second section rails from said track relay to said feed back source and thereby causes those rails further to be supplied with pulses of feed back energy which recur in step with said "off" code periods, a source of master code energy at the junction end of said first section, means governed by said impulse relay for connecting said source with the rails of said first section each time that said track relay picks up whereby to cause those rails to receive first section pulses of master code energy which correspond to the said recurring second section pulses of master code energy by which said track relay is operated, means located at the remote end of said first section and operated by the there received pulses of said first section master code energy for further supplying said first section rails with feed back energy in the form of pulses that recur in step with the "off" periods of said received master code and that are of normal polarity at times and of reverse polarity at other times, means at the junction end of said first section which distinguish the polarity of the there received pulses of said first section feed back energy, a selector relay at the junction end of said second section which is controlled by said polarity distinguishing means and which causes said there supplied pulses of second section feed back energy to have the same polarity as do said pulses of first section feed back energy, traffic governing apparatus controlled by the rail transmitted pulses of said first section master code energy, and other traffic governing apparatus controlled by the rail transmitted pulses of said second section feed back energy.

38. In combination, a stretch of railway track which includes adjoining first and second track sections and through which traffic passes in the direction of from said first to said second section, means at the remote end of said second section for supplying the rails thereof with master code energy in the form of recurring pulses that are separated by "off" period intervals, means at said section junction for repeating into

the rails of said first section each of the there received pulses of said second section master code energy, means located at the remote end of said first section and operated by the there received pulses of said repeated master code energy for further supplying said first section rails with recurring pulses of feed back energy that coincide with the "off" period intervals of that repeated master code, an approach relay at said section junction which responds to the said pulses of first section feed back energy that are there received and which releases only when the transmission of those pulses over the first section rails is discontinued, and a highway crossing signal positioned at said section junction and provided with an operating circuit which is controlled by said approach relay and which is completed only when that relay becomes released whereby said signal is brought into operation whenever a train enters said first section and is continued in operation as long as any part of the train remains within that section.

39. In combination: a stretch of railway track which includes adjoining first and second track sections and through which traffic may pass either in a first direction of from said first to said second section or in a second direction of from said second to said first section; means rendered effective by each first direction train that comes into said stretch for (1) supplying the remote end of said second section with master code trackway energy in the form of recurring pulses that are separated by "off" period intervals, (2) repeating into the rails of said first section each pulse of said second section master code energy that is received at the section junction from the second section rails, and (3) further supplying the remote end of said first section with recurring pulses of feed back energy that coincide with the "off" period intervals of said repeated first section master code; means rendered effective by each second direction train that comes into said stretch for (1) supplying the remote end of said first section with master code trackway energy in the form of recurring pulses that are separated by "off" period intervals, (2) repeating into the rails of said second section each pulse of said first section master code energy that is received at the section junction from the first section rails, and (3) further supplying the remote end of said second section with recurring pulses of feed back energy that coincide with the "off" period intervals of said repeated second section master code; an approach relay installed at said section junction and energized in step with all of the recurring pulses of said feed back energy that are there received from either of said two sections whereby to be maintained continuously picked up at all times that both of these sections are vacant and to release only when the transmission of said feed back energy is discontinued; and a highway crossing signal positioned at said section junction and provided with an operating circuit that is completed only when said approach relay becomes released whereby said signal is brought into operation wherever a train approaches said junction from either direction and is continued in operation as long as any part of the train remains within the section of said approach.
